PLURAL REGISTER PRINTING CALCULATOR
 Teresio Canevari, deceased, late of Torino, Italy, by
 Annita Gianotti, sole heiress and legal representative,
 Turin, Italy, assignor, by mesne assignments, to Friden,
 Inc., San Leandro, Calif., a corporation of Delaware
 Original application July 3, 1961, Ser. No. 123,085, now
 Patent No. 3,181,786. Divided and this application
 June 24, 1963, Ser. No. 297,478

Claims priority, application Italy, Jan. 5, 1957,
 69/57; July 8, 1957, Patent 565,040
 4 Claims. (Cl. 235—60.27)

This invention relates to printing calculating machines, and particularly to a printing calculating machine which, in addition to the usual functions of addition, subtraction, repeat operation, and total and subtotal taking, will also automatically multiply and divide and accumulate grand totals. This application is a division of the copending application Serial No. 123,085, filed July 3, 1961, now Patent No. 3,181,786, issued May 4, 1965, which application was a continuing application with respect to United States application Serial No. 753,316, filed August 5, 1958, now abandoned, which was a continuation-in-part of United States applications Serial Nos. 701,484, 701,485 and 701,659, filed December 9, 1957, now abandoned, which latter three applications were filed subject to a claim for priority under Italian applications Nos. 69, 70 and 71, filed January 5, 1957, since issued respectively as Patent 565,040, issued July 8, 1957, Patent 565,041, issued July 8, 1957, and Patent 564,394, issued June 14, 1957.

It is among the objects of the present invention to provide a calculating machine of the character indicated, which is operative; in single cycles, to read out and print totals and subtotals; which has at least two accumulative registers and is capable of accumulating grand totals in at least one of these registers and of reading out and printing such grand totals by single-cycle operations; which has a counter register, usable as a multiplier storage unit and as a quotient register, and is capable of back-transferring values from the grand total register to the counter register; which is capable of performing multiplication and division automatically; which is operative to enter a multiplier into the counter, or multiplier storage, register; which has means for predetermining the number of decimal places, or orders, in the product and is operative to automatically discard unwanted decimal places; which automatically clears discarded decimal places from the accumulator; which has mechanism for shifting the primary accumulator, or dividend register, and the counter, or quotient, register in both transordinal directions; which automatically returns the accumulator to the selected decimal position, or alternatively to its leftmost position, before printing out the product; and which utilizes the manual keyboard clearing control for clearing the selector after a multi-cycle operation, such as multiplication.

A further object resides in the provision of a calculating machine of the character indicated, in which the product or the quotient remains in the machine after the corresponding multiplication or division operation and is not printed and cleared out of the machine until the total key or the division total key is operated.

A more general object of the invention resides in the provision of an improved printing calculator and controls therefor.

Other objects and advantages will become apparent from a consideration of the following description and the appended claims in conjunction with the accompanying drawings wherein:

FIG. 1 is a plan view of the base showing the location of the frames, motor, main clutch, shift clutch and the assembled power cam shaft;

FIG. 2 is a right side elevational view of the machine with the covers removed;

FIG. 3 is a perspective view from the upper-right-front, showing the motor, main clutch, shift clutch, and the interconnecting means between the two clutches;

FIG. 4 is a perspective view from the upper-right-rear of the motor power slides and the interlocking slides for the control keys;

FIG. 5 is a perspective view from the upper-left-front showing a detail of the controls for setting the right shift pawl, and the interlock between the right and left shift pawls;

FIG. 6 is a perspective view from the upper-left-front showing a detail of the mechanism for controlling the shift clutch during multiplication;

FIG. 7 is a plan view of the value selection keyboard of the machine and the decimal point selection mechanism;

FIG. 8 is a right vertical section of the value selection mechanism taken on the line 8—8 of FIG. 7;

FIG. 9 is a perspective view from the upper-right-front of the escapement mechanism of the selection mechanism;

FIG. 10 is a rear view taken on the line 10—10 of FIG. 9 and shows the escapement levers in their depressed position;

FIG. 11 is a plan view of the restore mechanism for the selection carriage;

FIG. 12 is a left vertical view taken on the line 12—12 of FIG. 11;

FIG. 13 is a front sectional elevational view of part of the restore mechanism shown in FIG. 11;

FIG. 14 is a plan view of the sensing mechanism for the multiplication unit;

FIG. 15 is a partial right side view of the mechanism shown in FIG. 14;

FIG. 16 is a longitudinal left sectional view taken on the lines 16—16 of FIG. 1, showing the selection, actuators, printing mechanism, and the accumulators of the machine;

FIG. 17 is a partial, left elevational view taken on the line 17—17 of FIG. 1 and shows the actuator drive mechanism;

FIG. 18 is a detail in perspective from the upper-left-front of the shift-control setting levers;

FIG. 19 is a right elevational cross-section of the shiftable accumulator and the storage unit, or the traveling registers;

FIG. 20 is a left vertical view taken on the line 20—20 of FIG. 1 and shows the tens-transfer control mechanism;

FIG. 21 is a left vertical view taken on the line 21—21 of FIG. 1 and shows the pendent aligner mechanism;

FIG. 22 is a right side elevational view of the multiplier storage and traveling accumulator and the control of the credit balance indicator;

FIG. 23 is a perspective view from the upper-right rear of the addition and subtraction levers used in multiplication and division;

FIG. 24 is a right side view of the same levers;

FIG. 25 is a longitudinal right sectional elevation of the addition key and addition control mechanism;

FIG. 26 is a longitudinal right sectional elevation of the subtraction and PRINT ONLY keys and the subtraction control mechanisms;

FIG. 27 is a front elevational view of the total, transfer and addition control keys taken on the line 27—27 of FIG. 7;

FIG. 28 is a top plan view of FIG. 27, as indicated by the line 28—28 of that figure, with the key tops shown in phantom lines to show more clearly the mechanism;

FIG. 29 is a partial longitudinal right sectional elevation of the SUB TOTAL control key and its mechanism;

FIG. 30 is a partial right elevational cross-section of

the credit balance mechanism for the primary accumulator;

FIG. 30A is a perspective view from the upper-right-front showing a detail of the total and subtotal controls of FIGS. 29, 30, 31, 36 and 37;

FIG. 31 is a partial longitudinal right sectional elevation of the TOTAL key and its mechanism;

FIG. 32 is a right elevational view of the grand total accumulator and its connection with the actuators;

FIG. 33 is a partial right elevational cross-section of the pendent control cam and mechanism involved in entering positive values in the grand total accumulator;

FIG. 34 is a similar right elevational cross-section showing the mechanism involved in entering a negative value in the grand total accumulator;

FIG. 35 is an oblique view from the top-front taken on the lines 35—35 of FIG. 34;

FIG. 36 is a partial right elevational cross-section of the SUB GRAND TOTAL control key and its mechanism;

FIG. 37 is a partial right elevational cross-section of the GRAND TOTAL control key and its mechanism;

FIG. 38 is a left side elevational view of the machine with the covers removed;

FIG. 39 is a left side view of the multiplication terminating slide;

FIG. 40 is a top view taken on the line 40—40 of FIG. 39; the rear of the machine is toward the left of the view;

FIG. 41 is a left vertical view taken on the line 41—41 of FIG. 42;

FIG. 42 is a plan view of the bail structure for automatically initiating a clear-keyboard operation after division and multiplication;

FIG. 43 is a partial left elevational view of the latching mechanism of the TOTAL and SUB TOTAL keys operative during left shift for decimal point control;

FIG. 44 is a left elevational detail of parts used for the control of left tabulations;

FIG. 45 is a left elevational detail of the shift initiating linkage;

FIG. 46 is a vertical front detail view taken on line 46—46 in FIG. 44 showing part of the tabulation control mechanism;

FIG. 47 is a top detail view taken on the line 47—47 of FIG. 43; the rear of the machine is toward the left of the view;

FIG. 48 is a left-hand elevational section showing the zero block and print control cams and part of their mechanism, taken on the line 48—48 of FIG. 1;

FIG. 49 is a perspective view from the upper-right-front of part of the multiplier readout and count-entering mechanism for the counter unit;

FIG. 50 is a perspective view from the upper-right-front of one of the slide assemblies of the decimal-point control mechanism;

FIG. 51 is a right elevational cross-section of the paper carriage and its tabulating linkage and its drive;

FIGS. 52, 53 and 53A are perspective views from the upper-left-front of additional slides of the decimal-point control mechanism;

FIG. 54 is a perspective view from the upper-left-rear showing a detail of the repeat mechanism of FIGS. 11, 12 and 13;

FIG. 55 is a left-hand elevational sectional view taken on the line 55—55 of FIG. 1 showing the multiplication keys and related mechanism;

FIG. 56 is a detail of part of the mechanism of FIGS. 44 and 55;

FIG. 57 is a rear elevation showing a detail of FIG. 60;

FIG. 58 is a sectional top view of the shift clutch and the arrangement of power for shifting the primary accumulator; the rear of the machine is toward the left of the view;

FIG. 59 is a rear elevational detail of the feed pawl

associated with the primary accumulator taken on the line 59—59 of FIG. 58;

FIG. 60 is a right vertical sectional view taken on the lines 60—60 of FIG. 58;

FIG. 61 is a plan view of the decimal point mechanism employed in the machine;

FIG. 62 is a front vertical detail of the latch mechanism of the decimal point key and taken on the line 62—62 of FIG. 61;

FIG. 62A is a front vertical detail similar to FIG. 62 showing the parts in a different operated position;

FIG. 63 is a right elevational cross-section of the decimal point key and the excessive decimal eliminating mechanism;

FIG. 64 is a longitudinal right elevational view of the DIV. TOTAL key and its mechanism;

FIG. 65 is a left-hand elevational cross-section of the division control mechanism;

FIG. 66 is a longitudinal right elevational view of the BACK TRANSFER key and its mechanism;

FIG. 67 is a left, elevational, cross-sectional detail of the interlock for the BACK TRANSFER key;

FIG. 68 is a detail in perspective from the upper-left-front of the left shift control setting levers; and

FIGS. 69 and 70 are left vertical details of parts of the division control mechanism.

1. FRAME CONSTRUCTION

With continued reference to the drawings, and particularly to FIG. 1, the main components of the machine frame comprise a flat base plate 100 of generally rectangular shape having therein an opening 101, also of substantially rectangular shape, through which the fixed or grand total accumulator register of the machine is inserted during assembly of the machine. The frame also includes a number of parallel, vertical, frame plates extending perpendicularly up from the base plate 100, 108, an auxiliary frame plate 109 between the plates 102 and 103, a main right-hand frame plate 103, a left-hand bracket plate 104 mounted on, and disposed to the left of, the left-hand plate 102, left-hand and right-hand selection mechanism supporting plates 105 and 106, left-hand and right-hand printing mechanism supporting plates 107 and 108, an auxiliary frame plate 109 between the plates 102 and 105, auxiliary plates 110 and 111 disposed in spaced-apart relationship between the rear portions of the plates 102 and 103, a right-hand bracket plate 112 mounted on, and disposed to the right of, the right-hand frame plate 103, a rear cross plate 113, a front cross plate 114, and a selection lever bracket 115 disposed between plates 105 and 106.

The above members constitute the principal components of the machine frame, but a limited number of smaller plates and brackets will be referred to as the description continues.

2. DRIVE MECHANISM

Referring now to FIGS. 1 to 4, inclusive, the power supply mechanism of the machine comprises an electric motor 120 rigidly mounted on the rear portion of the base plate 100 and having a motor shaft 121 extending through, and projecting from, both ends of the motor. The motor speed is controlled by an electric governor mechanism 122 in a manner well-known to the art. The motor energization is controlled by a motor switch 123 (FIG. 2) mounted on the rear portion of the right-hand frame member 103 of the machine. This switch is opened and closed by a very small movement of its operating lever 124, the lever being moved forward, as viewed in FIG. 2, to close the switch. The switch is electrically connected into the governor circuit along with suitable resistance and condenser components, well-known to the art, to provide the desired operating circuit.

The motor shaft 121 extends through left-hand and right-hand bearings 125 and 126 mounted on the frame plates 102 and 103, respectively. This shaft carries near its right-hand end, a small drive gear 127 positioned between the plates 103 and 112, and near its left-hand end a small drive gear 128 is positioned between the plates 102 and 104.

Referring particularly to FIG. 3, the right-hand drive gear 127 of the motor shaft 121 meshes with, and drives the larger portion of a compound gear journaled on a stub shaft 134 and comprising a large gear portion 129 and a small gear portion 130 concentric with the larger gear portion. The gear portion 130 meshes with a large gear 131, which, in turn, meshes with a small idler, or reversing, gear 132 disposed at the side of the gear 131 substantially opposite the gear 130. The reversing gear 132 meshes with a large gear 133, which is shown in phantom in FIG. 3, and which is journalled for free rotation on the right-hand end portion of the main drive shaft 135. With this arrangement, the gear 133 is driven from the motor shaft 121 at a greatly reduced speed in a clockwise direction, as seen in FIGS. 2 and 3.

A ratchet wheel 136 secured to, and concentric with, the gear 133 is also journalled on the main shaft 135 and constitutes the driving element of the main drive clutch of the machine. The gears 127, 129, 130, 131, 132 and 133 are all disposed between, and supported by, the frame plates 103 and 112.

The main drive clutch is similar in construction and operation to the clutch described in Friden Patent No. 2,229,889 and shown in FIGS. 4 and 5 thereof. Two clutch disks 137 and 138 (FIG. 1) are mounted in spaced-apart relationship on, and drivingly connected to, the main drive shaft 135 at respectively opposite sides of the clutch ratchet 136. A clutch pawl 139 (FIG. 3) is disposed between, and pivotally mounted on, the disks 137 and 138 at one end of the pawl by a pivotal mounting 140 and this pawl extends around a portion of the ratchet 136. A tension spring 142, connected between the free end of the pawl and the clutch disk 137, urges the pawl toward the ratchet 136. The pawl is provided intermediate its length with a ratchet-engaging tooth 141, which engages with a tooth of the ratchet 136 to drivingly connect the gear 133 to the main drive shaft 135 when the pawl 139 is free to be moved by the spring 142 into engagement with the ratchet 136. A transverse shoulder 143 is provided on the outer portion of the pawl 139 near the free end of the pawl. A main control arm 150 for the main clutch is rockably mounted at its lower end on a fixed pivot 146 and has intermediate its length a detent formation 147 engageable with the pawl shoulder 143 to hold the pawl 139 out of engagement with the ratchet 136 and disable the clutch. A roller 149 is carried by the arm 150 on the roller pin, or axle, 148 (FIG. 4) and rides on the peripheral edge of the clutch disk 137. This disk is provided with a single low portion of limited angular extent in which the roller 149 rests when the main shaft of the machine is in full-cycle position. Thus the arm 150 is rockable, counter-clockwise as seen in FIG. 3, for disengaging detent 147 from pawl shoulder 143 for thereby permitting tooth 141 to engage ratchet 136 for enabling the clutch for starting a machine cycle. This counter-clockwise rocking of arm 150, through a link 160 (FIG. 2), also closes switch 123 for energizing the motor 120. A machine cycle consists of one full rotation of the main drive shaft 135. Once a machine cycle has started, the roller 149 (FIG. 3) rides out of the low portion and on to the high portion of the cam disk 137 and maintains the motor switch 123 closed until the cycle is completed so that the motor can stop only in the full-cycle position of the main drive shaft. As roller 149 drops into the low portion of cam disk 137 just before the end of the machine cycle, detent 147 moves into position to intercept shoulder 143 of the

pawl 139 for stopping it, and for thereby both disengaging pawl tooth 141 from ratchet 136 and stopping the rotation of disk 137 and shaft 135. This position of shaft 135, in which the clutch is disabled, is called the "home" position, or the "full-cycle" position.

The right-hand clutch and switch operating slide 151 (FIG. 2) is connected at its rear end to the upper extension of the control arm 150 by a rigid link 152 and pivotal connection 153. At its front end, the slide is pivotally connected to the upper end of an arm 154 (FIG. 4) projecting up from the right-hand end of a shaft 155 which extends transverse the front portion of the machine. Arm 154 is adjustably clamped by a screw 154a to an arm 154b which is fixed to shaft 155. Intermediate its length, the slide 151 is provided with upward and forward inclined notches 156 and 157 into which pins 158 and 159, projecting from the stems of the PRINT ONLY key 304 and the subtract (−) key 303, respectively (see also FIG. 26), are receivable to move the slide forward when either one of these keys is depressed. Forward movement of the slide 151 will rock the main clutch control arm 150 to release the clutch dog 139 and engage the main drive clutch to cycle the machine.

The link 160 (FIG. 2) is pivotally connected at its forward end to the upper extension of the clutch control arm 150, and extends rearward from this clutch control arm. At its rear end, this link is provided with a laterally offset foot 161 having therein a notch receiving the upper end portion of the switch control lever 124 so that when the link 160 is shifted forward, it closes the motor switch. This link is supported, near its rear end, on a pin 162 which is mounted on the frame plate 103 and extends through a longitudinal slot in the rear end portion of the link 160.

Referring to FIG. 4, an inner, left-hand clutch and switch-operating slide 163 is slidably supported at its rear end by a rod 164 extending through a notch in the rear end portion of the slide. At its front end, this slide is pivotally connected to the upper end of an arm 165, which also extends up from the shaft 155, and is adjustably clamped to an arm 165b which is rigid on the shaft.

The slide 163 is provided with upward and rearward inclined notches 170 and 171 which respectively receive pins 172 and 173 to move the slide forward. The pin 172 projects laterally from the stem of the multiplying (=) key 307 of the machine, and the pin 173 projects laterally from the stem of the multiplier entry (×) key 306, which keys will be later described in detail.

An outer, left-hand, switch-operating slide 175 is disposed parallel and to the left of the slide 163 and is supported at its rear end by the rod 164 received in a notch in the rear end portion of the slide. At its front end, the slide 175 is pivotally connected to the upper end of a bellcrank 176, which is also fixed to, and extends up from, the shaft 155. The slide 175 is provided with upward and forward inclined notches 177, 178 and 179 in position to respectively receive pins 180, 181 and 182 to move this slide forward. The pin 180 projects laterally from the stem of the division (÷) key 310 of the machine (see also FIG. 65), the pin 181 projects laterally from the stem of the ENTER DIVD key 309, and the pin 182 projects laterally from the error, or KEYBOARD CLEAR, key 308 of the machine.

Forward movement of the slide 163 or the slide 175, by rocking the shaft 155, moves the slide 151 forward and thus causes the main drive clutch of the machine to engage, and closes the motor switch 123, thus causing the machine to cycle.

A shaft 183 extends transverse the forward portion of the machine above the shaft 155 and is rockably supported in the left-hand and right-hand side plates of the machine frame. An arm 184 is fixed to, and projects

up from, the right-hand end of the shaft 183 (FIGS. 2, 4 and 26). A pin 185 projects from the upper end of the arm 184 through an aperture in the front end portion of a blocking bar 186 for the PRINT ONLY, subtract (—), and addition (+) keys 304, 303 and 302 of the machine. The blocking bar 186 is supported by links 166 and 167 (FIG. 26) and this bar carries upward projecting abutment formations 187 and 188 (FIG. 4) intermediate its length and an abutment formation 189 at its forward end. A pin 190 projects laterally from the stem of the PRINT ONLY key above the abutment formation 187. A pin 191 projects from the stem of the subtract (—) key above the abutment formation 188. The abutment formations 187, 188 are provided with flat top edges, which are movable, under the pins 190 and 191, to block the PRINT ONLY and subtract (—) keys when the blocking slide 186 is moved rearward, and the abutment formation 189 is provided with a flat top edge which is movable under a pin 204 (FIG. 25) on the addition (+) key to block the addition key when the blocking slide is moved rearward. The abutment formations 187 and 188 are provided with inclined upper rear corners so that the slide will be moved forward when either the PRINT ONLY or the subtraction (—) key is depressed. An inner left-hand blocking slide 192 (FIG. 4) is slidably supported at its rear end on the rod 164 and is pivotally connected at its forward end to the lower end of an arm 193 fixed to, and extending down from, the shaft 183. This blocking slide is provided with upward projecting abutment formations 194 and 195 which cooperate with the key stem pins 172 and 173 of keys 307 and 306, respectively. Each of these abutment formations has a flat top edge effective to engage under the associated pin and block the corresponding key when the slide 192 is moved rearward, and has a beveled upper rear corner which is engaged by the associated pin when the corresponding key is depressed, to move the slide forward.

An outer left-hand blocking slide 196 (FIGS. 4 and 65) is slidably supported at its rear end on the rod 164, and is pivotally connected at its forward end to the lower end of an arm 197 mounted on, and projecting down from, the shaft 183. This blocking slide has upward projecting abutment formations 198, 199 and 200 cooperating with the key stem pins 180, 181 and 182, respectively, of the division (÷) key 310, ENTER DIVD key 309 and the CLEAR KEYBOARD key 308. These abutment formations have flat top edges which move under the corresponding pins and block the associated keys when the slide is moved forward, and have beveled upper front corners so that the slide is moved rearward whenever one of the associated control keys is depressed. It will also be noted that each of the clutch and switch controlling slides 151, 163 and 175 is provided at the rear side of each of the notches therein with a flat abutment surface, as indicated at 200a, which will move under the associated pin, and block the corresponding key when the control slide is moved forward.

As shown in FIGS. 16, 27 and 29, a yoke 826 is mounted on the shaft 155 for a SUB TOTAL key 315, and a similar individual yoke is mounted on this shaft 155 for each of the other total keys 313, 314, 316 and 318 of the machine. Each of these yokes extends up from the shaft 155 and has an arm, such as 825, inclined up and forward against which a pin, such as 824, projecting from the corresponding key stem, pushes to rock the yoke and the shaft 155 in a counter-clockwise direction, as viewed in FIGS. 16 and 29, to thereby move the control slide 151 forward and establish an operating cycle of the machine. Each yoke, such as 826, has a second, or interlock, arm, such as 825a, which will swing over the pin, such as 824, of the key that is depressed to hold the key down, or alternatively, will swing under the pin of a key that has not been depressed, for preventing its depression. As is shown in FIG. 67, the BACK TRANSFER key

317 has a yoke 847, which is similar to yoke 826 on shaft 155, but which has only an interlock arm 849 cooperating with pin 1521 on the stem 1520 of key 317. A slotted bracket 828 (FIG. 27) fixed to frame piece 817, embraces each pin, such as 824, for guiding it. Blocking arms, one for each of the five total keys and the BACK TRANSFER key 317, as indicated at 208 (FIGS. 16 and 27), are mounted on, and extend up from, the shaft 183. Each of these arms has a notch, as indicated at 209, arranged to receive a square stud 210 on the associated key stem when the arm is in centered position. However, when the arms are rocked by angular or rotational movement of the shaft 183 either clockwise or counterclockwise, the square stud 210 will strike the blocking surface alongside the notch 209, thus blocking the total keys from operation.

The addition (+) key 302 through a pin 721 (FIGS. 25 and 27), cooperates with a yoke member 205, similar to 826 shown in FIG. 16, and rocks the shaft 155 in a counter-clockwise direction, as viewed in FIG. 4, when the addition key is depressed. This rocking of the shaft 155 by depression of the addition key moves the control slides 151, 163 and 175 forward, but the addition key does not move the blocking bars 186, 192 and 196. It will be noted that the blocking bars 186, 192 and 196 are resiliently urged to their neutral, or nonblocking, position by a spring-centering device 202 (FIG. 2) mounted on the frame plate 106 and engaging a pin 203 on the slide 186.

The interconnections among the keys thus far described serve two purposes. First, all of these keys, except the BACK TRANSFER key 317, that is, the keys 302, 303, 304, 306, 307, 308, 309, 310, 313, 314, 315, 316 and 318, are arranged to actuate the slide 151 for enabling the main clutch and for closing the switch 123. Second, these connections perform interlocking functions. Thus no key can be depressed after slide 151 has moved forward to actuate the switch and clutch, and only the BACK TRANSFER key 317 can be depressed without so moving slide 151. Also, because bars 192 and 196, connected to the left end of shaft 183, move rearward when bar 186 at the right end of that shaft moves forward, no key in the right group (303 and 304) can be depressed simultaneously with any key in the left group (306, 307, 308, 309 and 310). Further, because depression of a key in either of these two groups rotates the shaft 183 and tilts the blocking arms 208 (FIG. 16), no key in either the right or left group can be depressed simultaneously with a key in the front group, which consists of keys 302, 313, 314, 315, 316, 317 and 318. Additional interlocks are provided between certain keys within each group. For example, toggle 174, shown in FIG. 26, prevents the simultaneous depression of keys 303 and 304. Also, pin 168 (FIGS. 25, 27, 29 and 31) carried by the plus key 302 cooperates with gaps just below it in a subtotal link 823 and the total link 925 to prevent simultaneous depression of the plus key 302 and any one of the five total keys 313, 314, 315, 316 and 318. On the other hand, the BACK TRANSFER key 317 is left free to be depressed simultaneously with any other key in the front group, that is, with any one of the five total keys 313, 314, 315, 316 and 318, or with the plus key 302.

Control of the machine mechanism for different operations corresponding to the functions of the different control keys is provided in part by a series of cams mounted on the main drive shaft 135 of the machine. Referring to FIG. 1, these cams include, from left to right along the main drive shaft 135, a servo control cam 215, a full-cycle position centering cam 216, a selection carriage restore cam 217, a pendulum gear train aligning cam 218, a zero blocking bail actuating cam 219, a print mechanism control cam 220, a tens-transfer mechanism control cam 221, operating cams 222 and 223 for the actuator

mechanism of the machine, a detent cam or disk 224, a subtotal cam 225, a total cam 226, an addition and subtraction control cam 227, subtraction and addition resetting cams 228 and 229 used in the multiplication and division programs, a division alignment programming gear 230, a division programming cam 231, a motor switch opening cam 232 and a paper carriage tabulation control cam 233.

Referring to FIG. 2, a lever 235 is disposed in an upright position, rearward of the right-hand end of the main drive shaft 135 and at the outer side of the right-hand outboard plate 112. At its upper end, this lever is connected by a pivot pin 236 to the switch-operating link 160, and is provided near its lower end with a slot 237 extending in a direction longitudinal of the machine. A screw 238, carried by the frame plate 112, extends through the slot 237 to mount the lever on the frame plate. A tension spring 239 connects the upper end of the lever 235 to the fixed pin 162 and urges the link 160 in a rearward, or switch-opening, direction. A tension spring 240, connected between the lower end of the lever 235 and a fixed support 241 disposed forward of the lever, urges the lower end of the lever forward to bring an abutment 242 on the lower end of the lever into engagement with a fixed stop member 243. A cam-engaging extension 244 is provided on the forward edge of the lever 235 in alignment with the switch-opening cam 232. When the main drive shaft 135 is rotated, the lobe of the cam 232 engages the extension 244 near the end of the machine cycle and forces the lever 235 rearward. If the link 160 is free to move, the spring 240 will hold the lower end of the lever 235 against the stop 243 and the upper end of the lever will force the link 160 rearward to open the switch 123 in the event there should be any tendency for the switch to remain closed. If, as under certain circumstances to be later explained, the link 160 is not free to move rearward, or is moved forward while the cam lobe of cam 232 is in engagement with the cam-engaging extension 244, the spring 240 will yield, permitting the bottom end of the lever rather than the top end of this lever, to move rearward.

Referring to FIG. 3, the small drive gear 128 on the left-hand end of the motor shaft 121 meshes with a larger gear 250 of a compound gear disposed between the frame plates 102 and 104 and rotatably supported by these plates. A smaller gear 251 of the compound gear meshes with a large gear 252 journaled on a stub shaft 253 disposed transverse the machine and journaled in the frame plates 102 and 104. A shift clutch, similar in construction to the main clutch, couples gear 252 to shaft 253. A clutch ratchet 254 is secured to the gear 252 concentric with this gear and is also journaled on the stub shaft 253. A clutch cam disk 255 (FIG. 1) is secured to the shaft 253 and carries a pivotally mounted clutch pawl 256. This clutch pawl extends partially around the clutch ratchet 254 (FIG. 3) and is provided intermediate its length with a tooth 257 which is engageable with the teeth of the ratchet to drivingly connect the gear 252 to the shaft 253. A spring 258 resiliently urges the pawl 256 to ratchet-engaging position and the pawl is normally held out of engagement with the ratchet by a control arm 259 rockably mounted on a pivotal support 260. The control arm 259 is provided at one end with an abutment formation 261 engageable with a shoulder 262 on the outer edge of the clutch pawl 256 to hold the pawl out of engagement with the ratchet 254 and thus disengage the clutch. When the control arm 259 is rocked in a clockwise direction, as yielded in FIG. 3, it releases the clutch pawl 256 and the pawl then drivingly connects the motor-driven gear 252 to the shaft 253. As shown in FIGS. 45 and 55, a resiliently compressive strut 263 is pivotally connected at its upper end to the outer end of an arm 264 mounted on the left-hand end of a bail shaft 265 and rockable with the associated bail 266, the function of which will be later described.

At its lower end, the strut 263 is provided with a yoke formation 267 (FIG. 3) which straddles a pin 268 projecting from the shift clutch control arm 259 so that, when the strut 263 is forced down, it rocks the arm 259 clockwise to engage the shift clutch. The clutch control arm 259 has a second arm 269 extending down from the pivotal mounting 260. A spring 270, connected to the lower end of this second arm, resiliently holds the control arm 259 into engagement with pawl shoulder 262.

A shaft 275 extends transverse the machine forward of the motor 120 and carries at its left-hand end an up extending lever arm 276. A pin 277 projects from the upper end of the arm 276 through an elongate aperture 278 in the lower end portion of the control lever arm 269. A second, or auxiliary, control arm or bail 271 for the main clutch (FIG. 3) is rockably mounted on the pivot screw 146. The right leg 271a of bail 271 lies against the right side of the main control arm 150 and has an abutment, alongside of and similar to, abutment 147 on arm 150, engageable with shoulder 143 on the main drive clutch pawl 139 for disabling the main clutch and stopping the main drive shaft 135. Leg 271a also carries a roller (not shown), similar to roller 149 on arm 150, that rides on the periphery of the right clutch disk 138 (FIG. 1). Disk 138, like disk 137, has a single low portion that permits arm 280 to move, clockwise in FIG. 3, into pawl-intercepting position only when shaft 135 is in its home position. The left leg 280 of bail 271 carries a pin 2097 (see also FIG. 3) through which the bail 271 can be actuated. Leg 280 extends down from the pivotal mounting 146 and a rearward directed link 281 is pivotally connected at one end to the lower end of the leg 280. At its other, or rearward, end the link 281 is pivotally connected to the upper end of an arm 282, which is fixed to the right-hand end of the shaft 275 and extends up from this shaft.

The arrangement of the above-described connection between the shift clutch and the main drive clutch of the machine is such that whenever the shift clutch is engaged, the main drive clutch is automatically disengaged and, whenever the main drive clutch is engaged, the shift clutch is automatically disengaged. The functioning of this alternate engagement of the shift clutch and the main drive clutch will become further apparent as the description proceeds, and particularly in connection with the multiplication and division operations of the machine. Of course, since the connection between the clutches controls only the auxiliary control bail 271 of the main drive clutch, it is possible for both clutches to be disengaged at the same time, the shift clutch being disengaged by its control arm 259, and the main drive clutch being disengaged by its main control arm 150, but with the auxiliary control leg 280 in its clutch-engaging position relative to the main drive clutch.

A dual bevel gear arrangement 283 (FIG. 3) comprises a large bevel gear 283a and a smaller bevel gear 283b fixed to the right hand end of stub shaft 253. Two shafts 284 and 286 are disposed at an angle of substantially 90° apart and are driven by the bevel gear arrangement 283. The carriage return drive shaft 284 (see also FIG. 51) extends up from the inner end of the stub shaft 253 and carries at its lower end a bevel gear 285 which meshes with the bevel gear 283a to drive the carriage return shaft. The register shifting shaft 286 (see also FIGS. 58, 59 and 60) extends rearward from the inner end of the shaft 253. The shaft carries at its front end a bevel gear 287, which meshes with the bevel gear 283b to drive the register carriage shifting mechanism, to be later described.

3. ENTRY INPUT MECHANISM

The machine has a ten-key keyboard, including nine 75 digit keys 300 (FIG. 7) arranged in a 3 x 3 square for-

mation and consecutively numbered from "1" to "9," inclusive. A "0" key 301 is disposed to the left of, and a decimal point insertion key 1657 to the rear of, the group of nine digit keys. The control keys of the machine are arranged at the right-hand and left-hand sides of, and in front of, the group of digit keys 300. To the right of the digit keys, there is disposed the addition or (+) key 302, the subtraction or (−) key 303 and the PRINT ONLY key 304. To the right of these control keys, there is a manually movable lever 305 which controls the entry of values into the grand total accumulator, and which will be described in detail later. To the left of the digit keys 300 and immediately to the rear of the "0" key 301, there is a multiplier entry or (×) key 306 and a multiplication, or (=), key 307. To the left of this group of keys, there is the CLEAR KEYBOARD, or error key 308, the ENTER DIVD key 309 and the division, or (÷), key 310. To the left of this last-mentioned group of keys, there is a manually swingable lever 311 which controls the repeat operation of the addition key 302 and the subtraction key 303. To the left and rearward of the lever 311, there is a manually operable division stop lever 312.

Two rows of control keys are disposed in front of the group of digit keys 300, and the row nearest the digit keys includes the SUB GRAND TOTAL key 313, the DIV. TOTAL key 314 and the SUB TOTAL key 315.

The front row, which is the row farthest from the group of digit keys, includes the GRAND TOTAL key 316, the BACK TRANSFER key 317 and the TOTAL key 318.

Referring now to FIGS. 7, 8 and 9, each of the digit keys 300 is provided with a flat stem, as indicated at 320, slidably mounted for vertical movements in the upper and lower frame plates 321 and 322 of the keyboard frame.

A shiftable selection unit, generally indicated at 323, is disposed immediately below, and rearward of, the keyboard frame. The construction and operation of the selection unit 323 and the digit keys 300 are similar to those of the selection unit shown and described in greater detail in Friden Patent No. 2,371,752, and particularly in connection with FIGS. 9, 10, 11, 13, 15 to 22, and 25 of that patent. The selection unit 323 comprises a carriage frame having right-hand and left-hand end plates 319 (FIG. 16) and 324 (FIG. 8), and a pin box having spaced-apart and parallel plates 325 and 326 extending between, and secured to, the end plates at the front side of the carriage. The carriage frame is slidably supported for movement transversinal of the machine by an upper rail 327 and a lower rail 328. These rails are fixed to the machine frame in spaced-apart and parallel relationship to each other. The end plates of the selection unit carry sleeves, as indicated at 329, which slidably receive the upper rail.

A selection sector shaft 330 (FIG. 8) extends between, and is secured at its ends to the end plates of the carriage frame, rearward of a pin-box plate 325. Thirteen ordinarily arranged selection sectors 331 are rockably mounted on the shaft 330 in side-by-side relation. Each selection sector comprises an arcuate dial portion 332 supported on the hub portion 333 by spokes 334 and 335 and an arcuate gear, or rack portion, 336 supported on the hub portion by a spoke structure 337. The rack portion carries a series of rearward facing gear teeth 338 and has at its lower end a forward directed extension 339. Each selection sector is resiliently urged to rock in a clockwise direction, as viewed in FIG. 8, by an individual tension spring 340 and is releasably held against being rocked by its associated spring by an ordinal zero latch lever 341. The zero latch levers 341 are rockably mounted intermediate their length on a common transverse shaft 342 disposed between the pin-box plates 325 and 326. Each lever projects at its forward end through an aperture 344 in the front pin-box plate 326, and at its rear end, through an opening 343 in the rear pin-box plate 325.

A live tip 345 is pivotally mounted on each selection

sector 331 and is resiliently held against the forward end of the corresponding rack extension 339 by a spring 346. Each live tip is provided at its lower end with a forward projecting nose formation 347 which engages the rear end of the coordinal zero latch lever 341 to releasably hold the selection sector in "0" position against the force of the associated spring 340.

A stop bar 348 (FIG. 8) extends transverse the machine through the group of actuator sectors to the rear of, and parallel to, the shaft 330. The bar is so positioned that when a sector is in "0" position, the upper edge of the spoke formation 337 abuts the under-side of this bar to provide a positive stop for the "0" position of the sector for reasons which will later appear. Engagement of the rear edge of the spoke 334 with the upper edge of the stop bar 348 provides a positive "9" stop for the selection sector, to which position the selection sector is turned by the spring 340 when the "9" key is depressed. Operation of the keys from "1" to "8" inclusive, is also effective to stop the sectors at different angular positions corresponding to the value of the digit key depressed. The mechanism for differentially stopping or setting the selection sectors in accordance with the values "1" to "8" comprises ordinal rows of settable pins 355 slidably mounted in aligned apertures in the pin-box plates 325 and 326. The rows of pins extend substantially vertical and are ordinally arranged, being equal in number to selection sectors 331, with one row of pins in alignment with each of the live tips 345. There are eight pins in each row, consecutively corresponding from the bottom to the top of the row to the digit keys from "1" to "8," inclusive. When any pin is moved rearward by depression of the corresponding digit key, it provides a stop engageable by the nose 347 of the live tip 345 of the coordinal selection sector to stop the selection sector 331 at an angular position corresponding to the value of the digit key, the depression of which sets the pin. The spacings of the pins 355 and of the "9" stop 348, with respect to the zero latch 341, are such that the sector 331 rotates, under the force of spring 340, through the angle of one tooth of arcuate gear 336 when the "1" key is depressed, two teeth for the "2" key, etc.

A fixed plate 356 (FIG. 8) is mounted in the machine forward of the front ends of the pins 355 and substantially parallel to the pin-box plates 325 and 326. This plate is provided intermediate its height with an elongated slot 357 and at its lower edge with a notch 358. The slot 357 and notch 358 are located at the selection, or pin-setting, station which is in alignment with the first, or left-hand, order of the selection sectors when the shiftable selection carriage is in its home, or right-hand, position.

A zero latch releasing lever 359 (FIGS. 8 and 16) is rockably mounted on the support bracket 115 (FIG. 1), forward of the notch 358 (FIG. 8) in the plate 356 and has a rearward directed nose formation 360 disposed under the rear end of the zero latch lever 341 at the selection station. When the release lever 359 is rocked in a direction to raise the nose formation 360, it raises the forward end of the latch lever 341 at the selection station against the force of the latch lever restore spring 351 and moves the rear end of the latch lever down, out of engagement with the nose formation 347 of the coordinal live tip 345, thereby freeing the corresponding selection sector 331 for rotational movement by its spring 340.

A lever 361 (FIG. 8) is disposed immediately below the bottom plate 322 of the keyboard frame and is pivotally mounted intermediate its length on a fixed pivot 362. The upturned front end 363 of the lever 361 bears against the under-side of a rod 364 (see also FIGS. 9 and 10), which lies between the upper and lower frame plates of the keyboard frame and is mounted on the frame for vertical movement. Each of the digit key stems 320 has a lateral extension, as indicated at 365, extending over the top of the rod 364 so that this rod is moved down to rock

the lever 361 in a counter-clockwise direction, as viewed in FIG. 8, whenever one of the keys 300 is depressed. At its rear end, the lever 361 is pivotally connected to the upper end of a link 366, the lower end of which is pivotally connected to the zero latch release lever 359 to raise the rear end of this lever and release the selection sector at the selection station upon depression of a keyboard digit key.

A set of bellcrank levers 367 is disposed in side-by-side relationship below the keyboard frame 322 and are rockably mounted at their rear ends on a fixed pivot 368. The levers 367 have upturned front ends disposed immediately below the bottom plate 322 of the keyboard frame. The key stems 320 have portions, as indicated at 369, which extend down through the plate 322 in opposition, respectively, to the upturned ends of the corresponding levers 367. Each of the levers 367 is provided with a downward extension terminated in a finger portion 370 extending through the slot 357 in the plate 356 in opposition to the front ends of the corresponding pins 355. The arrangement is such that when the "1" key is depressed, it moves the lowermost finger 370 to set the bottom pin 355. When the "2" key is depressed, it moves the second finger from the bottom to set the second pin from the bottom, and similarly for the other pins, the "8" key moving the topmost finger to set the top pin of the corresponding row of pins 355.

A bracket 371 (FIG. 8) secured on the plate 115 (FIG. 1) is disposed forward of, and substantially parallel to, the plate 356 and at its upper end has a fixed pivot 362 which supports the lever 361. Tension springs 372, connected between this bracket and ears 373 on the several levers 367, resiliently retract these levers to their normal, or home, position, as shown in FIG. 8, and assist in raising the depressed keyboard keys 320 when the keys are released.

When the selection carriage 323, including the pin box, is returned from a value entering position to its right-hand, home position, as will be later described, cam fingers 374, shown in FIG. 16, extending from a comb mounted on the right-hand frame plate 106 (FIG. 1) of the machine, extend through slots 354 in the front end portions of the pins 355 and restore the set pins to their forward, home, or inoperative, position.

The selection carriage 323 is resiliently urged to the left from its right-hand, home, position by a mechanism particularly illustrated in FIG. 11. This mechanism comprises a carriage restore lever 375 of geniculate form, rockably mounted at one end on a pivot pin 376 so positioned that the axis of the rocking movement of the lever 375 is substantially perpendicular to the plane of the base plate of the machine. The pin 376 is carried by a bracket 377, mounted on the forward portion of the base plate 100 (FIG. 1) of the machine frame. The bracket 377 has a forward projecting arm 378 on which an ear is formed to hold a spring 379. The rear end of the spring connects to a stud on lever 375. The spring 379 urges the lever to rock in a counter-clockwise direction, as viewed in FIG. 11. A link 380, connected between the distal, or rear, end of the lever 375 and the left-hand side of the selection carriage 323, enables the spring 379 to urge the carriage to move to the left from its right-hand, home position.

Movement of the carriage to the left is controlled by an escapement mechanism, particularly illustrated in FIGS. 9 and 10. This escapement mechanism comprises a toothed rack 381 mounted on the upper edge of the rear pin-box plate 325 and projecting forward from this plate, as shown in FIG. 8. This rack preferably has a number of notches equal to one more than the number of orders of selection sectors 331, so that the group of selection sectors can be shifted to the left to a position in which the right-hand sector occupies an ordinal position one step to the left of the selection station, which is aligned with the position of the left-hand sector when the

selection carriage is in its home position. An escapement pawl 382 is rockably mounted near one end on an ear formation 383 extending up from the rear edge of the lower frame plate 322. This pawl is provided at its right-hand end with an up directed nose formation 384 (left-hand end in FIG. 10) which is normally held by a spring 394 in engagement with the notches between each two adjacent teeth 385 of the rack 381 to hold the rack against movement to the left. This nose formation is so shaped that the rack teeth will ratchet over the nose formation of the pawl 382 when the escapement rack is moved to the right.

An escapement control dog 386 is pivotally mounted at one end on an ear 387 projecting up from the lower frame plate 322. This dog is provided on its free, or left-hand, end with an inclined detent ear 388 which is normally held above the rack 381 by a spring 394, but which can engage in the notches between each two adjacent teeth 385 of the escapement rack 381 and temporarily hold the selection carriage in a half-step position in which it is shown in FIGS. 9 and 10. The free end of dog 386 is provided with a shoulder which engages a pin 390 projecting from the pawl 382 to move the free end of the pawl 382 down when the dog 386 is forced down.

The rod 364, which actuates the zero-release as described in connection with FIG. 8, is movably mounted on the lower frame plate 322 for vertical movement by a bail, including the bail arms 391 and 392 and the bail rod 393.

A rod 397, disposed above the lower frame plate 322 of the keyboard frame, is rockably supported at its ends in ears 398 and 387 projecting up from the front and rear edges of the lower frame plate 322. The dog 386 is fixed to the rear end of the rod 397, and a bellcrank lever 400 is fixed to the front end of this shaft.

A re-enforcing rod 401 extends between, and is fixed to, the dog 386 and an arm 402 of the bellcrank 400 to ensure that the dog 386 will rock with the rod 397. An arm 403 extends to the left from the lower end of the second arm 404 of the bellcrank 400. The arm 403 is provided at its left-hand end with a fork which receives the rod 364 so that the rod 397 will be rocked through the bellcrank lever 400 when the shaft 364 is forced down. Rocking of the rod 397 by the depression of a digit key, rocks the dog 386 to step the selection carriage to the left. First, the ear 388 moves into the inter-tooth space just below it. Then the dog 386 engages pin 390 to depress pawl 382 and withdraw nose 384 from engagement with the rack teeth. The rack then moves a half-step to the left (right in FIG. 10) and stops against ear 388 to leave the parts in the position shown in FIG. 10. When the digit key is released, dog 386 and pawl 382 rise. Because of the half-step, nose 384 cannot re-enter the notch it has just released, and stops against the lower face of the tooth to the right (left in FIG. 10). As ear 388 rises, its inclined surface lets the rack be moved to the left by spring 379 (FIG. 11) until nose 384 slips into the next notch. Accordingly, the selection carriage 323 has been moved one step to the left to bring the next sector 331 in alignment with the tips of levers 367 and 359 at the selection station (FIG. 8).

When the machine is cycled after a value has been entered into the selection mechanism, the selection mechanism is automatically restored to its right-hand, home, position by mechanism shown in FIGS. 11 and 12, and the selection sectors are restored to their zero condition by transmission mechanism to be later described.

As shown in FIGS. 11 and 12, a link 405 is connected at its forward end to the lever 375 by a pivotal connection 406 having two axes substantially at right angles to each other. This link extends rearward somewhat past the main drive shaft 135 and is provided at its rear end with a down extending hook formation 407. A stud 408 projects from the restore cam 217 in a position to engage the hook formation 407 near the end of an operat-

ing cycle of the machine and shift the link 405 rearward. Cam 217 and stud 408 are shown in their home, or full-cycle, position in FIG. 12. This rearward movement of the link 405 swings the lever 375 in a clockwise direction, as shown in FIG. 11, against the force of spring 379 and moves the selection carriage 323 back to its right-hand, home, position. Actually, the carriage is moved one step beyond its normal home position in order to restore the left-hand row of set pins 355 and is then released for a one-order movement to the left to bring its left-hand order to the selection station with the pins free to be set by the keyboard mechanism. The carriage is latched in this first order setting position by the escapement mechanism described above.

As mentioned previously, the manually operable lever 311 (FIGS. 7 and 12) is effective to condition the machine for repeat operation when this lever is manually moved to a predetermined position. As shown in FIG. 12, the lever has a substantially upright, flat stem 410 mounted intermediate its length on a fixed pivot 411 and is provided at its bottom end with two detent notches of inverted V-shape. A detent arm 412 is rockably mounted on a fixed pivot 413 carried by the machine frame 109 (FIG. 1) and carries, at its free end, a pin 414 resiliently urged into the detent notches in the lower end of the lever stem 410 by a spring 415.

In one detented position of the lever 311, the selection mechanism will be restored to its zero condition and home position at the end of each operating cycle of the machine, while in the other position of this lever, the position shown in FIG. 12, the selection mechanism will remain in its leftward displaced position and with the selection value therein at the end of an operating cycle so that this same value can be repeatedly entered into the accumulator of the machine.

A lever 416 is rockably mounted intermediate its length on a fixed pivot 417 and has its forward end positioned below a pin 418 carried by the lever 410 below the pivotal mounting 411 of this lever, the arrangement being such that when the lever is rocked to its rear, or "repeat" position, the forward end of the lever 416 is forced down by pin 418 and the rear end of this lever is raised. The rear end of the lever 416 rests under the outer end of one arm 419 of a bellcrank lever 420 (FIGS. 13 and 54) rockably mounted on a bracket 421 for rocking movement about an axis extending longitudinal of the machine. A shaft 422 extends transverse the machine adjacent the bracket 421 and is mounted for longitudinal sliding movement in the frame plates 109 and 105 (FIG. 1) of the machine. This shaft carries a pair of guide disks 423 and 424 disposed at respectively opposite sides of the link 405 and is resiliently urged to its right-hand home position by a compression spring 425. When the shaft 422 is in its home position, the link 405 is so positioned that its hook formation 407 is in the path of the stud 408 on the cam 217. A collar 426 is mounted on the shaft 422 and engaged by a second arm 427 of the bellcrank lever 420. When the bellcrank lever is rocked by the lever 416, as described above, the shaft 422 is moved to the left against the force of spring 425 and the hook formation of the link 405 is thereby moved out of the path of the stud 408 so that the selection carriage will not be restored to its home position during the machine operating cycle.

The bellcrank lever 420 (FIG. 13) is pivotally connected to the upper end of a link 430 (FIG. 12) and moves this link down when the bellcrank lever is rocked to move the hook formation 407 of the link 405 out of the path of the carriage restore stud 408. At its lower end, the link 430 is pivotally connected to the rear end of an arm 431 of a bail 1764 (FIGS. 12 and 54) pivotally mounted intermediate its length on a fixed pivotal support 432. The forward arm 1765 of bail 1764 carries a laterally projecting stud 433 engaged in a slot in the lower end

portion of the left-hand side flange 434 of a zero latch disabling bail 435. This bail extends across the space occupied by the selection sector unit when this unit is in its limiting, left-hand, position and is rockably mounted at its upper end on a transverse rod 436. The lower end of the bail 435 is rocked rearward when the link 430 is moved down, as described above, and a rearward directed flange, or ledge, 437 extends across the bottom edge of the bail. When the bottom end of the bail 435 is moved rearward, the flange 437 engages and overlies the forward ends of the zero latch levers 341 (FIG. 8), which have been moved to the left of the selection station. Then with each latch 341 blocked by flange 437, its co-ordinial live point 345 cannot slip past it into the "O" position shown in FIG. 8. Furthermore, this action of the bail flange 437 will not release any sectors that carry zero values. Under these conditions, after a value has been read out of the differentially set selection sectors to the left of the selection station, the sectors will return to their set position and will not be zeroized, as is the case in nonrepeat operations.

Depression of the "0" key 301 causes the selection carriage 323 to step ordinally to the left but does not release any of the zero latches 341 or set any of the pins 355. The "0" key has a flat stem 440 (FIG. 55) mounted for vertical movement on the frame plate 105 (FIG. 1). This stem carries a laterally projecting pin 441 engaged in a notch in the free, or distal, end of an arm 442 (FIG. 9). At its other end, the arm 442 is mounted on the left-hand end of a shaft 443, which extends transverse the machine forward of the entry input mechanism (see also FIGS. 16, 27 and 28). An arm 444 is mounted on the right-hand end of the shaft 443 and bears at its free, or rear end on the arm 402 of the bellcrank lever 404 to rock this lever in a counter-clockwise direction, as viewed in FIG. 9, and thereby move the free end of the escapement dog 386 down to operate the escapement and step the carriage one order to the left each time the "0" key is depressed and released.

4. ACTUATING MECHANISM

The actuating mechanism of the present calculator is similar to that shown and described in Chall Patent, No. 2,832,530, issued April 29, 1958, and shown particularly in FIGS. 9, 10 and 11 thereof. The actuating mechanism comprises a group of actuating sectors, or gears, 450 (FIGS. 16 and 21) mounted in ordinal arrangement for free rocking movements on an actuator gear shaft 451. The shaft 451 extends transverse the machine between the frame plates 107 and 108 (FIG. 1) and is rigidly mounted at its ends in these plates. The number of actuator sectors 450 for handling values is equal to the number of selection sectors 331 plus one. In addition, an extreme right-hand sector of less angular extent than the remaining sectors, is used to operate the symbol printing mechanism of the machine.

Each actuating sector is provided with an opening 452 of arcuate shape spaced forward from the shaft 451. 60 These openings are in registry with each other when the sectors are in their full-cycle, or home, position, as shown in FIG. 16. A bail rod 453 extends through the openings 452 of the several actuating sectors and is supported at its ends on the shaft 451 by bail legs, which restrict 65 the movements of the rod 453 to an arcuate path about the axis of the shaft 451.

The left-hand bail leg 454, as shown in FIG. 17, is fastened to the left-hand end of the actuator shaft 451 by a screw 456, which also fastens an arcuate-shaped 70 actuating member 449 to the shaft 451. The actuating member 449 has teeth 457 on its forward end in engagement with teeth 467 of a yoke, or loop, 462. The actuating member 449 has an extension 458 projecting up from the pivot screw 456 and carrying at its upper end a

laterally projecting pin 459 engageable in a notch 460 near the front end of a reciprocable link 461, the purpose of which will be later explained in connection with FIGS. 51 and 55 and the description of the multiplication and division operation of the machine. The right bail leg, not illustrated, may comprise a simple link connecting the shaft 451 to the bail rod 453.

The yoke, or loop, 462 (FIG. 17) surrounds the actuator lead and follow cams 222 and 223 mounted on the main drive shaft 135 (FIG. 1). This yoke 462 is supported on a fixed pivot 463 for rocking movement when the cams rotate with the main drive shaft. The yoke carries a cam following roller 464 engaging the peripheral contour of the lead cam 222, and a second cam following roller 465 engaging the peripheral contour of the follow cam 223. The contours of the cams 222 and 223 are such that from the beginning to near the middle of an operating cycle of the machine, the yoke is rocked down from its normal, or home, position (in which it is shown in FIG. 17) to its limiting operative position; remains in its downward limiting position for an interval, or dwell, at the middle of the cycle so that the printing operation can take place, as will be later described; and is then rocked up during the latter portion of the cycle to its normal, or home, position, which it reaches somewhat before the end of the operating cycle. The upper portion of the loop, or yoke, 462 is provided with an upstanding extension 466 having an arcuately-shaped rear edge provided with gear teeth 467 which mesh with the teeth 457 on the actuating member 449. With this arrangement, the actuator operating bail rod 453 is rocked down from its home position to its limiting operating position during the first portion of an operating cycle; remains for a short interval in its downward limiting position; and is then returned up to its normal, or home, position during the latter portion of the same cycle.

A pressure releasable connection (FIGS. 16 and 21) is provided between each actuator sector and the actuator operating bail rod 453. Such a connection comprises a bellcrank lever 468 pivotally mounted at its angle on the corresponding actuator gear, or sector, 450 by a pivotal connection 469. One arm of the bellcrank lever extends past the front side of the bail rod 453 and is provided with a notch, or seat, 470 in which the bail rod engages when it is at the upper end of the opening 452 in the corresponding sector. Beyond the seat 470, the same arm of the bellcrank lever 468 constitutes a rearward curved tail portion 471, which bears against the bail rod 453 when the bail rod is released from the seat 470 and moves through the opening 452. A spring 473, connected between the second arm of the bellcrank lever, or pressure latch, 468 and the corresponding actuating sector, maintains the latch pressed against the bail rod 453. The curved tail portion 471 of the latch maintains a downward, or counter-clockwise, pressure (FIG. 16) on the corresponding actuator sector even after the bail rod 453 has started to return from its limiting, downward, operative position. As the bail rod is returned to its upper position, it engages the edge of the sector at the upper end of the opening 452 in the sector and forces the sector back to its upper, or home, position, at the same time, engaging in the seat 470 in the corresponding latch lever 468.

A front add pendent gear train, generally indicated at 475 (FIGS. 16, 21 and 32), is disposed immediately in front of the group of actuator gears, or sectors, 450 and between the actuator sectors and the selection sectors 331. This pendent gear train, or mechanism, comprises a cage having a left-hand side member 474 (FIG. 32) and a right-hand side member 476 (FIG. 16) connected together by a bridge formation 477. Gear shafts 478, 479 and 480 extend between, and are mounted on, the cage side members in spaced-apart and parallel relationship to each other. The upper gear shaft 478 carries a

set of transmission gears 481, equal in number to the full number of actuator sectors 450 and 455. Each of these gears meshes with a coordinal print wheel drive gear 486 rotatably mounted on a fixed gear shaft 487. The ends of the gear shaft 478 extend out of the cage and engage in bearing apertures in the machine frame members 107 and 108 (FIG. 1) to provide a mounting about which this whole pendent gear mechanism 475 can swing or rock.

10 The right-hand side member 476 of the pendent gear cage is extended up above the gear shaft 478 and provided at its upper end with an operating tongue 482 (FIG. 16) extending perpendicular to the right for operatively swinging the pendent gear train, as will be later described in connection with FIGS. 25 and 26. Shaft 480 extends to the right to be engaged for swinging the pendent for the grand total-taking operation (FIG. 36).

The intermediate gear axle 479 carries a series of gears 483, which series contains one gear fewer than the series 20 of gears 481, since it is not necessary to have a gear 483 coordinal with the symbol mechanism actuator. The lower gear shaft 480 carries a series of gears 484 equal in number to, and coordinally meshing with, the gears 483. The gears 483 (FIG. 32) mesh with the coordinal 25 gears 481 and 484 so that the gears 481 and 484 turn in the same direction.

At the beginning of addition, subtraction, print only, keyboard clearing, multiplier entry and dividend entry operations of the machine, the front add pendent mechanism 475 is swung forward by mechanism to be later described, to mesh the gears 484 with the rack portions 336 of coordinal selection sectors 331. After the gears 484 have been meshed with the rack portions of the selection sectors, the actuator operating bail rod 453 is 30 moved down, thereby urging the actuator sectors 450 down. Those actuator sectors in alignment with selection sectors which have been set to the digits of a selection value and stepped to the left of the selection station, will be stopped when the corresponding actuator sectors have 35 been turned back to their "0" position in which they are stopped by the stop bar 348 (FIG. 8), as described above. Thus, each actuator gear sector 450 rotates (counter-clockwise as seen in FIG. 16) through an angle corresponding to a number of teeth equal to the value of the digit set into the coordinal selector sector 331. Those 40 actuator sectors to the left of the left-hand selection sector 332 are held against movement by a sector locking blade 485 (FIGS. 8, 16, 21 and 32) which is mounted on, and extends to the left from, the selection carriage 323 and 45 engages between adjacent teeth of the add pendent gears 484 which are disposed to the left of the left-hand selection sector.

Thus, at the end of the first portion of the operating cycle, those actuating gears, or sectors, 450, which are in 50 alignment with those selection sectors 331 which have been stepped to the left of the selection station of the input mechanism, will be differentially set to the same input value which was entered into the selection sectors from the keyboard. The selection value will, however, have its 55 lowest place in the right-hand actuator sector, excluding the symbol printing sector, because that actuator sector is aligned with the units-order position of the selector 323, which is the position one step of the selector to the left of the selection station, and the one that contains the last digit entered.

Under certain circumstances, the gears 484 are brought 60 into mesh with the drive gears 488 of a fixed or "grand total" accumulator 489 (FIG. 32) for entering values therein (FIG. 33) and retrieving grand totals therefrom (FIGS. 36 and 37).

A front subtract pendent gear assembly, generally indicated at 490, has a cage including side members 491 and 499 (FIGS. 16, 21 and 32) and a transverse bridge member 492 connecting the side members. The cage is 65 rockably mounted at its upper end by pivotal mountings,

as indicated at 493 (FIG. 16), between the cage side members and the adjacent frame plates of the machine. A pair of gear axles, or shafts, 494 and 495 extend through the side members of the cage in spaced-apart and parallel relationship to each other and carry sets of gears 496 and 497, respectively. The gears 496 are constantly in mesh with the coordinal actuator sectors 450. Shaft 495 extends to the right to permit the gears 497 to be moved into mesh with the accumulator drive gears 488 (FIG. 32) for certain operations to be described later, as for example, in connection with grand-total taking (FIG. 36). The subtract pendent has two sets of gears 496 and 497 as compared with the three sets 481, 483 and 484 of the add pendent 475 so that it drives the accumulator gears 488 in the opposite direction.

The machine has a shiftable, or primary, accumulator unit, generally indicated at 505 (FIGS. 16, 19 and 66), disposed to the rear of the actuator sectors 450. This unit comprises a carriage frame, including left-hand and right-hand end plates 506 and 507 rigidly held in spaced-apart and parallel relationship to each other by elements extending between, and fastened to, the end plates. This accumulator carriage is slidably mounted on upper and lower guide rails 508 and 509 extending between, and fastened to, the frame plates 110 and 103 (FIG. 1), and carries the primary accumulator 505 and a multiplier storage unit, or counter register, generally indicated at 510.

A rear add pendent gear mechanism, generally indicated at 512 (FIGS. 16, 19 and 21), and similar to the front add pendent 475, is provided between the actuator sectors 450 and the drive gears 513 of the primary accumulator 505. This add pendent gear mechanism has a cage, including left-hand and right-hand side members 511 and 514, and a bridge structure 515 extending between the side members.

Gear shafts 516, 517 and 518 extend between, and are mounted in, the cage side members in spaced-apart and parallel relationship to each other and the cage is pivotally supported by the projecting end portions of the shaft 516. A set of gears 519 is mounted on the shaft 516 and these gears are ordinarily in mesh with the actuator sectors 450. A set of gears 520 are mounted on the shaft 517 and are ordinarily in mesh with the gears 519, and a set of gears 521 are rotatably mounted on the shaft 518 and are ordinarily in mesh with the gears 520.

The assembly is swingable about the axis of shaft 516 to move the gears 521 into, and out of, mesh with the accumulator drive gears 513 during particular operations of the machine, as will be later described. An arm 522 (FIG. 16) is fixed to the right side member 514 and extends up from the shaft 516. An actuating tongue, or bail, 523 extends perpendicular to the right from the upper end of this arm for swinging the add pendent gear mechanism 512, by mechanism to be later described (FIG. 25). A hook arm 524 (FIGS. 16 and 21) of geniculate form extends first down from the rear end of the left-hand side 511 of the add pendent cage at the left-hand end of the shaft 518, and then forward below the add pendent gear mechanism 512. A laterally projecting hook formation 525 is provided at the forward end of this arm for terminating the automatic division operation (FIG. 65).

A rear subtract pendent gear mechanism, generally indicated at 526, is disposed above the add pendent gear assembly 512 and between the actuator sectors 450 and the accumulator drive gears 513. It is similar to the front subtract pendent 490 and includes a cage pivotally mounted at its front end on fixed pivotal supports 527 and 540 (FIGS. 16 and 21). The cage of the subtract pendent gear assembly 526 has left-hand and right-hand side members 541 and 528, respectively. A bridge structure 529 extends between the side members and holds these members in spaced-apart and parallel relationship to each other.

Gear shafts 530 and 531 (FIG. 19) extend between, and are supported by, the side members of the gear cage in spaced-apart and parallel relationship to each other. A set of gears 532 is rotatably mounted on the shaft 530 and are ordinarily in mesh with the actuator sectors 450. A set of gears 533 is rotatably mounted on the shaft 531 and these gears are ordinarily in mesh with the gears 532. This subtract pendent gear assembly is swingable about its pivotal mountings 527 and 540 to bring the gears 533 into mesh with the accumulator drive gears 513 during the latter part of an operating cycle of the machine to subtractively enter a value in the accumulator 505. An arm 534 is fixed to, and extends down and forward from, the pivotal mounting 527. An operating tongue, or bail, 535 projects laterally from the distal end of the arm 534 and is engaged by mechanism to be later described (FIG. 26) for swinging the subtract pendent gear assembly 526. Shaft 518 of the add pendent and shaft 531 of the subtract pendent extend to the left for engagement by the pendent aligning mechanism (FIG. 21), and at the right for engagement during the read-out, or total-taking operation (FIG. 30).

With the above-described arrangement, during an addition cycle of the machine, the front add pendent gear assembly 475 is swung to mesh the gears 484 with the teeth of the rack portions 338 of those selection sectors 331 which have been stepped to the left of the selection station of the input selection mechanism. The bail rod 453 is then moved down and those actuator sectors 450 to the right of the left-hand end of the series of selection sectors will be turned counter-clockwise as seen in FIG. 16, until the coordinal selection sectors are returned (also counter-clockwise) to their "0" positions and stopped by the zero stop bar 348, thereby differentially setting the operative actuator sectors. Those actuator sectors to the left of the left-hand end of the series of selection sectors will be held in their "0" positions by the coordinal add pendent gear trains and the locking blade 485 (FIGS. 16 and 32). After the bail rod 453 has been moved down to its limiting operative position, it is momentarily stopped in this position, during which time the printing operation takes place, and pendent 475 is disengaged from selector sector gears 331. The bail rod 453 is then returned up to its home position, returning to "0" position all of the actuator sectors which have been differentially set. Just before the rod 453 starts this return movement, the rear add pendent gear assembly 512 is swung to mesh its gears 521 with the coordinal accumulator drive gears 513 so that, during the return movement of the differentially set actuator sectors to their "0" position, the value which was set into the actuator sectors will be entered additively into the rear, or primary accumulator 505.

A subtraction cycle of the machine is similar in that the front add pendent gear assembly 475 is swung near the beginning of the cycle to mesh the gears 484 with the coordinal selection sector racks 331 and the operating rod 453 is moved down to its limiting operative position, thereby differentially setting those actuator sectors which are in ordinal alignment with the selection sectors which have been set and stepped to the left of the selection station of the selection mechanism, as described above. However, when the rod 453 starts its upward movement back to its home, or normal, position, the rear subtract pendent gear assembly 526 is rocked to mesh its gears 533 with the accumulator drive gears 513. As the differentially set actuator sectors are restored to their home, or "0," position, the value which was set into these sectors from the input selection mechanism is subtractively entered into the rear accumulator 505.

Actuator sector detent levers 536 (FIG. 16) are disposed in side-by-side, ordinal arrangement immediately below the actuator sectors. These levers are rockably mounted at their angles on a shaft 537, which extends transverse the machine and is mounted at its ends in the

frame plates 107 and 108. Each lever has a forward directed arm provided with an upturned distal end portion carrying a detenting roller 538 which engages between adjacent teeth of the coordinal actuator gear, or sector, 450 to releasably detent the sector in any angular position in which the sector comes to rest. Each of the arms 536 also has an arm extending down from the shaft 537. A spring 539, connected at one end to the lower end of this down projecting arm, resiliently rocks the detenting lever in a direction to engage the detenting roller 538 between the teeth of the coordinal actuator sector. A bail 542 (FIG. 16) lies above the detent arms 536 and is fixed to shaft 537. Secured to the right end of shaft 537 is a lever arm 543 (FIG. 31) carrying a cam follower roller 544 riding on the periphery of total cam 226. Secured to the left end of shaft 537 is an arm 1305 (FIG. 20) connected by a link 1313 to a lever 1309 that swings about shaft 487. The lower end 1323 of lever 1309 carries a roller 1324 that rides on tens-transfer cam 221. Spring 1307 on lever 1305 and spring 1311 on the upper end of lever 1309 urge the rollers 544 and 1324 against their cams. When either roller 544 (FIG. 31) or roller 1324 (FIG. 20) is on the high part of its cam, bail 542 (FIG. 16) holds the levers 536 depressed so that detent rollers 538 are free of the actuator gear segments. Cam 226 prevents engagement of the rollers 538 with the actuator gear segments during the first part of the machine cycle, that is, until the actuator segments have completed their descent. Cam 221 prevents the engagement of the detent rollers with the actuator segments during the last part of the operating cycle, and disengages the detents 538 just as the actuators begin their ascent. Consequently the detent rollers 538 are engaged substantially only during the printing operation. Lever 1309, so controlled by cams 221 and 226, also actuates the print blocking mechanism, as will be described later in connection with FIG. 20.

5. PRIMARY ACCUMULATOR

The primary, or shiftable, accumulator 505 is shown in right elevational cross-section in FIG. 19. This accumulator is similar to that disclosed in Chall Patent No. 2,832,530 already referred to, and is shown particularly in FIGS. 16, 20 and 22 thereof. This accumulator 505 has left-hand and right-hand end plates 506 and 507 and has separator plates disposed between, and in parallel relationship to, the end plates. There is a separator plate 545 for each order of the accumulator. Each of these plates has a rearward and upward directed projection 546, a downward and rearward extending projection 547 and a forward extending projection 548. Notched combs 549, 550 and 551 engage the projections 546, 547, and 548, respectively, to firmly hold the accumulator separator plates in properly spaced-apart and parallel relationship to each other. These plates are also held in properly spaced-apart relationship by other means, including concentric spacing washers 552 on the accumulator drive gears 513, concentric tens-transfer cams 553 on the accumulator gears 554, spacing washers 556 on the positive tens-transfer levers 557 and similar washers 558 on the negative transfer levers 559. The accumulator carriage frame, in addition to the end plates 506 and 507, includes a transverse plate 560 extending between the end plates rearward of the accumulator and fastened at its ends to the end plates of the carriage, and a transverse plate 645, also extending between, and fastened at its ends, to the end plates of the carriage at the lower edge of the front side of the accumulator.

The accumulator drive gears 513 are rotatably mounted on a drive gear shaft 561 which extends through the forward extensions 548 of the end and intermediate plates of the accumulator. A series of detenting levers 562 are rockably mounted, one at each end, on a shaft 563 extending through the forward extensions of the accumula-

tator plates near the comb member 551 and each of these levers carries at its free end a detenting roller 564 engageable between adjacent teeth of the coordinal accumulator drive gear 513. Each accumulator drive gear 513 is resiliently urged to rock in a direction to engage its detenting roller between the teeth of the coordinal drive gear by a tension spring 565.

The accumulator gears 554 are rotatably mounted on a gear shaft 566 which is disposed rearward of, and parallel to, the shaft 561 and is mounted at its ends in the carriage frame plates 506 and 507. The drive gears 513 are constantly in mesh with the coordinal accumulator gears 554. Each accumulator gear 554 has twenty gear teeth so that an accumulator gear will be driven through an angular interval of 180°, or one-half of a rotation for an input of ten units.

The positive tens-transfer levers 557 and separator washers 556 are mounted on a shaft 567 which extends transversely between the end frame plates 506 and 507 of the accumulator. Each of these levers is of bellcrank-shape and carries, on the outer end of one of its arms, a three-armed live tip 568. The live tip is pivotally mounted on the outer end of the arm of the lever 557 and is resiliently held by a spring 569 in a rotational position determined by a stop structure 570. A spring 571, connected between the second arm 572 of the bellcrank lever 557 and the comb 550, urges the lever to rock in a clockwise direction, as viewed in FIG. 19. One arm 573 of the live tip 568 bears at its outer end against the rear end of a latch lever 574 to hold the bellcrank lever 557 against being rocked by the spring 571, and another arm 575 of lever 557 projects from the pivotal mounting of the live tip 568 toward the coordinal accumulator gear 554 and carries at its distal end a shoe structure 576, which, when the live tip arm 573 is released from the latch lever 574 and the bellcrank lever 557 is rocked by the spring 571, engages a tooth of the coordinal accumulator gear 554 and turns the accumulator gear through one unit, or tooth space, of rotation. Movement of the accumulator gear is limited to a single complete unit space by engagement of an abutment formation 577 on the bellcrank lever 557 with a fixed stop rod 578.

Each of the latch levers 574 is rockably mounted at its forward end on a latch lever shaft 580 which extends transverse the accumulator below the accumulator gear shaft 566. A spring 581 urges the latch lever 574 to a position in which it engages the outer end of the live tip arm 573 and to hold the coordinal tens-transfer lever 557 in its inoperative position, movement of the latch lever 574 by the spring 581 being limited by engagement of an abutment formation 582 on the latch lever with a fixed stop rod 583. A live tip 584 is rockably mounted on the latch lever 574 intermediate the length of this lever and is resiliently held by a spring 585 in a rotated position relative to the lever 574 limited by a stop formation consisting of a pin 586 on live point 584 and a hole in lever 574. This live tip, or live point, lever 584 has an arm extending from the latch lever 574 toward the accumulator gear shaft 566, such arm being tipped by an abutment formation 587.

The tens-transfer cam 553 (FIG. 19) has diametrically opposed double beveled arms, or extensions, and, when an accumulator gear has been turned in a positive or additive direction (counter-clockwise as seen in FIG. 19) through ten unit spaces from one of its "0" positions, one end of the tens-transfer cam 553 engages the adjacent edge of the abutment formation 587 and rocks the latch lever 574 down. Downward movement of the free end of the latch lever releases the coordinal tens-transfer lever 557 so that this lever can be rocked by the spring 571. The shoe formation 576 carried by the tens-transfer lever is offset one order up (one order to the left) from the order of the associated latch lever 574 so that when an accumulator gear in one order trips the positive tens-transfer mechanism, the associated tens-transfer lever will

turn the accumulator gear in the next higher order one unit space in a positive or additive direction.

If the accumulator gear is turning in a negative or subtractive direction (clockwise in FIG. 19) when the transfer cam 553 engages the abutment formation 587, the live tip 584 will be rocked against the force of the spring 585 to allow the end of the tens-transfer cam to pass the abutment formation, but the latch lever 574 will not be moved to release the associated tens-transfer lever 557.

The negative tens-transfer mechanism is similar in all respects to the positive mechanism just described. A shaft 590, disposed immediately above, and parallel to, the shaft 567, supports the tens-transfer levers 559 of the negative tens-transfer mechanism, and the lever 559 in each order of the mechanism carries a rockably mounted live tip 591 rocked to a position determined by the stop formation 592 by the spring 593. A series of ordinal latch levers 596 is rockably mounted on a latch lever shaft 597 extending transverse the accumulator above the accumulator gear shaft 566 and, in each order, the rear end of a latch lever 596 engages the forward end of an arm 598 of the live tip 591 to hold the coordinate tens-transfer lever 559 against being rocked by the associated spring 594.

A live tip lever 602 is rockably mounted on each negative latch lever 596 intermediate the length of the latch lever, and is resiliently urged by a spring 604 to a rotational position determined by a stop formation 603. Another arm of the live tip lever 602 projects in toward the accumulator gear shaft 566 and is tipped at its inner end with an abutment formation 605. Whenever the coordinate accumulator gear 354 is turned through ten unit spaces from one of its "0" positions in a subtractive or negative direction (clockwise in FIG. 19), one end of the corresponding tens-transfer cam 553 engages the abutment formation 605 and rocks the coordinate latch lever 596 out until the rear end of this lever releases the forward end of the arm 598 of the coordinate live tip 591. This releases the corresponding tens-transfer lever 559 for rocking movement by its spring 594 about the shaft 590. An arm 606 of the lever 591 projects in toward the coordinate accumulator gear 554 and carries at its inner end a shoe 607 which engages a tooth of an accumulator gear and rotates the accumulator gear one unit, or tooth, space when the corresponding lever 559 is rocked by the associated spring 594. When the accumulator gears are turning in a positive or additive direction (counter-clockwise in FIG. 19), the end of the tens-transfer cam 553 engaging the abutment formation 605 carried by the coordinate negative latch lever, will rock the rockable lever 602 as it passes the abutment formation and will not move the corresponding latch lever 596 out to release the negative tens-transfer levers 559.

With the above-described arrangement, 10's will be carried from order-to-order of the accumulator from the lowest to the highest order required for a computation up to the limit of the accumulator.

Since the tens-transfer is accomplished by tripping a spring-driven pawl 557 or 559 of one order for driving the accumulator gear wheel 554 of the next higher order (the next order to the left), means are provided for resetting those pawls. It will be apparent later that when a number is entered in the accumulator 505, from the actuator, each accumulator wheel 554 will be rotated not more than nine tooth spaces by the actuator. Consequently, for each number so entered, each order can initiate not more than one tens-transfer. And since only one such number can be entered during each cycle of operation of the machine, it will be sufficient to reset the tens-transfer pawls 557 and 559 only once during each cycle. Also, it is necessary to prevent the transfer pawls 557 and 559 from engaging the wheels 554 while those wheels are being driven by the actuator. Both of these control actions are accomplished by bails 610 and

612 extending transverse the rear portion of the machine. The positive bail includes the bail rod 610 disposed in opposition to abutment formations 611 extending toward the bail rod from the positive tens-transfer levers 557. This bail rod 610 extends through openings in the accumulator plates 506 and 507, and is rockably mounted at its ends on the ends of the shaft 567 by bail legs 609 (FIGS. 19 and 22). The negative bail rod 612 extends transverse the accumulator through openings in the accumulator plates and is opposed to abutment formations 613 projecting toward the bail rod from the negative tens-transfer levers 559. This bail rod 612 is mounted at its ends on the ends of the shaft 590 by bail legs 633.

Referring to FIG. 20, a bellcrank lever 615 is rockably mounted at one end on a fixed pivotal support, such as the shaft 331, and has an up extending arm 617 carrying at its upper end a cam following roller 618 engaging the edge of the tens-transfer cam 221 mounted on the main drive shaft 135 (FIG. 1). A forward extending arm 619 of the lever 615 is pivotally connected at its forward end to the upper end of a link 620, the lower end of which is connected to the free end of an arm 621. The crank arm 621 is fixed at its other end to one of the left-hand tens-transfer bail legs 622 of the front, secondary, or grand total, accumulator 489, to be later described in detail.

A link 623 (FIG. 20) is pivotally connected at its forward end to the upper end of the arm 617 of the geniculate lever 615 and extends rearward to a location adjacent the rear of the machine. At its rear end, the link 623 is pivotally connected to one end of an arm 624, the other end of which is fixed on the left hand end of a shaft 625 which extends transverse the lower rear portion of the machine and is journaled in the machine frame for rotational movement. The legs supporting the positive tens-transfer bail 610 are provided with downward and rearward inclined extensions, as indicated at 627, for the bail leg 609 (FIGS. 20 and 22). Since the accumulator 505 must move left and right in the machine, on rails 508 and 509 (see for example, FIG. 20), and since the tens-transfer bail rods 610 and 612 must be controlled at all positions of the accumulator, an additional bail rod 626 (FIGS. 20 and 22) extends between, and is fixed at its ends to, the distal ends of the extensions 627 of the left and right bail legs 609. Lever arm 631 is fixed to the right-hand end of shaft 625, extends up and forward, and has a slot at its distal end embracing the bail rod 626. Each of the two positive tens-transfer bail legs 609 is drivingly connected to the corresponding leg 633 of the negative tens-transfer bail 612 by a gear connection 630 so that the two tens-transfer bail legs move simultaneously and coextensively.

With this arrangement, when the link 623 is moved rearward by the high part of the tens-transfer restore cam 221 (FIG. 20), the shaft 625 is rocked counter-clockwise, as seen in FIG. 20, and rocks the bail 626 to move the tens-transfer bails 610 and 612 against the abutments 611 and 613 (FIG. 19) of the tens-transfer levers 557 and 559, to move those levers out so they can be relatched by the levers 574 and 596.

In FIG. 20, cam 221 is shown with the follower roller 618 at the beginning or leading portion of the low part of the cam, which turns counter-clockwise as seen in FIG. 20. Accordingly, in this position, the link 623 is in its extreme forward position. However, in FIG. 20, link 623 is shown interrupted, and its rear end (left end in this view), and also the lever 624 and bails 610 and 612, are shown in a position corresponding to a different point in the cycle of the machine operation. The position of the bail rods 610 and 612 corresponding to the low part of cam 221 is approximately that shown in FIG. 19, with those bails lying about the same distance apart as the shafts 567 and 590 about which they swing. In this position of the bails, the tens-transfer pawls 557 and 559 are

free to operate. The low part of the cam 221 is of sufficient angular extent to give the time needed for the tens-transfers to take place, even when the machine does not stop between cycles, as in multiplication and division.

Shortly after the beginning of the cycle, the high part of the cam 221 comes under the roller 618, moves the link 623 rearward, and spreads the two bail rods 610 and 612 to their maximum separation for resetting any of the tens-transfer pawls 557 and 559 that may have been tripped during the previous machine cycle. Some time after the middle of the machine cycle (when printing has been completed) the actuator segments 450 begin rotating clockwise, as seen in FIG. 19, for entering the value in the accumulator. At this point, or even earlier, the intermediate portion of cam 221 comes under the roller 618 for moving the bail rods 610 and 612 to approximately the position in which they are shown in the left portion of FIG. 20. In this position, the rods 610 and 620 permit the tens-transfer levers 557 and 559 (FIG. 19) sufficient movement that they can be released by their latch levers 574 and 596, but not enough freedom to permit them to move into engagement with the teeth of the accumulator gear wheels 554.

Thus during the time that the accumulator wheels 554 are being driven by the actuator gears 450 for the entry of a value into the accumulator, the latches 574 (for a positive entry, for example) can be tripped by the tens-transfer cams 553, but the transfer levers 557 can move only far enough to escape the latches 574 and not far enough to engage the accumulator wheels 554, which may be rotating to receive entries from the actuator. Finally, when the actuator has been disengaged from the accumulator, as will be explained later, the low part of cam 221 (FIG. 20) comes under the roller 618 to move the bail rods 610 and 612 toward each other into the position shown in FIG. 19 to let the transfer pawls 557 complete their motion under force of the springs 571 for effecting the tens-transfer. At this point, if the tens-transfer operation causes one of the cams 553 to trip a transfer lever, that one will operate immediately.

The tens-transfer must be completed before the end of the cycle for the proper control of those operations in automatic division that respond to the presence or absence of a negative value, or overdraft, in the accumulator.

A spring 632 (FIG. 20), connected between the lever 615 and the base plate of the machine, resiliently urges the lever 615 to rock in a direction to maintain the cam following roller 618 in firm engagement with the periphery of the cam 221. Extensions 633a of the bail legs 633 are connected to links 1548 for similarly controlling the tens-transfer mechanism of the counter, or multiplier, register 510, as will be explained later.

Mechanism for inserting the "fugitive 1" by an end-around transfer to maintain a true credit balance indication in the accumulator is shown in FIG. 19. A positive "fugitive 1" bail 635 extends transverse the accumulator just above the shaft 580, and the bail is rockably mounted at its ends on the end portions of this shaft. At its left-hand end, this bail has a leg 636, similar and parallel to the positive latch levers 574 (FIG. 19), except that it does not carry a latching abutment on its rearward end. It does, however, carry a rockable lever, or live point, 584, the abutment formation 587 of which is engaged by the tens-transfer cam 553 on the highest order (leftmost) accumulator gear 554 when this gear is moved from a "9" to a "0" position in the positive input direction (counter-clockwise in FIG. 19). Engagement of the highest order tens-transfer cam 553 with the abutment of the rockable lever 584 on the bail arm 636 rocks the bail arm down in the same manner that the latch levers 574 are rocked down by the coordinate tens-transfer cams. At its right-hand end, the bail 635 carries an arm, or bail leg 637 which is also disposed parallel to the latch levers 574 and carries at its distal, or rear, end

an abutment formation 638 which normally engages the arm 573 of the four-armed lever, or live point, 568 mounted on the lowest order (rightmost) tens-transfer lever 557. The "fugitive 1" bail normally maintains the lowest order tens-transfer lever against tens-transfer movement, but, when the highest order accumulator gear moves in the positive entry direction from "9" to "0" to rock the bail 635, the bail releases the lowest order tens-transfer lever and a "1" is entered into the lowest order of the accumulator.

The negative "fugitive 1" bail 640 is similar and is disposed immediately below the shaft 597 and is rockably mounted at its ends on the end portions of this shaft. This bail has at its left-hand end a rearward extending leg carrying the live tip, or lever, 602 which is engaged by the tens-transfer cam on the highest order accumulator gear to rock the bail when this gear moves in a negative direction from a "9" to a "0" position. At its right-hand end, the bail 640 has a rearward extending leg 639 provided with an abutment formation 629 engaging the leg 598 of the coordinate four-armed lever, or live point, 591 mounted on the lowest order tens-transfer lever 559. When the bail is rocked by the tens-transfer cam on the highest order accumulator gear, the lowest order tens-transfer lever 559 is released to carry a "1" into the lowest order of the accumulator.

For the purpose of reading out totals from the accumulator, the accumulator is equipped with a positive zero blocking bail 641 (FIG. 19) and a negative zero blocking bail 642. The positive zero blocking bail 641 is mounted at its ends on the ends of the shaft 580 and is movable by the totalizing mechanism, to be later described, into position to block the formations 587 against movement so that, when the accumulator gears are turning in a clockwise, or negative, direction in reading out a positive total, they will be positively stopped when they reach their "0" positions. Normally, the bail 641 is clear of the abutment formations 587 so that the tens-transfer cams 553 on the accumulator gears can pass these abutments in the negative direction of rotation. The bail 642 is rockably mounted at its ends on the end portions of the shaft 597 and is movable by the totalizing mechanism into position to block the abutment formations 605 so that the accumulator gears will be stopped by engagement of the tens-transfer cams 553 with these abutment formations when the accumulator gears are being turned in a counter-clockwise, or positive, direction for reading out a negative total from the accumulator. The bail 642 is normally clear of the abutment formation 605 so that the ends of the tens-transfer cams 553 can pass these abutment formations when the accumulator gears are being turned in a positive or additive direction.

A toothed rack member 643 (FIGS. 19 and 58) is disposed at the rear side of the rear plate 560 of the frame of the shiftable accumulator 505 and is rigidly fastened to this plate. This rack member has a portion projecting to the left of the accumulator (toward the bottom of FIG. 58) and provided in its lower edge with rack teeth 644 by means of which the accumulator is stepped to the left by the accumulator shifting mechanism, to be later described in detail. A second rack 644 is disposed against the forward side of the transverse frame plate 645 at the lower forward portion of the accumulator and also has a toothed portion extending to the left of the accumulator. This rack is provided in the upper edge of its left-hand portion with rack teeth (FIG. 59), by means of which the accumulator is stepped to the right by the accumulator shifting mechanism.

6. GRAND TOTAL ACCUMULATOR

The front, fixed, secondarily, or grand total, accumulator 489 is located below, and forward of, the actuator, as shown in FIG. 16. A detailed cross-section appears in

FIG. 32. This accumulator comprises a flanged base 628 of rectangular shape, disposed within the opening 101 (FIG. 1) in the base plate 100 and fastened to the base plate by bracket members, as indicated at 646 (FIG. 32), of angular cross-sectional shape. A pair of end plates and a plurality of separator plates, as indicated at 647, extend perpendicularly up from the accumulator base 628 and are rigidly fastened to the base by notched clamp bars 648 and 649 extending through aligned, rectangular apertures in the plates near the forward and rear sides of the base. Screws, as indicated at 650 and 651, hold the clamp bars to the base. In addition to the notched clamp bars 648 and 649, the plates 647 are held in properly spaced-apart and parallel relationship by a comb 654 extending transverse the accumulator and engaging the upper end of the accumulator plates. The front accumulator has accumulator wheels, tens-transfer mechanism, and the like, substantially identical to those of the rear accumulator 505 (FIG. 19). Like the rear accumulator, it has as many orders as the actuator, exclusive of the symbol control sector. Unlike the rear accumulator, this front accumulator 489 is fixed in position. Each of its orders is aligned with one of those of the actuator, for the entry and retrieval of values. A shaft 652 for the accumulator drive gears 488 extends through upper, reduced width portions 653 of the accumulator plates and the drive gears are journaled on this shaft in side-by-side, ordinal arrangement and are maintained in position along the shaft by suitable spacing washers 659.

An accumulator gear shaft 660 extends through the accumulator end and separator plates in spaced and parallel relationship to the shaft 652. A plurality of twenty-tooth accumulator gears 661 are journaled, in ordinal arrangement, on the shaft 660 and each of these gears carries a double-ended tens-transfer cam 662. Each accumulator gear thus has two "0" positions corresponding to the diametrically opposite end portions of its tens-transfer cam 662.

A pair of shafts 663 and 664 extend through the lower portions of the accumulator plates in spaced-apart and parallel relationship to each other. A plurality of positive tens-transfer levers 665 is mounted in ordinal arrangement on the shaft 663 and held in properly spaced parallel relationship by concentric spacing washers 666. Each of the positive tens-transfer levers 665 is of bellcrank-shape and carries at the outer end of one of its arms a pivotally mounted four-armed lever, or live tip, 667 urged by a spring 668 in one rotational direction to a position determined by a stop structure 669.

A plurality of negative tens-transfer levers 671 is mounted in ordinal, side-by-side relationship on the shaft 664. Each of these levers 671 is of bellcrank-shape and carries, at the outer end of one of its arms, a pivotally mounted four-armed lever, or live tip, 672 urged by a spring 673 to turn in one direction to a position determined by a stop structure 674. Each four-armed lever 672 has an upward and rearward directed arm 675.

Each transfer lever 665 is resiliently urged to turn in a clockwise direction, as viewed in FIG. 32, by a tension spring 690, and each of the four-armed levers 667 includes an arm 691 directed inward from the pivotal mounting of the lever 667 on the lever 665. At its inner end, each arm 691 carries a shoe 692 which is engageable with a tooth of an accumulator gear 661 to rotate the accumulator gear one unit space in the positive or additive direction when the tens-transfer lever is rocked by its spring 690. The lever arm 691 is offset so that the shoe formation 692 engages a tooth of the accumulator gear of the order next above the order of the gear carrying the tens-transfer cam which actuates the associated latch lever 679.

When an accumulator gear 661 has been turned in a positive or additive direction (counter-clockwise in FIG. 32) through ten unit spaces from one of its "0" positions, one end of the associated tens-transfer cam 662 engages the abutment formation 684 and rocks the associated

latch lever 679 outward to release the detent formation 689 of this latch lever from the arm 670 of the coordinal four-armed lever 667. This frees the tens-transfer lever 665 to be rocked by its spring 690 to move the accumulator gear of the next higher order one unit space in the positive or additive direction.

The stop structure 683 is so arranged that when the accumulator gears rotating in the positive or additive direction and one end of a tens-transfer cam 662 engages the abutment formation 684 on the coordinal live tip lever 681, the associated latch lever 679 will be rocked outward to release the coordinal tens-transfer lever 665. However, when the gears are turning in the negative or subtractive direction, if an abutment formation 684 is engaged by one end of the coordinal tens-transfer cam, the live point lever 681 will be rocked against the force of its spring 682 and the end of the tens-transfer cam will pass by the abutment formation 684 without rocking the latch lever 679 outward.

The negative tens-transfer levers 671 are urged to rock by springs, as indicated at 695, and are releasably held against being rocked by these springs by coordinal latch levers 696 mounted in ordinal arrangement on the shaft 678. Each four-armed lever 672 of the negative tens-transfer mechanism has an arm 697 extending toward the coordinal accumulator gear and provided at its inner end with a shouldered shoe, or finger, 698 which engages a tooth of the gear of the next higher order, and turns the gear when the corresponding tens-transfer lever 671 is rocked. Each of the negative latch levers 696 is urged by a spring 699 to its inward, latching position in which an abutment 700 on the latch lever engages a fixed stop rod 701. Each negative latch lever carries a pivotally mounted live tip lever, or pawl, 702 urged by a spring 703 to a rotational position determined by a stop pin 704. Each live tip lever 702 carries at its inner end an abutment formation 705 which is engaged by an end of the coordinal tens-transfer cam 662 to rock the associated latch lever outward to releasing position when an end of the cam engages the abutment formation while the accumulator gear is turning in the negative or subtractive direction (clockwise in FIG. 32).

A tens-transfer restore bail rod 706 is engageable with abutment formation 707 on the positive tens-transfer levers 665 to restore these levers to latched condition after a tens-transfer has been completed. A negative restore bail rod 708 is engageable with abutment formations 709 on the negative tens-transfer levers 671 to restore these levers to latched condition after a tens-transfer. The bails 706 and 708 are rockably mounted on the rods 663 and 664 by gear-tooth connected bail legs 622 and 715, as shown in FIG. 20, and these bails are operated by the cam 221 through the lever 516, link 620 and arm 621, as described above.

A positive "fugitive 1" bail 710 (FIG. 32) is rockably mounted at its ends on the end portions of the shaft 677 and is rockable by the highest order tens-transfer cam 662 of the accumulator when the highest order (leftmost) accumulator gear passes through its "9" to "0" position, as it will do when the value in the accumulator changes from negative to positive, to make a tens-transfer from the highest to the lowest order of the accumulator. A positive zero blocking bail 711 is also rockably mounted at its ends on the end portions of the shaft 677 and is movable by the total-taking mechanism of the machine to a position in which it blocks the abutment formations 684 against upward movement to stop the negatively rotating accumulator gears when they reach their "0" positions as a positive total is being read out of the accumulator.

A negative "fugitive 1" bail 712 is rockably mounted at its ends on the end portions of the shaft 678 and is rocked by the highest order tens-transfer cam 662 when the highest order accumulator gear passes from its "0"

to "9" position incident to a change in sign of the value in the accumulator from positive to negative, as described above, to make a tens-transfer from the highest to the lowest order of the accumulator. A negative zero block bail 713 is rockably mounted at its ends on the end portions of the shaft 678 and is moved by the total-taking mechanism of the machine to a position to block the abutment formations 705 during readout when the total value in the accumulator has a negative sign. Blocking of the abutment formations 705 will stop the positively rotating accumulator gears at their "0" positions as the negative value is read out of the accumulator.

7. ADDITION OPERATION

Referring now to FIG. 25, the stem 720 of the addition (+) key 302 (FIG. 7) carries, near its lower end, a laterally projecting pin 721 (see also FIG. 27) which overlies the forward, distal end of one arm 722 of a bellcrank lever 723 rockably mounted at its angle on a fixed pivotal support 724. At its upper end, the other arm 725 of the bellcrank lever is pivotally connected to the forward end of a link 726 which extends rearward of the machine from the upper end of the bellcrank lever arm 725. Intermediate its length, the link 726 is slidably supported on a pin 169 which projects through a longitudinal slot in the link, and at its rear end, the link carries a laterally disposed roller 728. A spring 727 connected to arm 725 biases bellcrank 723, clockwise as seen in FIG. 25, and the link 726 rearward. With this arrangement, when the add key 302 is depressed, the bellcrank lever 723 is rocked in a counter-clockwise direction, as viewed in FIG. 25, and the link 726 is shifted forward. It will be noted that the link 726 is also guided for longitudinal movement by passing through a notch in a notched bracket 729 on the adjacent frame side plate of the machine.

The roller 728 bears on the upper forward end portion of a lever 730. This lever is rockably mounted intermediate its length on a fixed pivot pin 731 extending transverse the machine and is provided at its rear end with a fork formation 732 slidably receiving a pin 733. A second lever 734 is rockably mounted at its rear end on a movable pivot 735 and carries the pin 733 at its front end. A third lever 736 is provided at its front end with a fork formation 737 slidably receiving the fixed pivot pin 731, and is provided at its rear end with an up directed hook formation 738. The lever 736 is rockably mounted on the lever 734 by a pivotal connection 719 disposed intermediate the lengths of both levers.

With this arrangement, when the upper end of the lever 730 is moved forward by forward movement of the add key link 726, the fork formation 732, on the rear end of this lever, is raised, raising the pin 733 as the lever 730 is rocked about the fixed pivot pin 731. This action raises the forward end of lever 734 and the pivotal connection 719. This, in turn, rocks the lever 736 about the fixed pivot 731 and raises the hook formation 738 to engage the positioning bail 523 of the add pendent gear train 512. Hook 738 will be used to rock the gears 521 (FIG. 16) of this gear train into mesh with the accumulator drive gears 513 of the primary, or shiftable, accumulator 505 at a predetermined point in the operating cycle, as will presently appear.

The movable pivot mounting 735 is carried at the upper end of one arm 739 (FIG. 25) of a three-armed lever 740 rockably mounted at the conjunction of its arms on a shaft 741 which extends transverse the machine below, and parallel to, the main drive shaft 135. A second arm 742 of the lever 740 carries, at its upper end, a cam following roller 743 bearing against the peripheral contour of the add-subtract control cam 227 (FIG. 1) mounted on the main drive shaft 135. The third arm 744 of the lever 740 extends rearward and is connected at its rear end to the lower end of a spring

745, the upper end of which is connected to the right-hand frame side plate of the machine to resiliently urge the lever 740 to rock in a counter-clockwise direction, as viewed in FIG. 25, and maintain the roller 743 in firm engagement with the edge of the cam 227. The lever 734 and the link 736 are resiliently urged down by a spring 746 connected between the arm 739 of the lever 740 and a down projecting extension 747 on the intermediate portion of the lever 734.

Referring to FIG. 36, a link 748 is pivotally mounted at its rear end on the pivot 735 at the upper end of the lever arm 739 and is provided at its front end with a yoke formation 749 slidably receiving a pin 750 projecting laterally from one end of a lever 751. Lever 751 is rockably mounted intermediate its length on a pivot 752 and has at its other, or front, end, a laterally projecting pin 753 which is engaged by an element of the total-taking mechanism to rock the lever in a clockwise direction, as illustrated in FIGS. 29, 31 and 36, during a total-taking operation of the machine. Near its forward end, the link 748 is provided with a transverse shoulder 754 which lies forward of the forward edge of the operating bail 482 (FIG. 16) of the front add pendent gear train 475 which is connectable to both the selector 323 and the fixed, or grand total, accumulator 489. When the lever 751 is rocked, incident to a total-taking operation, it lowers the link 748 to remove the shoulder 754 from its normal alignment with bail 482, but during the adding operation and other value input operations, pin 750 serves as a stationary guide for link 748.

Depression of the add key establishes an operating cycle of the machine by closing the motor switch and engaging the main drive clutch of the machine, as described above (FIGS. 4 and 27), causing the main shaft 135 and the add-subtract control cam 227 to cycle through a complete rotation. Cam 227 is shown in its home, or full-cycle, position in FIGS. 25 and 36. The contour of the add-subtract cam 227 is such, that at, or near, the beginning of the add cycle, the three-armed lever 740 is rocked clockwise, moving the link 748 (FIG. 36) rearward. Engagement of this link with the operating bail 482 of the front add pendent gear assembly 475 meshes the gears 484 of this assembly with the teeth of the rack portions of the selection sectors 331 (FIG. 16), which have been stepped to the left of the selection station, as described above. The cam maintains the gears 484 in mesh with the selection sectors during the first portion of the operating cycle until the selected value has been read out of the selection sectors and the actuating sectors 450 have been differentially set to the same value. When the actuating sectors have been differentially set, the printing operation takes place and the cam following roller 743 rides off of the high portion of the cam 227 onto its lowest portion, permitting the spring 745 to rock the three-armed lever 740 in the counter-clockwise direction, as viewed in FIG. 36, to disengage the add pendent gears 484 from the selection sectors 331. Since the hook formation 738 (FIG. 25) was set behind the operating bail 523 of the rear add pendent gear assembly 512 when the add key was depressed, movement of the three-armed lever 740 to its extreme counter-clockwise position moves the link 736 and the bail 523 forward, and this action brings the gears 521 of the rear add pendent gear assembly 512 (FIG. 16) into mesh with the drive gears 513 of the accumulator 505. This condition continues while the actuating sectors are being restored to their home, or full-cycle, position for entering the value in the accumulator, and near the end of the cycle the roller 743 (FIG. 25) rides on to a cam portion of intermediate height, returning lever 740 to its home position and thereby returning the add pendent gear assembly 512 to its neutral, or centered, position in which its gears 521 are out of mesh with the accumulator drive gears 513. If

there initially was a value in the accumulator, the present entry will be added to it, as has been described, and some of the accumulator gears 554 (FIG. 19) may turn past their "9" positions and lift their latches 574 (the present entry being an addition). Accordingly as the value is being entered by the actuator sectors into the accumulator gears, the tens-transfer bails 610 and 612 are held in an intermediate position (about the position shown in FIG. 20) to let the levers 557 escape the latches 574, and just at the end of the cycle, the tens-transfer operating bails 610 and 612 of this accumulator are moved into about the position shown in FIG. 19 to permit the tens-transfers to be completed, as described above. Pin 721 of the add key operates the yoke 205 (FIG. 27), which is similar to the yoke 826 (FIG. 16) on the shaft 155 (FIG. 4) to operate the main clutch which maintains the add key depressed until the end of the operating cycle. When the cycle is completed, the shape of the main clutch disk 137 (FIG. 3) releases the yoke and the add key is released to rise to its normal, or raised, position, thus terminating the operation of the machine at the end of the single add cycle. If the add key is held down beyond the first cycle, the machine will continue to operate and will add zeros for each cycle following the first add cycle until the add key is released.

8. SUBTRACTION OPERATION

Referring to FIG. 26, the subtract (−) key 303 has a flat stem 760 mounted for vertical movement on the right-hand frame plate 106, which stem carries the pin 159 which moves the right-hand switch and clutch controlling slide 151 (FIG. 4) to establish a cyclic operation of the machine when the subtract key is depressed.

The key stem 760 is provided, in its upper portion, with a longitudinal slot 761 receiving a pin 762 projecting laterally from one end of a bellcrank lever 763 rockably mounted at its angle on the right-hand frame plate 106 by a pivot pin 764. The other end of the bellcrank lever 763 is connected by a pin 765 to the central part of a subtract slide 766. The slide 766 is supported intermediate its length on the fixed pin 169 projecting through a longitudinal slot in the slide and at its front end by a fixed pin 769 extending through a similar slot in a forward extension 768. The slide 766 is also guided by a vertical notch in the bracket 729. A spring 770, connected to the front end of the extension 768, resiliently urges the slide 766 in a rearward direction, this slide being moved forward by the pin 762 engaging the upper end of the slot 761 in the subtract key stem when the subtract key is depressed.

At its rear end, the slide 766 carries a roller 771 bearing on the forward end portion of a lever 772 rockably mounted intermediate its length on the fixed pivot pin 731. At its rear end, the lever 772 has a fork formation 773 slidably receiving a pin 774 projecting laterally from the forward end portion of a lever 775. The lever 775 is pivotally mounted at its rear end on the movable pivot 735 and is pivotally connected intermediate its ends to an operating link 776 by a pivot pin 777. The operating link 776 is provided at its front end with a yoke formation 778 slidably receiving the fixed pivot pin 731, and is provided at its rear end, with an up projecting hook formation 779. With this arrangement, when the lever 772 is rocked, in a counter-clockwise direction as viewed in FIG. 26, by a forward movement of the subtract slide 766, the hook formation 779 is raised to engage the operating bail 535 of the subtract pendent gear assembly 526 for the rear, shiftable, or primary, register 505.

In the subtraction operation, depression of the subtract key functions to establish a machine operating cycle by closing the motor switch and engaging the main drive clutch, as explained above. During the first portion of

the cycle, the link 748 (FIG. 36) is moved rearward to engage the operating bail 482 of the front add pendent gear train to mesh the gears 484 thereof with the selection sector racks to differentially set the actuator sectors, as described above in connection with the addition operation. During the latter portion of the subtract operating cycle, the link 776 (FIG. 26) is moved forward by the spring 745 to swing the actuating bail 535 of the rear subtract pendent gear assembly 526 to mesh the gears 533 (FIG. 19) of this assembly with the accumulator drive gears 513 and subtractively enter the selected value from the actuating sectors into the rear, or primary, accumulator 505.

The pendent gear trains are held in mesh with the selection sectors and with the corresponding accumulator drive gears by pendent gear aligning mechanism, particularly shown in FIG. 21. A T-shaped aligning member 785 for the front pendent gear mechanisms 475 and 490 is slidably mounted at its upper end on the main drive shaft 135, and extends down and forward from that shaft. At its lower end, this T-shaped member carries spaced detenting teeth 786 and 787 projecting up from the lower end of the member. A bail 788 is rockably mounted on the shaft 831 and has one leg 790 extending up and forward from the bail rod, and carrying at its distal end, a cam following roller 791 engaging the peripheral edge of the pendent gear aligning cam 218. A second arm 792 of the bail is pivotally connected at its distal end to the aligning T-shaped member 785 near the lower end of this member by a pivotal connection 793. A bar 794 is fixed to the left-hand side portion of the frame of the add pendent gear mechanism 475 and this bar is provided at its lower end with two spaced-apart double bevel teeth 795 and 796. A bar 797 is fixed to the left-hand portion of the frame of the subtract pendent gear mechanism 490 and this bar is provided at its lower end with a single, double beveled, tooth 798. The cam 218 is so shaped that, as soon as the add-subtract control cam 227 has moved the pendent gear train 475 to mesh its gears with the teeth on the selection sectors 331, the aligning T-shaped member 785 is raised by a spring 799 connected to the bail arm 790, and the tooth 786 on the aligning member will be disposed at the outer, or rear, side of the tooth 796 to hold the pendent gear mechanism in this position during the first portion of an addition or subtraction cycle. The cam 218, shown in approximately its home position in FIG. 21, has two substantially opposite lobe portions so that, at the middle of the cycle, it forces the aligning member 785 down to release the tooth 796, freeing the pendent gear assembly 475 to move to its neutral position. After the middle of the cycle, the cam frees the aligning member 785 to be again raised by the spring 799 and, with the add pendent gear assembly in its centered, or neutral, position, the tooth 786 will enter the space between the two teeth 795 and 796 and hold the pendent gear assembly in this centered position. If, however, the pendent gear assembly 475 has moved to mesh its gears with the accumulator drive gears 488 (FIGS. 16 and 32), when the member 785 was raised after the middle of the cycle, the tooth 786 would engage the outer, or forward, edge of the tooth 795 and hold the add pendent gear assembly in this position until near the end of the cycle. If, after the middle of the cycle, the front subtract pendent gear assembly 490 had been moved to mesh its gears with the accumulator drive gears 488, when the aligning member 785 was raised after the middle of the cycle, the tooth 787 on this member would engage the outer, or rear, side of the tooth 798 and hold the subtract pendent gear assembly in operative, or meshing, position until near the end of the cycle.

In FIG. 21, an aligning slide, or fork, 800 for the rear pendants is mounted on the frame plate 107 immediately forward of the primary accumulator 505 for forward and rearward movement. A bellcrank lever 801 is connected at its upper end to the fork 800 by a pivotal connection

802 and is rockably mounted at its lower end on a fixed pivotal mounting 803. An arm 804 extends forward from the lower end of the lever 801 and is provided in its forward end with a notch receiving a pin extending laterally from the rear end portion of an arm 805 extending rearward from the bail leg 792 of the bail 788. With this arrangement, the aligning fork 800 is moved forward by the spring 799 whenever the cam following roller 791 rides off of a high portion of the cam 218.

The fork 800 carries at its rear end upper and lower jaw members 806 and 807. The jaw member 806 is provided at its rear end with an abutment formation 809 extending perpendicular to the right from the jaw member and positioned to engage the left-hand end portion of the gear shaft 531 of the rear subtract pendent gear assembly 526. If the subtract pendent gear assembly has been moved into mesh with the accumulator drive gears 513, the abutment 809 will be moved to a position in which it rides on top of the left-hand end of the shaft 531 and holds the subtract pendent gear train in mesh with the accumulator drive gears, for example, from the middle to the end of the "subtract" operating cycle. If, on the other hand, the subtract pendent gear train has not been moved from its inoperative position, upon forward movement of the yoke 800, the abutment formation 809 will move under the gear shaft 531 and prevent accidental meshing of the subtract pendent gears with the accumulator drive gears.

The jaw member 807 similarly is provided at its rear end with an abutment formation 810 extending perpendicular to the right from the jaw member and positioned to engage under the right-hand end of the gear shaft 518 of the add pendent gear train assembly 512 when this gear train assembly is moved into mesh with the accumulator drive gears 513. If the yoke 800 is moved forward while the gear train assembly 512 is still in its inoperative position, the abutment formation 810 will move above the left-hand end of the shaft 518 and hold this gear assembly against accidental engagement with gears 513.

9. SUBTOTAL OPERATION

Referring particularly to FIG. 29, the SUB TOTAL key 315 has a flat stem 815 slidably mounted in the front cross-member 114 of the machine frame. This key stem extends through aligned guide slots in an upper flange portion 816 and a lower flange portion 817 of the frame cross-member 114 and is resiliently urged to its upper limiting position by a spring 818. An extension 819 projects forward from the key stem immediately below the upper flange 816 when the key is in raised position, and near its forward end, this extension 819 rests on the upper edge of a bail 820 rockably mounted on the transverse shaft 443 (FIGS. 9 and 16). An arm 822 projects up from the right-hand end of the bail 820 and is connected at its upper end to the forward end of the subtotal actuating link 823 which extends longitudinal of the forward portion of the right-hand side of the machine.

The pin 824 projects to the right from the lower portion of the key stem 815 and engages in the notch of the yoke 826 mounted on, and extending up from, the shaft 155. As has been previously explained in connection with FIG. 4, rocking of the shaft 155, acting through the arm 154, moves the link 151 forward to close the motor switch and engage the main drive clutch of the machine. Thus, depression of the SUB TOTAL key will cause the machine to cycle. The lower end of the key stem 815 rests on the upper edge of the bails 827 and 1416, which are rockably mounted on the shaft 155 and have down extending arms connected at their lower ends to the forward ends of links 832 and 1417 (shown also in FIG. 4), and connected to the rear with the blocking mechanism 835 (FIGS. 29 and 30) and the symbol bail 1419 (FIG. 29). The operation of the blocking mechanism will be described later in detail.

At its rearward end, the subtotal link 823 (FIG. 29) carries a laterally projecting pin 840 bearing on the rear edge of one arm 841 of a bail 842 (FIG. 30A) rockably mounted on a shaft 843 extending transverse the upper, intermediate portion of the machine. The bail 842 has a rearward projecting arm 844, provided at its rear end with a forward facing hook formation 845. Arm 844 lies under pin 753 (FIG. 29) of lever 751 as previously described under "Addition Operation." Pin 750 at the rear of lever 751 guides link 784 which is moved by cam 227 each time the machine cycles. Thus, depression of the SUB TOTAL key 315 lowers pin 750 so that shoulder 754 on link 748 lies below ear 482 of the front add pendent 475 (FIG. 16), and can not drive it.

10 A lever 850 (FIG. 29) is rockably mounted intermediate its length on a transverse shaft 851 and is provided at its upper end with a laterally extending abutment formation 852. The bail 842 is resiliently rocked in a clockwise direction, as viewed in FIG. 29, by a spring 853 to maintain the hook formation 845 in engagement with the abutment formation 852 on the upper end of the lever 850 and holds this lever against rocking movement about the shaft 851.

15 As shown in FIG. 30, the lever 850 has an arm extending down from the shaft 851 and has a third arm 854 projecting rearward from a location adjacent the shaft 851. At its rear end the arm 854 carries a cam following roller 855 arranged to bear on the peripheral edge of the subtotal cam 225 mounted on the main drive shaft 135 (shown also in FIG. 1). Two links 870 and 1050, connected to lever 850, actuate sign-sensing mechanisms of the rear, or primary, accumulator 505 (FIGS. 16 and 19), and the front or grand-total accumulator 489 (FIGS. 16, 31 and 32), respectively. Subtotal cam 225 is shown in 20 its home, or full-cycle, position.

25 An upper bellcrank lever 856 (FIG. 30) is rockably mounted at its angle on a pivotal support 857 disposed rearward of the main cam shaft 135, and a corresponding lower bellcrank lever 858 is rockably mounted at its angle 30 on a pivotal support 859 disposed immediately below the pivotal mounting 857. The lever 856 constitutes the left-hand leg of a bail, the cross-member 860 whereof extends transverse the right-hand portion of the machine, rearward of the pivotal mounting 857. The lever 858 also constitutes the left-hand leg of a bail, the cross-member 40 861 of which extends transverse the right-hand portion of the machine, rearward of the pivotal mounting 859. These left bail legs 856 and 858 lie just to the right of the rear pends 526 and 512 (FIGS. 16 and 19) for 45 engagement with the right ends of shafts 531 and 518 for moving the pends. Bails 860 and 861 extend transverse the machine so as to be engageable at all times with lever arms 889 and 897, which are mounted on, and move with, the movable accumulator 505. The bail leg 856 has an arm 862 extending down from the pivotal mounting 55 857 and provided with a forward opening notch 863. The bail leg 858 has an arm 864 projecting up from the pivotal mounting 859 and provided near its upper end with a forward opening notch 865. A spring 866, connected between the upper and lower bails 856 and 858, 60 rearward of the pivotal mountings 857 and 859, resiliently urges the rearward disposed cross-members 860 and 861 of the bails toward each other.

65 The link 870 (FIG. 30) is connected at its forward end to the lower end of the lever 850 by a pivotal connection 871 and is curved up over the main drive shaft 135. At its rear end, the link 870 has a Y-formation, or yoke, 872 carrying spaced, laterally projecting, pins 873 and 874. The upper pin 873 is in alignment with the notch 863 in the arm 862 of the upper bail leg 856, and the lower pin 874 is in alignment with the notch 865 in the arm 864 of the lower bail leg 858.

70 A substantially T-shaped sign sensing gate 875 is disposed at the right-hand end of the accumulator 505 and is rockably mounted at the midlength location of its cross-member on the accumulator gear shaft 566. The 75

cross-member of the T-shaped gate 875 is substantially vertical and has an arm 877 which extends rearward from its pivot 566 and is bent downward intermediate its length to pass by the shafts 610 and 612 of the tens-transfer restore mechanism, described above in connection with FIG. 19. At its rear end, the tail, or stem, 877 carries a rearward projecting abutment pin 878, used in the division operation of the machine (FIGS. 22, 25, and 26). Rearward of the pivot 566, an arm 879 projects up from the rearward directed arm 877 and then extends to the left to constitute at tongue 880 positioned to be engaged by the abutment formations 608 and 577 (FIG. 19) of the lowest (rightmost) order tens-transfer levers 557 and 559 when these levers are released by the right-hand legs of the "fugitive 1" entering bails 635 and 649, as previously described.

When, as explained above in connection with FIG. 19, the highest order (leftmost) accumulator gear 554 is turned in a negative direction through its "0" to "9" position because of an overdraft in the register, the negative "fugitive 1" entering bail will be rocked to release the lowest order negative tens-transfer lever to subtractively enter a "fugitive 1" into the register to give a true negative balance. When the lowest order negative tens-transfer lever moves, it engages the tongue 880 (FIG. 30) and rocks the sign sensing gate 875 to its negative position, which is the clockwise, or broken line, position, as shown in FIG. 30. When, on the other hand, the highest order accumulator gear moves in a positive direction from its "9" to "0" position in response to a change of sign from negative to positive of the values stored in the accumulator, the positive lowest order tens-transfer lever will engage the tongue 880 and rock the sign sensing gate 875 to its positive position, as shown in full lines in FIG. 30.

The gate 875 is detented in its positive and negative positions by a bellcrank lever 881, rockably mounted at its angle on a pivot stud 882, and having an arm 883 provided with notches in which a pin 884 on the arm 877 engages in the different positions of the gate. A spring, 885, connected between a bellcrank lever arm 886 and a fixed spring stud, resiliently holds the notched end of the arm 883 in engagement with the pin 884.

A feeler finger 887 (FIG. 30) in the form of a bellcrank lever, is rockably mounted at its angle on a pivot stud 888, mounted on the right-hand end plate of the shiftable accumulator carriage frame, rearward of the upper bail cross-member 860. The finger 887 has an arm 889 projecting forward from the stud 888 and engaged at its forward end under the bail cross-member 860, and has a second arm 890 extending up from the pivot 888. A spring 891, connected between the upper end of the arm 890 and a fixed stud, resiliently urges the lever 887 to rock in a clockwise direction as seen in FIG. 30 to maintain the forward end of the arm 889 against the lower edge of the bail cross-member 860.

A second, or lower, feeler finger, in the form of a bellcrank lever 895, is rockably mounted at its angle on a pivot stud 896 carried by the right-hand end plate of the accumulator carriage frame. This lever has one arm 897 extending forward from the stud 896 and bearing near its front end on the upper edge of the bail cross-member 861. A second arm 898 of the lever 895 extends down from the stud 896, and a spring 899, connected between the lower end of the arm 898 and a fixed stud, resiliently urges the lever 895 to rock in a counter-clockwise direction in FIG. 30 to maintain the forward end portion of the arm 897 in engagement with the upper edge of the cross-member 861.

The jaw-like bails 860 and 861 are normally held apart against the force of the spring 866 by a rectangular gate 900 mounted on the upper portion of the shaft 838 and extending rearward from this shaft. A vertically disposed flange 901 extends laterally from the rear end of the gate 900 and has a length greater than the width of the gate so that the flange extends above, and below,

the gate. The lower edge of the arm 856 rests on the upper end of this flange 901 and the upper edge of the bail arm 858 bears against the lower end of the flange.

The cross portion of the sign sensing gate 875 is provided with oppositely extending abutment formations 902 and 903. The sensing fingers 889 and 897 are provided with shoulders 904 and 905, respectively, and when the sign sensing gate is in its positive position, as illustrated in solid lines in FIG. 30, indicating a positive total in the accumulator, the outer end of the abutment formation 902 is in alignment with the shoulder formation 904 of the finger 887 and holds this finger against rocking movement. At the same time, the abutment formation 903 is out of alignment with the shoulder 905 of the sensing finger 895 so that this finger is free to move. When the sign sensing gate 875 is in its alternative, or negative, position (dotted lines in FIG. 30), the finger 895 is blocked against movement by abutment 903 while the finger 887 is free to move.

The gear shaft 531 of the negative or subtractive pendent gear assembly 526 (FIG. 19) is extended to the right and underlies the left-hand leg 856 of the upper bail (FIG. 30), and the gear shaft 518 of the positive or additive pendent gear assembly 512 is extended to the right and overlies the left-hand bail leg 858. The sign sensing mechanism of FIG. 30 is put into operation when gate 900 is turned to a non-blocking position and link 870 is moved forward to release bellcranks 856 and 858 to the action of spring 866. Under this condition, if the upper bail leg 856 is free to move by reason of the sign sensing gate 875 not blocking the upper feeler finger 887, the spring 866 will depress shaft 531 to move the negative pendent gear assembly into mesh with the accumulator drive gears 513 (FIG. 19) to read out a negative value from the accumulator, whereas, if the lower bail leg 858 is free to move by reason of the non-alignment of the sign sensing gate 875 with the shoulder 905 of the lower feeler finger 895, the positive pendent gear assembly 512 will be moved into mesh with the accumulator drive gears 513 to read out a positive value from the accumulator.

The zero blocking bails 641 and 642 (FIG. 22) are supported by bail legs at the respectively opposite sides of the accumulator 505 and the bail legs at the right-hand side of the accumulator are indicated at 906 and 907 (FIG. 22) for the bails 641 and 642, respectively. The bail 641 is rockably mounted on the transverse shaft 580 and the bail leg 906 has a forward projecting arm 909 which overrides the transverse portion 861 of the spring-operated bail 858 (FIG. 30). Similarly, the zero block bail 642 is rockably mounted on the transverse shaft 597, and the right-hand leg 907 of this bail has a forward projecting arm 911 which underlies the lower edge of the cross-member 860 of the spring-actuated bail 856. It is apparent from this description that when the lower, or positive read-out, bail 858 is moved up by the spring 866 (FIG. 30), the lower, or positive, zero blocking bail 641 (FIG. 22) will be set (see also FIG. 19), and when the upper, or negative, read-out bail 856 is moved down by the spring 866, the upper, or negative, blocking bail 642 will be set.

When the SUB TOTAL key is depressed (FIG. 29), the sub-total link 823 is moved forward, rocking the bail 842 to lift the hook 845 from the abutment formation 852 at the upper end of the lever 850, thereby freeing this lever so that the cam following roller 855 (FIG. 30), carried by this lever, can follow the peripheral contour of the subtotal cam 225. When a lobe 912 of the cam 225 moves away from the roller 855, the lever 850 is free to rock and thus the link 870 is moved forward. At the same time that the link 823 is moved forward, the blocking link 832 (FIGS. 29 and 30) is moved rearward, turning the shaft 838 to move the flange 901 of the blocking gate 900 from between the jaw bails 856 and 858. With

the gate 875 in the position shown in FIG. 30, the bail 858 will now be free to move up, since the abutment 903 of the sign sensing gate 875 is out of alignment with the shoulder 905 on the sensing feeler 895. This upward movement of arm 858 will move the positive pendant gear assembly 512 (FIGS. 19 and 22) into mesh with the accumulator drive gears 513 and will simultaneously set the positive zero blocking bail 641. Since depression of the SUB TOTAL key causes the machine to cycle, as explained above, those actuator sectors 450 which are in ordinal alignment with the drive gears 513 of the accumulator, will be rocked until the coordinate accumulator gears are brought back to their "0" positions, in which positions they will be stopped by the abutments 587, which are blocked by the set zero blocking bail 641. This action will read the value standing in the accumulator into the actuator sectors and these sectors will set the printing mechanism to print the subtotal in a manner to be later described. If the sign sensing gate 875 (FIG. 30) had been in its alternative position from that shown in full lines in FIG. 30, the upper bail 856 would have been free to move, since the sign sensing gate 875 would then have been out of alignment with the sensing finger 889 and downward movement of the bail leg 856 would have moved the negative pendant gear assembly 526 into engagement with the accumulator drive gears and would have set the negative zero blocking bail 642.

When a positive value is read out of the accumulator, the accumulator gears are driven backward to "0," that is, in the negative direction. Although the positive readout is performed by the positive pendant gear assembly, the accumulator gears turn in the negative direction because the readout from the accumulator is made during the first half of the operating cycle. Thus the positive pendant gears are used for both entry and readout of positive values. Similarly, for reading out a negative total, the accumulator gears are driven by the negative pendant gears in the forward, or positive direction, to "0," because the actual value in the accumulator is the tens complement of the negative value that is read out and printed.

Since accumulator 505 is shiftable, the readout operation may take place when some sectors at the left, or higher order, portion of the actuator are not aligned with any gears of the accumulator. Accordingly the rear shiftable accumulator 505 is provided with a plate which extends to the left of the left-hand frame plate of the accumulator and engages the gears of either of the pendant gear assemblies to the left of the highest order gear of the accumulator to hold the corresponding gears of the pendant gear assembly which has been moved into driving association with the accumulator against movement. This holds all of the actuator sectors 450 to the left of the highest order accumulator gear against movement so that erroneous values cannot be entered into the printing mechanism above the highest order of the accumulator.

It will be noted that the bails 856 and 858 (FIG. 30) cannot move to set the pendant gear assemblies of the shiftable, or principal, accumulator 505 to extract a total from this accumulator unless the blocking gate 900 is swung out of the way of these bails by rearward movement of the link 832. It will also be noted that, since the selected pendant gear assembly is meshed with the accumulator drive gears at the beginning of the operation, the total value will be read out of the accumulator during the downward movement of the actuator sector operating bail 453 (FIGS. 16, 17 and 21) so that the total value can be printed during the dwell at the bottom of the downward stroke of the actuator. The upward stroke of the actuator then restores the actuator sectors and the printing mechanism to "0" position.

Since the lobe 912 of the subtotal cam 225 (FIG. 30) is of limited angular extent, the selected pendant gear assembly will remain in mesh with the accumulator drive gears during the upward stroke of the operator bail. The

value which was read out of the accumulator during the downward stroke of the actuator bail 453 will thus be restored to the accumulator during the upward stroke of this bail. Just at the end of the cycle and after the actuator sector operating bail 453 has been returned to its upper, or full-cycle, position, the roller 855 (FIG. 30) rides up onto the cam lobe 912, thereby disconnecting the selected pendant gear train assembly from the accumulator drive gears. Since the subtotal key 315 will have been released before the end of the cycle, movement of the cam lobe 912 under the roller 855 will rock the lever 850 in a counter-clockwise direction, as shown in FIG. 30, causing the hook 845 to relatch the abutment formation 852 at the upper end of this lever. Movement of the lever 850 in the direction specified will move the link 870 rearward, thereby forcing the jaw-like bails 856 and 858 apart so that the flange 901 of the blocking gate 900 can return to its position between the right-hand bail legs and hold the bails in inoperative position. The springs 891 and 899 maintain the forward ends of the feeler fingers 887 and 895 against the adjacent edges of the bail cross-members 861 and 860 so that the sensing finger 887 or 895, which had been moved in for the taking of the subtotal, is moved out of the way of the corresponding abutment formation on the sensing gate 875, freeing this gate to change its position if the sign of the total value in the accumulator changes. The length of the bail cross-members 860 and 861 is such that the fingers 887 and 895 can slide along these cross-members during shifting movements of the primary accumulator.

10. TOTAL-TAKING OPERATION

As shown in FIGS. 27 and 31, the TOTAL key 318 has a flat stem 915 guided in the front frame member flanges 816 and 817 for vertical movement. This key is raised by a spring 916 to its upper limiting position as determined by the engagement of a pin 917 carried on the stem engaged with the undersurface of the upper frame member flange 816. Near its lower end, the key stem 915 carries a pin 918 which engages in the inclined notch 919 of a yoke member 920 mounted on, and extending up and forward from, the shaft 155 so that, when the TOTAL key is depressed, the shaft 155 is rocked by the yoke member 920 to establish an operating cycle of the machine in the manner described above. The pin 917 rests on the upper surface of a forward extending tongue 921 of a bail 922 rockably mounted on the shaft 443 and urged to a limiting position in a clockwise direction of movement by a spring 923. An arm 924 extends up from the bail 922 and is connected at its upper end to the forward end of a total-taking control link 925 by a pivotal connection 926. Near its rear end, the link 925 carries a laterally projecting pin 927, which rests on the upper, or rear, edge of one arm 928 of a lever 929 rockably mounted on the shaft 843. Lever 929 lies between the two arms of bail 842 (FIG. 30A) and has a leftward-extending ear 930 that overlies the forward extending arm 846 of bail 842. Thus depression of the TOTAL key 318 rocks bail 842 as in the SUB TOTAL operation for lowering pin 750 and link 748 and for lifting latch 845 from ear 852 of the subtotal lever 850.

A bellcrank lever 935 (FIG. 31) is rockably mounted on the shaft 851 on which the subtotal lever 850 is mounted, and this bellcrank lever has an arm 936 extending up from the shaft 851 and an arm 937 extending rearward from this shaft. The arm 937 carries at its free, rear end, a cam following roller 938 riding on the peripheral edge of the total cam 226 so that rocking movement of the lever 935 is controlled by the total cam. A spring 939 connected between the lever arm 937 and a fixed stud 934, holds the roller 938 in contact with the edge of the total cam.

A pawl lever 940 is pivotally connected at one end to the upper end of the bellcrank lever arm 936 by a pivot

pin 941 and has at its forward, or free, end, a shoulder formation 942 projecting up from the upper edge of the pawl. A spring 943 urges the pawl to its lower, or retracted, position, as shown in FIG. 31.

The lever 929 has an arm 944 extending down and rearward from the shaft 843 and terminating at its rear end in an up curved portion 945, which bears against the under edge of the pawl 940.

When the TOTAL key is depressed, it moves the link 925 forward and the pin 927 rocks the lever 929 in a counter-clockwise direction, as viewed in FIG. 31. Rocking of the lever 929 raises the free forward end of the pawl 940 as the hook formation 845 is lifted away, and the shoulder 942 is engaged with the rear edge of the abutment formation 852 so that rocking movements of the lever 850 are now controlled by the total control lever 935 and the total cam 226.

The total cam 226, shown in home position in FIG. 31, has a lobe portion extending through an angular extent only slightly less than 180°, and the trailing end of this lobe portion is positioned under the roller 938 when the cam is in its full-cycle position.

Depression of the TOTAL key also rocks the bail 827 (FIGS. 4 and 29) and shifts the link 832 (FIGS. 29 and 30) rearward to remove the blocking gate 900 from between the jaw-like bails 856 and 858, in the same manner as described above in connection with the subtotal operation, so that one of these bails will move the subtract pendent gear assembly 525 or the add pendent gear assembly 512 into meshing engagement with the primary accumulator drive gears 513 (FIGS. 16 and 19), as described above. Immediately after the total-taking machine cycle starts, the lobe portion of the cam 226 moves from under the cam following roller 938, thereby freeing the levers 935 and 850 to rock in a clockwise direction, as viewed in FIG. 31. This shifts the control link 870 (FIG. 30) forward and frees the bail members 856 and 858 to engage the selected pendent gear assembly with the accumulator drive gears. The actuator sector operating bail 453 (FIGS. 16, 17 and 21) is then moved down to transfer the value from the rear accumulator 505 into the actuator, as in the subtotal taking operation.

During the dwell at the end of the down stroke of the accumulator sector actuating bail 453, the total value read out of the accumulator is printed. However, as soon as the printing has been completed, the lobe of the total cam 226 (FIG. 31) picks up the cam following roller 938 and restores the levers 850 and 935 to their original position, and the selected pendent gear assembly is disengaged from the accumulator. The accumulator is now in its cleared, or "0," condition and, since no pendent gear is in driving engagement with the accumulator while the actuator sectors are restored by upward movement by the sector operating bail to their full-cycle position, the total value is not returned to the accumulator, and the accumulator is left in its cleared, or "0," condition.

At its rear end, the total control link 925 carries a down extending hook formation 955 which engages behind a laterally extending abutment formation 956 on the upper end of a clear-signal lever 957 rockably mounted intermediate its length on a fixed pivot support 958. The full description of the clear signal will be found in Harold J. Chall Patent No. 2,857,098, wherein lever 1096 shown in FIG. 14 is identical to lever 957 herein.

11. POSITIVE AND NEGATIVE TRANSFERS INTO THE GRAND TOTAL REGISTER

Totals can be transferred from the primary accumulator 505 to the grand total accumulator 489 and entered there either additively or subtractively. Each such interregister transfer leaves the primary accumulator cleared and either adds the transferred value to, or subtracts it from, any value already in the grand total accumulator. The operation is initiated by setting lever 305 (FIG. 7) for either

an additive or subtractive grand total entry and then depressing the TOTAL key 318.

As shown in FIG. 33, a lever 960 is rockably mounted intermediate its length on the transverse shaft 731 and has at its forward end an up facing cam edge 961. At its rear end, this lever is provided with a yoke, or fork, formation 962 having therein a longitudinally extending notch, or slot, 963. This notch slidably receives a pin 970 projecting laterally from a link 964 pivotally mounted at its rear end on the pivotal mounting, or stub, shaft 735 carried at the upper end of the intermediate arm 739 of the three-armed lever 740, which is rocked by the add-subtract control cam 227 on the main power shaft of the machine. As has been previously explained, a second arm 742 of the three-armed lever 740 carries the cam following roller 743, engaging the peripheral edge of the add-subtract cam. The third arm 744 is connected to the spring 745, which rocks the lever 740 in a counter-clockwise direction to maintain the roller 743 in firm engagement with the edge of the add-subtract cam. A spring 965, connected between the arm 739 and a down projecting extension 966 on the link 964, urges the forward end of this link down to a position in which a downward extension 967 on the rear portion of the lever 960 rests on a shelf 968 provided on a fixed guide bracket 969. The link 964 has at its forward end, a shoulder formation 971 disposed immediately rearward of the tongue 482 (FIG. 16) of the front add pendent gear assembly 475.

With this arrangement, it will be observed that when the lever 960 is rocked in a counter-clockwise direction, as viewed in FIG. 33, the forward end of the lever 964 will be raised to bring the shoulder formation 971 into alignment with the add pendent gear tongue 482. Then, when the lever 740 is rocked counter-clockwise by the cam 227 and the spring 745, during the last half of a machine cycle, the add pendent gear will be swung to mesh its gears 484 with the drive gears 488 of the grand total accumulator.

As shown in FIG. 34, a lever 972 is also mounted on the pivot shaft 731 in side-by-side relationship to the lever 960 and this lever 972 is provided at its forward end with an up facing cam edge 973. At its rear end, the lever 972 is provided with a fork formation 974 having therein a longitudinal slot 975. This lever has near its rear end, a downward projection 976 which rests on the guide bracket shelf 968 when the levers are in their retracted, or unoperated, position, as shown in FIG. 34.

A link 977 is pivotally mounted at its rear end on the stub shaft 735 carried by the intermediate arm 739 of the add-subtract cam lever 740 and extends forward into overlapping relationship with the rear portion of the lever 972. This link 977 has, near its front end, a down projecting extension 978 which extends through a slot in the guide bracket shelf 968 to guide the front end of the lever, and has, intermediate its length, a laterally projecting pin 979 which is received in the slot 975 in the fork formation 974 at the rear end of the lever 972. A spring 980 is connected between the intermediate arm 739 of the add-subtract cam lever and a down extension 981 on the link 977. The extension 981 projects down below the spring 980 and carries, at its lower end, a forward directed foot formation 982, which, when the forward end of the link 977 is raised by counter-clockwise rocking of the lever 972, is brought into opposition to the right-hand end of the intermediate gear shaft 494 (FIG. 16) of the subtract pendent gear train 490. Thus, with the lever 972 rocked as indicated above, when the add-subtract lever 740 is rocked counter-clockwise by the cam 227 and the spring 745, during the last half of a machine cycle, the link 977 will be moved forward and the foot formation 982 carried by this link will engage the extended right-hand end portion of the gear shaft 494 and move the subtract pendent gear train assembly 490 (FIG. 16) to mesh the gears 497 thereof with the drive gears 488 of the grand total accumulator.

Rocking of the levers 960 and 972 is controlled by a

bail 985 (FIGS. 33 and 34) rockably and slidably mounted on a short transverse shaft 986 projecting to the right from the upper portion of the bracket 969. The bail 985 has a rearward and upward projecting arm 987 and a forward projecting arm 988. At its upper end, the arm 987 carries a laterally projecting pin 989 received in a notch 990 in an offset hook formation 991 extending from the upper edge of the total control link 925. With this arrangement, each time the total control link 925 is shifted forward by depression of the total key 318, the bail 985 is rocked in a counter-clockwise direction, as viewed in FIGS. 33 and 34.

At its front end, the arm 988 carries a roller 992 which is selectively engageable with the cam edges 961 and 973 of the levers 960 and 972, respectively, depending on the position of the bail 985 along the shaft 986.

The position of the bail 985 along the shaft 986 is controlled by the lever 305 (FIGS. 2 and 7), through the intermediary of a bellcrank lever 995 and a link 996. The bellcrank lever 995 is pivoted at its rear end on screw 993 (FIG. 35) at the upper end of bracket 969 (FIGS. 33 and 34) and is connected at its other end to the rear end of the link 996 by a pivotal connection 994. At its forward end, the link 996 is connected to the flat stem of the lever 305 (FIG. 2) below the pivotal mounting 999 of this lever on the machine frame. At its bottom end the lever stem 998 is provided with three spaced detent notches 1000, 1001 and 1002. A detent pin 1003, carried by a spring-biased detent lever, not illustrated, seats selectively in the detent notches to latch the lever 305 in any one of its three positions. At its angle, the bellcrank lever 995 carries a pin 1004 which depends from the lever between the arms 987 and 988 of the bail 985.

As explained above, each time the total control link 925 is moved forward, the bail 985 is rocked counter-clockwise (FIGS. 33 and 34). When the setting lever 305 is in its neutral position, the bellcrank lever 995 positions the bail 985 so that the roller 992 (FIG. 35) misses both cam edges 961 and 973 of the levers 960 and 972. Accordingly, the machine performs a total-taking operation (taking the value from the primary accumulator 505, printing and clearing) without entering any value in the grand total accumulator. When the setting lever 305 is tilted forward, exposing the plus (+) sign through the window of the casing (not shown), the bail 985 is moved to the right along the shaft 986 until the roller 992 is over the cam edge 961 of the addition control lever 960 of the grand total accumulator. Under these conditions, the add pendent gear train 475 (FIG. 16), one end of which is continuously engaged with the actuator sectors 450, is engaged with the drive gears 488 of the grand total accumulator by the add-subtract cam 227 (FIG. 33) and lever 740 at the end of the downward movement of the actuator sectors. This operates to hold the add pendent gear train 475 in engagement with the gears 488 during the upward movement of the actuators so that the total value which was extracted from the primary accumulator 505 by the total-taking operation and set up in the actuator sectors during the down stroke of the actuators, is entered into the grand total accumulator during the up stroke of the actuators as the actuator sectors are returned to their normal, or "0," position. Since the link 964 has no formation engageable with the forward edge of the add pendent gear tongue 482, and since the link 748 (FIG. 37) has been depressed out of engagement with the tongue 482 at the beginning of the total operation, the add pendent gear 475 will not move into engagement with the selection sectors 331 during this operation.

If the lever 305 is tilted rearward to its subtract position, the bail 985 will be moved to the left along the shaft 986 by the bellcrank lever 995 until the roller 992 is above the cam edge 973 of the subtract control lever 972. Under these conditions, as shown in FIG. 34, when the TOTAL key is depressed and the bail 985 is rocked by the forward movement of the total control link 925, the

link 977 will be raised to bring the foot formation 982 into opposition to the extended right-hand end of the shaft 494 of the subtract pendent gear 490 (FIG. 16), as explained above. Under these conditions, when the add-subtract cam 227 rotates, the subtract pendent gear train 490 will be meshed with the grand total accumulator drive gears 488 at the end of the down stroke of the actuator sector operation and will remain in engagement with these drive gears during the up stroke of the actuators so that the value read out of the primary accumulator 505 and set up in the actuator sectors will be subtractively entered into the grand total accumulator 489 as the actuator sectors are returned to their neutral, or "0," position.

15 The total-taking operation extracts the value from the primary accumulator 505 in the form of its absolute value accompanied by an indication of sign which controls the symbol printing wheel. This sign indication is not carried over automatically to the entry of the value into the grand 20 total accumulator 489, and accordingly, the operator must choose the sign of each such entry by means of key 305. Referring again to FIG. 2, a bellcrank lever 1005 is rockably mounted at its angle on a fixed pivot screw 1006 and has an arm 1007 extending down and rearward from 25 the pivot screw. At its distal end, the arm 1007 is provided with an up facing abutment formation 1008 which is engaged by a roller 1009 on the carriage tabulator control cam 233. The bellcrank lever 1005 also has an arm 1010 extending forward from the pivot screw 1006 and 30 provided at its forward end with a V-shaped formation 1011 disposed immediately below a pin 1012, which pivotally connects the forward end of the link 996 to the lever stem 998. The bellcrank lever 1005 is rocked by the roller 1009, in a clockwise direction as viewed in 35 FIG. 2, each time the machine cycles, to raise the V-shaped formation 1011. When the V-shaped formation is raised, one side or the other will engage the pin 1012, depending upon the addition or subtraction position of the lever 998, and will return the lever to its neutral position at the end of a cycle if the lever has previously been 40 set to enter a total value extracted from the primary accumulator into the grand total accumulator. The lever 305 thus must be manually set to the selected addition or subtraction position each time a value is entered into the grand total accumulator.

12. SUB GRAND TOTAL-TAKING OPERATION

Referring to FIGS. 7 and 36, the SUB GRAND TOTAL key 313 has a flat stem 1035 guided for vertical movement in the transverse flanges 816 and 817 of the front frame member 114. This key stem has a forward directed extension 1036 which rides on the upper edge of the bail 820 which is rockably mounted on the transverse shaft 443. As has been previously described in connection with the subtotal operation (FIG. 29), the bail 820 has an up directed arm 822, at the right-hand side of the machine and this arm is pivotally connected at its upper end to the forward end of the subtotal control link 823 to move this link forward when the bail 820 is rocked either by the SUB TOTAL key 315 or the SUB GRAND TOTAL key 313. This releases the upper end of the subtotal lever 850 so that the cam following roller 855 on the arm 834 (FIG. 30) of this lever can follow the contour of the subtotal cam 225.

65 A pin 1037 (FIG. 36) projecting laterally from the lower portion of the key stem 1035, engages in the inclined slot 1038 of a yoke 1039 which is mounted on the shaft 155 and rocks this shaft when the SUB GRAND TOTAL key is depressed. Rocking of the shaft 155 (FIG. 4) enables the main clutch of the machine and closes the motor switch to cycle the machine in the manner described above in connection with the addition and subtraction operations. The bottom end of the key stem 70 1035 engages the upper edge of an inner bail 1040 (see

also FIG. 4), which is also rockably mounted on the shaft 155. This bail 1040 has a depending arm 1041 pivotally connected at its lower end to the forward end of a link 1427, the rear end of which is pivotally connected to the lower end of a depending arm 1428 of a symbol printing control bail 1429 rockably mounted on the shaft 831. A spring 1045, connected between an extension 1046 on the key stem 1035 and the upper portion of the front frame 114, raises the key 313 to its upper position when downward pressure on the key is relieved.

The curved link 1050 (FIG. 36) is pivotally connected at its upper end to the distal end of the arm 854 of the subtotal lever 850 (FIG. 30) so that, during this sub-grand-total operation, cam 225 and roller 855 control the movements of the link 1050. Link 1050 actuates a sign sensing mechanism for the grand total accumulator which is similar to the sign sensing mechanism shown in FIG. 30 for the primary accumulator 505.

A pair of mutually opposed, bellcrank-shaped feeler fingers 1051 and 1052 is rockably mounted at their angles on a bracket 1053 extending up from the machine base 100 at the right-hand end of the fixed, or grand total, accumulator 489, the feeler finger 1051 being supported on a pivotal mounting 1054 and the sensing finger 1052 being pivotally mounted on a support 1055. A spring 1056, connected between up extending arms of the fingers 1051 and 1052, urges these arms together. Arms 1057 and 1058 on the fingers 1051 and 1052, respectively, extend in or toward each other from the pivotal mountings 1054 and 1055 and carry, at their inner ends, laterally projecting pins 1059 and 1060, respectively. A blocking gate 1061, mounted on a shaft 1062 rockably mounted on the bracket 1053, normally engages under the pins 1059 and 1060 and holds the sensing fingers 1051 and 1052 against movement by the spring 1056. An abutment cam plate 1063, mounted on the link 1427, engages a pin 1064 projecting radial from the shaft 1062 and rocks this shaft when the link 1042 is moved rearward in response to depression of the SUB GRAND TOTAL key 313. This rocking of the shaft 1062 moves the blocking gate 1061 from under the pins 1059 and 1060 and frees the sensing fingers 1051 and 1052 for movement by the spring 1056 when other conditions, to be presently described incident to the freedom of movement of these sensing fingers, have been accomplished.

After the blocking gate 1061 has been moved from under the pins 1059 and 1060 by depression of the SUB GRAND TOTAL key 313, the sensing fingers 1051 and 1052 are still held by the link 1050 against movement by the spring 1056. At its lower end the link 1050 carries a laterally projecting pin 1066 which engages under the overlapping arms 1057 and 1058 of the sensing finger levers and holds these levers against movement until the lobe 912 (FIG. 30) of the subtotal cam 225 moves from under the cam following roller 855. As soon as the subtotal cam lobe moves from under the roller 855, the upper end of the lever 850 having been released from the hook 845 by depression of the key, the sensing fingers 1051 and 1052 (FIG. 36) are free to move, except that one of them will still be restrained against movement by a sign sensing gate 1065 (FIGS. 36 and 37).

The sign sensing gate 1065 is a T-shaped structure, pivotally mounted at the midlength location of its cross-member on gear shaft 660 (FIG. 16) carried by the right-hand end plate of the fixed, or grand total, accumulator. This sensing gate has laterally extending wing formations 1071 and 1072 and is rocked between two different operative positions by a tongue 1073 (FIG. 16) extending to the left from the end of the stem portion of the member. This tongue is engaged by the first order arms, similar to the arms 606 and 575 of the positive and negative tens-transfer levers 559 and 557 of the primary accumulator 505, as shown in FIGS. 19 and 22.

With this arrangement, when the total in the grand total accumulator is positive, the sensing gate 1065 will

be rocked counter-clockwise to block the finger 1052 (FIG. 36) and to release the finger 1051 so that this finger can engage the projecting right-hand end of the gear shaft 480 of the positive pendent gear assembly 475 (FIG. 16) to move this pendent gear assembly into mesh with the accumulator drive gears 488 to positively read out the positive value in the accumulator during the down stroke of the actuator sector operating bail 453. When the value in the accumulator is negative, the gate 1065 is rocked to block the positive sensing finger 1051 and free the negative sensing finger 1052 to engage the projecting right-hand end of the gear shaft 495 of the negative pendent gear assembly 490 to engage this assembly with the drive gears 488 of the fixed accumulator to read out the negative value in this accumulator during the down stroke of the actuator sector operating bail 453.

The values read out of the grand total accumulator into the actuator sectors, are printed at substantially the midpoint of the cycle, as will be presently described, and 20 after this has been accomplished, the value is returned to the grand total accumulator during the upstroke of the actuator 450, since the restricted lobe on the subtotal cam will not move the link 1050 and the sensing fingers 1051 and 1052 to release the actuated pendent gear assembly from the accumulator drive gears until substantially the end of the subtotal-taking cycle.

A pin 1074 (FIG. 36), projecting to the left from the upper portion of the up extending arm of the sensing finger 1051, engages the positive blocking bail 711 (FIG. 32) to move this bail to blocking position when the lever 1051 is moved to mesh the positive pendent gear assembly with the accumulator drive gears, and a similar pin 1075 projects from the upper portion of the up extending arm of the lever 1052 to move the negative blocking bail 713 (FIG. 32) to blocking position when the lever 1052 is moved to engage the negative or subtractive pendent gear train with the accumulator drive gears.

13. GRAND TOTAL-TAKING OPERATION

Referring to FIGS. 7 and 37, the GRAND TOTAL key 316 has a flat stem 1076 guided for vertical movement in the transverse flanges 816 and 817 of the front transverse frame member 114. This stem carries a laterally projecting pin 1077 which rides on the upper surface of a forward projecting finger 1078 of the bail 922 (see also FIG. 31). This total bail 922 is rockably mounted on the transverse shaft 443, as previously described, and is resiliently urged in a clockwise direction to its inoperative position by the spring 923. The up-projecting arm 924, at the right-hand end of this bail, is pivotally connected at its upper end to the forward end of the total control link 925, as previously described, and near its rear end, the link 925 carries a laterally projecting pin 927 which rocks the lever 929 rockably mounted on the transverse shaft 843. As was described in detail in the total-taking operation (FIG. 31), the lever 929, when rocked, disengages the hook 845 from the upper end of the lever 850 to free this lever, simultaneously sets the detent pawl 940 against the abutment 852 at the upper end of the lever 850 to latch the bellcrank lever 935 to the lever 950 so that movements of this lever will be controlled by the total cam 226 instead of the subtotal cam 225, and through ear 930 (FIG. 30A), rocks bail 842 and lever 751 (FIG. 31) to lower shoulder 754 of the link 748 below ear 482 of the front add pendent 475.

Near its lower end, the key stem 1076 (FIGS. 27 and 37) carries a laterally projecting pin 1079 engageable in the notch 1080 in a yoke 1081 mounted on the shaft 155. When the key 318 is depressed, the action of the pin 1079 on the yoke 1081 rocks the shaft 155 to engage the main clutch of the machine and close the motor switch so that the machine will cycle, as has been previously described.

The bottom end of the key stem 1076 rests on the upper edge of the bail 1040 to rock this bail and move the link 1427 rearward so that the abutment cam plate 1063 on this link will swing the blocking gate 1061 to its inoperative position. At its rear end, the link 1427 is pivotally connected to the lower end of the depending arm 1428 of the symbol printing control bail 1429, the operation of which will be later described.

The operation of the link 1050, the spring 1056, and the sensing finger levers 1051 and 1052, in meshing the positive pendent gear assembly 475 and the negative pendent gear assembly 490 with the drive gears of the fixed, or grand total accumulator, is the same as that described above in connection with the sub grand total operation, except that the operation of the link 1050, being now under the control of the total cam 226 after the value has been read out of the fixed accumulator and printed, the associated roller will ride back onto the lobe, or high portion of the total cam and the fingers 1051 and 1052 will be immediately retracted, disengaging the activated pendent gear assembly so that the value read out of the accumulator during the down stroke of the actuating sectors will not be returned to the accumulator during the up stroke of the actuator. The grand total accumulator will thus be left in a zeroized, or cleared, condition at the end of the grand total cycle.

14. PRINTING OPERATION

Referring particularly to FIG. 16, the ordinarily arranged print wheel drive gears 486 are in mesh with the coordinate gears 481 of the add pendent gear train 475, and the gears 481 are constantly in mesh with the coordinate actuator sectors 450. With this arrangement, the drive gears 486 will be turned an amount proportional to the movement of the coordinate actuator sectors 450 during the down stroke of the actuator 453 and will be returned to their "0" position during the up stroke of the actuators in which the actuator sectors 450 are returned to their normal, or "0," position.

A plurality of ordinarily arranged print wheel carriers 1085 is rockably mounted on a transverse shaft 1086. Each of these carriers carries a rotatably mounted idler gear 1087 which meshes with the coordinate drive gear 486 when the carrier is in its normal, or retracted, position, as illustrated in FIG. 16. Each carrier also carries a print wheel 1088 having digit values from "0" to "9" uniformly spaced around the periphery thereof, except that the extreme right-hand print wheel carries machine operation symbols instead of digit values, as will be later explained. Each print wheel has, at one side thereof, a gear 1089, the teeth of which mesh with the coordinate idler gear 1087 so that the print wheels will be set to values corresponding to the movements of the coordinate actuator sectors 450. A paper-carrying platen 1090 is disposed immediately to the rear of the print wheels 1089 and is mounted on a rotatable shaft 1091 which is given an increment of rotational movement, as will be later explained, immediately after each printing operation so that the values printed by the printing, or type, wheels will be properly spaced lengthwise of the paper or strip on which the values are printed. The platen also moves longitudinally with the paper carriage in which it is mounted, as will be later described in detail.

Each print wheel carrier 1085 has a rearward extending tail portion 1092 (FIG. 16), and a spring 1093 is connected between the rear end of each tail portion 1092 and the transverse shaft 527 to rock the carriers in a manner to strike the print wheels against the front side of the platen 1090 when the carriers are released. The carriers are normally held in their retracted position by a transverse bail rod 1094 which extends transverse the machine and upon which the rear end portions of the tail formations 1092 of the print wheel carriers rest.

Referring to FIGS. 20 and 48, the print control bail rod 1094 is supported at its ends by bail legs, the left-

hand one of which is shown in FIGS. 20 and 48 and indicated at 1095. These bail legs are rockably mounted on the shaft 1086 (FIG. 20) on which the print wheel carriers are mounted, and are urged down at their rear ends by individual springs, as indicated at 1096. The bail rod 1094 extends through the vertical frame plates 107 and 108 and moves through substantially vertical slots in these frame plates, as indicated at 1097, for the plate 107.

10 As shown in FIG. 48, an arm 1098 is rockably mounted on the print wheel idler gear shaft 487 and carries at its other end a cam following roller 1099 which is disposed above, and rearward of, the main drive, or cam, shaft 135 and rides on the periphery of the print control cam 220. An arm 1100, also mounted on the shaft 487, is fixed at its forward end to the upper end of the arm 1098 and has the upper edge of its rear end disposed beneath a pin 1101 carried by the bail leg 1095.

The cam 220 has a deep low portion 1102 of limited angular extent, which low portion comes into registry with the cam following roller 1099, approximately 180° after the beginning of the machine operating cycle and just after the actuating sector rod 453 (FIG. 16) reaches the end of its down stroke. The roller 1099 is in the low portion 1102 during the middle portion of the cycle. While the rod 453 dwells at the bottom of its stroke and just before the rod starts its up stroke, the roller 1099 rides out of the low portion 1102 and restores the print wheel carriers to their normal, or full-cycle, position.

15. PRINT BLOCKING MECHANISM

The machine is equipped with a ribbon mechanism, including ribbon spools 1300 (FIG. 2) and 1301 (FIG. 38) disposed to the right and left, respectively, of the printing mechanism and mounted on a ribbon supporting and feeding mechanism 1302 which is mounted on the upper edges of the vertical side plates of the machine. As such ribbon mounting and feeding mechanisms are well-known in the art, a detailed description is considered unnecessary for the purposes of the present disclosure. A bracket 1303 (FIG. 2) is detachably mounted on, and extends up from, the paper carriage. This bracket carries a paper roll 1304, upon which the paper strip is led past the print wheels for use in listing addition and subtraction items, with the paper carriage locked in its right-hand position, as described above. The bracket 1303 can be easily detached from the paper carriage when it is desired to use the tabulating features of this carriage.

As shown in FIG. 20, the lever arm 1305 is adjustably clamped onto the left-hand end of the shaft 537 which carries the actuator detenting arms 536 (FIG. 16). A hook 1306 projects forward from arm 1305, and the spring 1307, connected between this hook and a bracket 1308 to which the lower end of the spring 1096 is attached, resiliently urges the arm 1305 and the shaft 537 to rock in a counter-clockwise direction, as viewed in FIG. 20.

The lever 1309 (FIG. 20) is rockably mounted on the shaft 487 on which the print control arms 1098 and 1100 are mounted (FIG. 48). A strong spring 1311 (FIG. 20), connected to the upper end of the lever 1309 and extending forward therefrom, resiliently urges this lever to rock in a clockwise direction, as viewed in FIG. 20. A zero foil control rod, or bail, as indicated at 1312, is connected at one end to the lever 1309 above the pivotal mounting 487 and extends across the printing mechanism transverse the machine to control the zero foil latches in a manner well-known to the art. The link 1313 is pivotally connected at one end to the upper end of the arm 1305 by a pivot stud 1314 and is pivotally connected at its other end to the lever 1309 below the shaft 487 by a pivot stud 1315. The lever 1309 has the depending tail portion 1323, which carries at its bottom end the cam following roller 1324 engaging the tens-transfer control cam 221. As explained in connection with FIGS. 16 and

31, since shaft 537 connected to arm 543 and roller 544 (FIG. 31) and lever 1309 (FIG. 20) carrying roller 1324 are connected by link 1313, their operation is controlled by both cams 226 (FIG. 31) and 221 (FIG. 20). With this arrangement, when the shaft 537 is rocked to detent the actuator sectors at the end of the down stroke of the sector operating bail, the lever 1309 is rocked, clockwise in FIG. 20, and moves the locking pawl control rod 1312 to engage the locking pawls so that the print dials 1088 will be locked for the printing operation.

An arm 1316 (FIG. 20) is rockably mounted on the pivotal support 487 and has at its upper end a downwardly facing hook formation 1317 which is engageable with an abutment formation 1318 on a forward extending tail portion 1319 of the print control bail leg 1095 (see also FIG. 48). The arm 1316 is provided at the forward side of the pivotal mounting 487 with a spring hook formation 1320, and a spring 1321, connected between this hook formation and the upper end of the lever 1309, resiliently rocks the arm 1316 in a counter-clockwise direction, as viewed in FIG. 20, to move the hook formation 1317 over the abutment formation 1318. This rocking movement of the arm 1316 relative to the lever 1309 is terminated by a stop formation 1322 on the forward side of the arm 1316 which engages the forward edge of the lever 1309. The arrangement is such that when the detent pawls 536 (FIG. 16) are out of engagement with the actuator sectors, the hook 1317 (FIGS. 20 and 48) is disposed above the abutment formation 1318 and will preclude accidental operation of the printing mechanism. However, when the shaft 537 is rocked to detent the actuator sectors at the end of the downward stroke of the sector operating bail, the lever 1309 is rocked in a counter-clockwise direction, as viewed in FIG. 20, and moves the hook arm 1316 in a clockwise direction to remove the hook 1317 from above the abutment formation 1318 to thereby free the print control bail 1094 to descend for the printing operation when the print control cam follower rides into the low portion of the print cam, as described above.

16. KEYBOARD CLEARING OPERATION

The keyboard or selection mechanism clearing key 308 (FIGS. 7, 48 and 65) has an elongate, flat stem 1335 mounted for vertical movement on the left-hand frame plate 109 by suitable means, such as vertically spaced studs 1336 and 1337 extending through corresponding, longitudinal slots in the key stem. Intermediate its length, this stem carries the pin 182 (FIG. 4) which engages the cam edge 179 of the actuating slide 175 to move the actuating slides 175 and 151 forward to cycle the machine when the key is depressed and which pin also engages the extension 200 of the interlocking bar 196 to interlock the remaining control keys when the CLEAR KEYBOARD key is depressed. Depression of the CLEAR KEYBOARD key 308 will thus cause the machine to cycle and cause the actuator sector operating bail to move, first down, during the first half of the operating cycle, and then up, during the latter half of the same cycle.

A three-armed print blocking lever 1338 (FIG. 48) is rockably mounted at the juncture of its arms on the left-hand end of a fixed stub shaft 1339 supported by a suitable bracket, not illustrated, from the machine base. One arm 1340 of the lever 1338 extends forward and has the upper edge of its forward end portion disposed below a pin 1341 projecting to the right from the lower end of the key stem 1335 so that the lever 1338 will be rocked in a clockwise direction, as viewed in FIG. 48, when the key 308 is depressed.

A spring 1342, connected between the lever arm 1340 and one arm 1343 of a bail 1762 rockably mounted on the shaft 164, resists the rocking of the lever 1338 by depression of the key 308 and resiliently urges the lever 1338 to rock in a counter-clockwise direction, as viewed in FIG. 48. The lever 1338 has the second arm 1345 extending up and rearward from the shaft 1339. This

lever arm is provided at its upper end with an offset shoulder 1346 which is moved under the cam following roller 1099 on the print control arm 1098 when the lever 1338 is rocked in a clockwise direction, as viewed in FIG. 48, by depression of the CLEAR KEYBOARD key 308. When the shoulder 1346 is disposed under the cam following roller 1099 as the low portion 1102 of the print cam 220 comes into register with the roller 1099, the shoulder 1346 will prevent the roller from dropping into the cam low portion and thus the printing operation of the machine will be suppressed. It may be noted that the lever arm 1345 carries, near the shoulder 1346, an adjustable stop 1347 and that the print control arm 1098 has a rearward projecting tail portion 1348 which engages the stop 1347 when the lever 1338 is in its normal position and the roller 1099 rides into the cam low portion 102 during a printing operation. This provides an adjustable cushioned stop for the print wheel actuating movement of the arm 1098. While the shoulder 1348 and the stop 1347 are illustrated, these elements could be omitted, if desired, without loss of the print suppressing function of the lever arm 1345.

The lever arm 1345 has a tail portion 1349 extending up and rearward beyond the shoulder 1346 and carrying at its distal end a laterally projecting pin 1350. The pin 1350 is engaged in a terminal notch 1351 provided in the lower end of the lever 1352 which is rigidly mounted at its upper end on the left-hand end of shaft 1286. The shaft 1286 extends transverse the rear, intermediate, upper portion of the machine and carries on its right-hand end the depending arm 1285, the bottom end of which engages the pin 1288 when the shaft 1286 is rocked (FIG. 2) and prevents the lever 1270 from rocking. This will prevent tabulating movement of the paper carriage of the machine during the keyboard clearing cycle.

Referring to FIG. 48, the key stem 1335 is provided intermediate its length with a rearward extending arm, or projection, 1360, carrying near its rear end a laterally projecting pin 1361. The pin 1361 rests on the upper edge of the front arm 1362 of the left part of a double lever 1363 rockably mounted on the shaft 164. The left part of lever 1363 consists of the forward and rear arms 1362 and 1366, and has slots 2026 and 2027 embracing respectively the supporting shaft 164 and a guide pin 1358. The front end of arm 1362 has a portion offset to the left to underlie pin 1361 on stem 1335 of the CLEAR KEYBOARD key 308. Another part of forward arm 1362 underlies a pin 1353 (FIG. 55) on a stem 1528 of the multiplier entry (X) key 306 and aligned with pin 1361. The right part of the double lever 1363, consisting of a rear arm 1367 and a forward arm lying parallel to arm 1362, rocks on shaft 164 and carries the pin 1358 which lies in slot 2027. A spring 1364 urges the complete double lever 1363 (counter-clockwise in FIG. 48) against the pins 1361 and 1353, which in the normal, raised positions of keys 306 and 308, determine the normal position of double lever 1363. Another spring, not shown, urges the left part 1362, 1367 rearward so that shaft 164 and pin 1358 normally lie in the front ends of slots 2026 and 2027, as shown in FIG. 48. Thus the two parts of the double lever 1363 rock as a unit about the supporting shaft 164, and the right part in addition can slide forward on shaft 164 and pin 1358.

The right-hand lever arm 1367 is provided at its rear end with a forward and upward facing hook formation 1370 which, when the lever 1363 is rocked by depression of the CLEAR KEYBOARD key 308, engages behind the extended left end of the gear axle 480 of the front add pendent gear train 475 (see FIG. 21). This positioning of the hook formation 1370, while leaving the lower end of the add pendent gear train 475 free to move forward into mesh with the input selection sectors 333 and turn these sectors back to their "0" position during

the first portion of the keyboard clearing cycle, blocks movement of the add dependent gear train to mesh the gears 484 thereof with the accumulator drive gears 488 (FIG. 32) and thus cautiously prevents the value read out of the selection mechanism from being entered into the stationary, or grand total, accumulator.

Since neither the addition nor the subtraction control mechanism has been set by depression of the clearing key, there will be no entry into the primary or shiftable accumulator 505 during the clearing operation.

After the value has been read out of the selection mechanism and the sectors returned to, and latched in their "0" positions during the first portion of the operating cycle, the shiftable selection carriage is restored to its right-hand, home position near the end of this cycle and the entry value is canceled from the machine without being printed or added into either of the accumulators.

17. SHIFTING MECHANISM FOR THE PRIMARY REGISTER 505

As has been previously explained, the primary register is mounted in a frame, or cage, including end plates 506 and 507, which are slidably mounted on the parallel rods 508 and 509 (FIGS. 19 and 22) for movement transverse the machine. The end plates 506 and 507 are held in spaced and parallel relationship by cross plates 645 and 560, the plate 560 being located at the rear of the accumulator, and the plate 645 being located at the lower front portion. The rack bar 644 extends along, and is secured to, the front cross plate 645, as shown in FIGS. 22 and 58. This bar extends to the left (down in FIG. 58) of the left-hand end plate 506 and is provided in the upper edge of its portion to the left of the end plate 506 with ratchet teeth 1444, as shown in rear elevation in FIG. 59. A similar rack bar 643 extends along, and is fixed to, the rear cross plate 560. This bar also extends to the left of the left-hand end plate 506 and is provided in its bottom edge with a series of ratchet teeth, not illustrated but similar to teeth 1444 (FIG. 59).

As has been previously explained, the shaft 286 (FIGS. 3 and 60) is driven from the shift clutch through the shaft 253 and the miter gears 283 and 287. It will be noted that the miter gear 287 is journaled in an angle bracket 1446 (FIG. 58) supported on the frame plate 110. A pair of drive sleeves 1447 and 1448 (FIGS. 58 and 60) is slidably mounted on the shaft 286 which extends transversely across the rack bars 643 and 644. The drive sleeve 1448 is disposed adjacent to, and above, the rack bar 644 and is provided with a rear extension 1448a of reduced diameter having diametrically opposed longitudinal slots therein. A pin 1458 extends diametrically through the shaft 286 and is engaged in the slots in the extension 1448a to drivingly connect the shaft 286 to the drive sleeve 1448 while leaving the drive sleeve free to slide along the shaft. The drive sleeve is provided with an eccentric groove in which is disposed a driving element 1462 (FIG. 59) having a down projecting tooth 1463 to engage with the rack teeth of the rack bar 644. The drive sleeve 1448 is also provided with a concentric groove 1459, and a pin 1460 (FIG. 58) is engaged in this groove and carried by a rockable lever 1461 (FIG. 55) which is effective to move the sleeve along the shaft 286 to bring the driving tooth 1463 into, and out of, engagement with the teeth of the rack bar 644. The driving element 1462 has an up extending, slotted extension 1464, and a pin 1465 mounted on the frame plate 110 by an angle bracket 1466, engages in the slot in the extension 1464 to hold the driving element 1462 against rotation.

With this arrangement, when the shaft 286 is rotating and the driving element 1462 is in alignment with the teeth of the rack bar 644, the tooth 1463 of the driving element will successively engage the teeth of the rack bar 644 and step the accumulator carriage and the accumulator 505 to the right (left as seen in FIG. 59).

The drive sleeve 1447 is entirely similar to the drive

sleeve 1448, and the shaft 286 is drivingly connected to this drive sleeve by a pin 1450 extending through the shaft 286 and through diametrically opposed slots in a reduced portion 1449 of the sleeve. This sleeve has a concentric groove 1453 in which a pin 1454 carried by an arm 1798 (FIGS. 58, 55 and 43) is engaged, and an eccentric groove in which the driving element 1451 is mounted. The element 1451 has an up directed tooth 1452 and a down directed, slotted extension, 1456. A pin 1457, fixed at one end to the rear cross plate 113, is engaged in the slot of the extension 1456 and restrains the driving element 1452 against rotation. When the shaft 286 is rotated and the driving element 1452 is in alignment with the teeth of the rack bar 643 of the shiftable accumulator carriage, the shiftable accumulator is stepped to the left (down as seen in FIG. 58). Rack 643 has a second series of notches 1467 on its upper face. A detent arm 1468 journalled at 1468a carries a roller 1469 that is urged into the notches 1467 by a spring 1470. The spacings of the notches 1467 and of the teeth 1444 are the same as the spacings of the orders in the accumulator. The drive ratio between shaft 253 (FIGS. 3 and 58) and shaft 286 is one-to-one so that driving elements 1462 and 1451 operate in synchronism with shift clutch 254, 256, and have a definite home position. Preferably that home position is the position in which the driving element is retracted its maximum from the rack, the mid-cycle position then being substantially that shown in FIG. 59. A detent 1430 cooperates with a notch 1431 in the periphery of a disk 1432 on the rear end of shaft 286 for helping to center the shaft 286 in its home position.

With the above arrangement, the shiftable accumulator can be stepped to the left or to the right by controllably positioning the drive sleeves 1447 and 1448 and engaging the shift clutch. Suitable means, to be later described, are provided to preclude the possibility of both driving elements being brought into alignment with their corresponding rack bars at the same time. The extent of movement of the shiftable accumulator is controlled by moving the drive sleeves and also by the control of the shift clutch, as will later appear.

18. MULTIPLIER STORAGE

A multiplier storage unit, or counter, generally indicated at 510 in FIG. 19, is mounted on the shiftable accumulator carriage 505 and also serves as a cycle counter or quotient register when the machine is used for division.

The unit 510 has a frame, including a pair of inverted L-shaped frame plates, as indicated at 1471 and 1472 in FIGS. 20 and 64. The right-hand plate 1471 is disposed against the outer side of the right-hand frame plate 507 of the carriage of the shiftable accumulator unit 505 and is rockably mounted at its lower end on the lower portion of the plate 507 by a pivotal mounting 1473 (FIGS. 19 and 64). The plate 1472 is disposed at the outer side of the left-hand frame plate 506 of the shiftable accumulator unit 505 and is rockably mounted at its lower end on the lower portion of the plate 506 by a pivotal mounting 1474 (FIG. 20). The two plates 1471 and 1472 are held in parallel registering relationship to each other by the pivotal mountings 1473 and 1474 and by a plurality of shafts and tie rods extending between the upper portions of the two plates, as will presently appear.

The two plates 1471 and 1472 are so positioned that the toe portions of the inverted L-shaped configurations extend toward the actuator sectors 450. A series of three parallel gear shafts 1475, 1476 and 1477 extend between, and are mounted at their ends, in the upper portions of the frame plates 1471 and 1472. The shaft 1475 is disposed inward of the extremities of the toe portions of the frame plates and carries a series of register, or counter, gears 1478. The intermediate shaft 1476 carries a series of idler gears 1479 (FIG. 19) meshing coordinally with the gears 1478. The shaft 1477 is disposed adjacent the

extremities of the toe portions of the frame and carries a series of drive gears 1480 which mesh coordinally with the idler gears 1479 and with the gear teeth of the co-ordinatal actuator sectors 450 when the storage unit 510 is rocked forward, as will be presently described.

A pair of cam levers 1481 and 1482 (FIGS. 20, 64 and 66) are rockably mounted intermediate their length on a common rock-shaft 1483 extending through the upper portions of the side plates 506 and 507 of the shiftable accumulator carriage. The shaft 1483 is disposed rearward of the frame plates 1471 and 1472 and the right-hand cam lever 1481 has in its forward end an inclined cam slot 1484 which receives a pin 1485 projecting laterally from the intermediate portion of the right-hand frame member 1471 of the storage unit 510. The left-hand cam lever 1482 has a similar inclined slot 1486 which receives a pin 1487 projecting laterally from the left-hand frame plate 1472 of the storage unit (FIG. 20). The cam slots 1484 and 1486 are so shaped that when the front ends of the levers 1481 and 1482 are raised, the upper end of the unit 510 is moved forward to mesh the drive gears 1480 (FIG. 19) with the teeth of the co-ordinatal actuator sectors 450, and the storage unit is locked in this position until the cam levers are rocked to move their front ends down. The levers are resiliently urged to rock in a direction to move their front ends down and retract the storage unit from the actuator sectors by springs 1488 and are arranged to be rocked in the opposite direction by mechanism including a lever 1489 (FIG. 64).

The levers 1481 and 1482 extend rearward of the rock-shaft 1483, and a bail rod 1490 extends between the rear portions of the two levers. A bellcrank consists of two lever arms 1489 and 1492 fixed to opposite ends of a bushing that rotates freely on a shaft 1491. The lever arm 1489 bears at its free end on the bail rod 1490, and the rearward directed arm 1492 is pivotally connected at its rear end to the upper end of a link 1493. The lateral position of lever arm 1489 is such that it can engage bail 1490 for actuating levers 1481 and 1482 at all lateral positions of the movable assembly 505, 510.

The link 1493 is part of a servo mechanism used to rock the multiplier storage unit 510 to bring its drive gears 1480 (FIG. 19) into, and out of, mesh with the teeth of the actuator sectors 450. The link 1493 is pivotally connected at its lower end to the rear end of an arm 1494 of a bail 1495 rockably mounted on a fixed shaft 1496. A second arm 1497 of the bail depends from the shaft 1496 and is pivotally connected at its lower end to the rear end of a link 1498 which extends forward to a location immediately below the main drive shaft 135 of the machine. At its front end, the link 1498 is pivotally connected at 1500 to a lever 1501 rockably mounted intermediate its length on a fixed stub shaft 1502. The link 1498 is connected to the lever 1501 below the stub shaft 1502, and the portion of the lever below the connection 1500 provides an abutment which engages a fixed stop 1503 to limit rocking movement of the lever 1501 in a clockwise direction, as viewed in FIG. 64.

Referring particularly to FIG. 66, a cam lever 1504 is rockably mounted at its upper end on the fixed stub shaft 851 and has at its lower end a cross portion carrying at the forward end thereof a laterally projecting pin 1505, and at the rear end thereof a cam following roller 1506. The roller 1506 rides on the peripheral edge of the add-subtract cam 227 at a location below, and forward of, the main cam shaft 135. The roller 1506 is maintained in contact with the add cam by a spring 1507 connected between the lower end of the lever 1504 and the arm 742 of the add-subtract cam lever 740 so that the lever 1504 rocks or oscillates each time the add cam is turned by an operating cycle of the machine. A hook arm 1508 is pivotally connected at its rear end to the upper end of the lever 1501 and carries at its forward end an up directed hook formation 1509 which engages in front of the pin 1505 when the forward end of the hook arm is raised.

When the hook 1509 is in engagement with the pin 1505 and the machine is cycled, the lower end of lever 1504 is moved forward, rocking lever 1501 in a counter-clockwise direction, as viewed in FIG. 66, forcing the link 1498 rearward. Rearward movement of the link 1498 rocks the bail 1495 in a counter-clockwise direction, raising the link 1493. Raising of the link 1493 rocks the arms 1492 and 1489 in a counter-clockwise direction and this rocks the lever 1481 in a clockwise direction, as viewed in FIG. 66, forcing the upper end of the unit 510 forward to engage the drive gears 1480 with the teeth of the co-ordinatal actuator sector 450. This constitutes the power-operated or servo mechanism for moving the storage unit 510 into, and out of, entry value receiving position.

The hook 1509 is controlled by the multiplier entry key 306 and the BACK TRANSFER key 317 of the machine (FIG. 7). The BACK TRANSFER key 317 (FIG. 66) controls the position of the hook arm 1508 through a linkage, including a bail 1510, rockably mounted on the shaft 1408 extending transverse the forward right-hand portion of the machine immediately above the machine base 100. This bail has an arm 1512 extending rearward from the shaft 1408 and connected to the forward end of the hook arm 1508 by a short pivoted link 1513. The bail 1510 has a second arm 1514 extending down and forward from the shaft 1408 and pivotally connected at its lower end to the rear end of a link 1515, the forward end of which is pivotally connected to the forward end of an arm 1516 of a bail 1517. The bail 1517 is rockably mounted on a bail shaft 1518 extending transverse the machine at the forward side of the value entering keyboard. The arm 1516 has a forward portion of its upper edge formed as a cam edge 1519 which underlies pin 1521 on the stem 1520 of the BACK TRANSFER key 317.

When the BACK TRANSFER key is depressed, the hook 1509 is raised to engage the pin 1505 to thereby move the storage mechanism forward to engage the storage mechanism drive gears 1480 with the co-ordinatal actuator sectors 450.

The shape of the add-subtract cam 227 and the position of the cam following roller 1506 around this cam is such that the storage mechanism is not moved forward until the beginning of the second half of an operating cycle. Also, the yoke 847 (FIG. 67) for the BACK TRANSFER key, on the shaft 155, lacks a lower arm such as 825 (FIG. 16), and is thus incapable of establishing an operating cycle by itself, but must be used in combination with some other control key. The BACK TRANSFER key may be used with the addition key and, in such case, will cause the value read out of the input value selection mechanism to be entered into the storage mechanism 510. It will be noted, however, that the storage mechanism can enter values in one direction only and does not distinguish between addition and subtraction operations. When the BACK TRANSFER key is used in combination with the TOTAL or SUB TOTAL key, it will enter the value from the primary accumulator into the storage mechanism, and when used with the GRAND TOTAL or SUB GRAND TOTAL key, will enter the value from the grand total accumulator into the storage mechanism.

The value in the storage mechanism can be read out and printed by a division total operation, presently to be described. If the DIV. TOTAL key 314 and the BACK TRANSFER key 317 are pressed simultaneously, the value will be read out of the counter or storage unit 510, printed, and returned. Thus, a total value can be transferred from the primary accumulator to the grand total accumulator by first simultaneously depressing the TOTAL or SUB TOTAL key and the BACK TRANSFER key and then depressing the DIV. TOTAL key with the grand total entry lever 305 set in operative position.

The bail 1517 (FIG. 66) has, at its left-hand end, an arm 1522 depending from the supporting shaft 1518 and provided at its lower end with an inclined cam edge 1523

bearing on the pin 1524. Referring to FIG. 55, the pin 1524 is carried at the front end of the lever arm 1525 disposed at the outer side of the left-hand frame plate 105 and supported on the stud 1526 carried by this frame plate. The pin 1524 extends through the aperture 1527 in the plate 105 where it engages the terminal cam edge of the bail arm 1522 (FIG. 66). The stem 1528 of the multiplier entry (X) key 306 carries at its lower end the roller stud 1529 which bears on an up facing cam edge provided on the rear end portion of lever 1525, as shown in FIG. 55.

When the multiplier entry key (X) 306 is depressed, the lever 1525 is rocked counter-clockwise, as viewed in FIG. 55, raising the pin 1524. This rocks the bail 1517 counter-clockwise, as viewed in FIG. 66, and raises the front end of hook arm 1508 to engage the hook 1509 with the pin 1505 on lever 1504. This will move the storage mechanism 510 forward, at the beginning of the second half of the operating cycle, to engage the storage mechanism drive gears 1480 with the coordinal actuator sectors 450, as explained above.

The multiplier entry key stem 1528 (FIG. 55) carries the pin 173 which engages the cam edge 171 of the actuating slide 163 (FIG. 4) to move the actuating slides forward and establish an operating cycle of the machine when the multiplier entry key (X) 306 is depressed.

Since, unless link 748 (FIG. 31) is lowered by total link 925, the addition pendent gear train 475 (FIG. 16) automatically reads out the value in the input selection mechanism during the first half of an operating cycle, as previously explained, upon depression of the multiplier entry (X) key, the multiplier value in the selection mechanism will be read out into the actuator sectors during the first half of the operating cycle established by depression of the multiplier entry (X) key, and from the actuator sectors into the multiplier storage mechanism during the latter half of this cycle. The multiplier entry key does not condition any of the pendent gear trains to enter the multiplier input value into either of the accumulators. The multiplier value is automatically cleared from the input value selection mechanism at the end of the multiplier entry operation.

The arm 1545 extends rearward from the left-hand end of bail 1416 (FIG. 64) and overlies, at its rear end, the pin 1524, previously described. Depression of the multiplier entry (X) key thus rocks the bail 1416 counter-clockwise, as viewed in FIG. 66, and moves the link 1417 (FIG. 66) forward to set the symbol printing mechanism to print the multiplier entry symbol.

19. DIVISION TOTAL OPERATION

A second cam lever 1530 (FIG. 64) is rockably mounted at its upper end on the stub shaft 851 to the left of the cam lever 1504 (FIG. 66) and carries a cam following roller 1531 engaging the edge of the total cam 226. The lever 1530 extends down through an opening in the base 100 of the machine, and a spring 1532 connected between the lower end of this lever and a fixed stud, maintains the roller 1531 in engagement with the edge of the cam 226 so that the lever 1530 will rock or oscillate during each rotation of the cam shaft 135. A second hook 1533 is pivotally mounted on the upper end of the lever 1501 and has at its forward end a hook formation which is engageable with a pin 1534 projecting from the intermediate portion of the lever 1530. The hook 1533 is disposed below the pin 1534 and is resiliently urged to rock in a direction to engage the pin by a spring 1535 connected between a depending tail portion of the hook and the lever 1501.

A bail 1536 (FIG. 64) is rockably mounted on a transverse shaft 1537 and this bail has an extended, rearward directed arm 1538 carrying, at its rear end, a pin 1539 which overlies the upper edge of the hook 1533. The bail 1536 also has an extended, forward directed arm

1540 provided, at its forward end, with a longitudinal notch 1541 which receives a pin 1542, carried by the stem 1543 of the DIV. TOTAL key 314.

A spring 1544 normally raises the key 314 and rocks the bail 1536 in a clockwise direction, as viewed in FIG. 64, to lower the pin 1539 against the hook 1533 and maintain the hook out of engagement with the pin 1534. However, when the DIV. TOTAL key is depressed, the bail 1536 is rocked in a counter-clockwise direction, as viewed in FIG. 64, thereby freeing the hook 1533 to rise under the urgency of the spring 1535 and engage the pin 1534. When the hook 1533 is engaged with the pin 1534 and the lever 1530 is rocked by the total cam 226, the lever 1501 will be rocked to move the storage mechanism 510 forward to engage its drive gears 1480 with the coordinal actuator sectors 450. Since this operation is controlled by the total cam, the value will be read out of the storage unit 510 during the first portion of the cycle; printed at the end of the first half of the cycle; and, during the second half of the cycle, the storage unit will be disengaged from the actuator sectors 450 and left in a zeroized, or cleared, condition. The bail 922 which actuates the total link 925 (FIGS. 31 and 37) has a forward extending arm 922a (FIG. 64) which underlies a pin 1543a on key stem 1543 of the DIV. TOTAL key. It is the link 925, acting through bail 985 (FIGS. 33 and 34), that sets up the grand total entry. Consequently, and as has been previously stated, as the actuator sectors are being restored during the second half of the cycle, the value can be entered into the grand total accumulator if desired.

A pin 1546 (FIG. 27) on the division total key stem 1543 acts, through a yoke on the shaft 155 (FIG. 4), to rock this shaft and establish an operating cycle of the machine in the manner previously described.

20. MULTIPLIER STORAGE UNIT

Referring now to FIG. 19, a series of ordinally arranged 40 detent levers 1550 is rockably mounted on a shaft 1551, which extends between the upper forward portions of the storage unit supporting plates 1471 and 1472. Each lever 1550 extends down and rearward from the shaft 1551 and carries, at its rear end, a detenting roller 1552 which engages between the teeth of the coordinal idler gear 1479. 45 A spring 1553 is connected between a forward projecting ear on each detent lever 1550 and a spring supporting tie rod 1554 extending between the forward upper corners of the plates 1471 and 1472 to resiliently urge the rollers 1552 into detenting engagement with the coordinal gears 1479.

The storage, or counter, unit 510 is provided with a tens-transfer mechanism which is spring-actuated in timed relationship to the operating cycles of the machine, as shown in FIG. 19. Each of the drive gears 1480 of the storage mechanism is provided at the left side thereof with a single lobe cam, or lug, 1555 at the "9½" position of this gear and of the coordinal counter gear 1478, that is, between the "9" and "0" positions. In FIG. 19, these gears 1480 and 1478 are shown in their "0" position. A series of two-armed, or V-shaped, latch levers 1556 is rockably mounted upon, and extend forward from, a transverse rod, or shaft, 1557. The lower arm of each of the levers 1556 has, at its forward end, a double beveled detent formation 1558 which is engaged by the lug 1555 on the coordinal gear 1480 when this gear passes through its "9½" position in either direction of rotation to rock the front end of the lever 1556 down.

An upper arm 1558a of each latch 1556 bears against a depending tail portion 1559 of a coordinal tens-transfer lever 1560 rockably mounted on the idler gear shaft 1476. Each tens-transfer lever 1560 has a portion extending up from the shaft 1476 as an upper extension, or tail, portion 1561 which extends rearward and then up from the upper end of the main portion of the transfer lever. A

spring 1562 is connected between the upper end of each tens-transfer lever and the spring supporting tie rod 1554 to rock the corresponding transfer lever in a counter-clockwise direction, as viewed in FIG. 19, when the lever is released. A bail 1563 is rockably mounted on the ends of a transverse shaft 1564 and has a depending comb edge 1563a engageable with the upper ends of the upper tail portions 1561 of the tens-transfer levers to hold these levers in inoperative position when the bail is lowered. This bail, however, is normally raised to free the transfer levers and is lowered to render the levers inoperative only during the division operation of the machine, as will be later described.

A tens-transfer control bail 1566 is positioned immediately above the rearward extending tail portions 1561 of the tens-transfer levers and is normally positioned a distance forward of the up extending, terminal parts of the tail portions 1561 so that, when a tens-transfer lever is released by its corresponding latch lever 1556, the transfer lever can move a distance sufficient to prevent its being relatched, but not sufficient to complete a tens-transfer. A feed pawl 1567 is pivotally connected at one end to the upper end of the main portion of each tens-transfer lever 1560 and extends forward from the tens-transfer lever. The feed pawl is arranged to engage the teeth of the drive gear 1480 of the order next above (to the left of) the drive gear carrying the tens-transfer lug 1555 which operates the latch lever 1556 to release the tens-transfer lever on which the feed pawl is mounted. With this arrangement, when a tens-transfer lever 1560 is released from its associated latch lever 1556, the gear train of the next higher order will be advanced one unit space.

Referring to FIGS. 19 and 22, the bail 1566 has geniculate bail legs, as indicated at 1568, one at each end thereof, and these legs are mounted at their angles on the gear shaft 1476 adjacent the supporting plates 1471 and 1472 of the storage unit. One arm of each bail leg 1568 extends up to the adjacent end of the cross-member, or bail, 1566, and the other arm 1549 extends rearward from the shaft 1476. Springs, as indicated at 1569, are connected between the upper portions of the up extending arms of the bail legs 1568 and up extending arms of levers 1547, mounted one on each end of the gear shaft 1477, to resiliently urge the bail 1566 in a forward direction to release the tens-transfer levers. The arms, as indicated at 633a in FIG. 20, are mounted on the upper tens-transfer restore bail of the primary accumulator 505, one at each end of this accumulator, and extend forward from the bail shaft 590 and bail rod 612. The pivoted links, as indicated as 1548, connect the free, forward end of each arm 633a to the free end of the rearward extending arm 1549 of the bail leg 1568 at the corresponding side of the accumulator.

With this arrangement, the bail 1566 is held in position to block the tens-transfer levers during the first portion of the cycle while the value is being entered into the storage mechanism. During the second half of the cycle, the bail 1566 is moved by the tens-transfer cam 221 (FIG. 20) to free the tens-transfer levers to complete the tens-transfers, and at the beginning of the subsequent cycle, this bail is moved rearward to relatch the tens-transfer levers in the same manner as has been previously described for the tens-transfer restore mechanism of the primary and secondary accumulators of the machine.

The storage unit tens-transfer mechanism is operative only when a multiplier is being read out of the storage mechanism during a multiplying operation of the machine, as will later appear.

A zero blocking bail 1547 (FIG. 22) has bail legs 1547a extending rearward from shaft 1477 on which they are journaled, a cross member 1547b (FIG. 19), and tail portions 1547c resting on pins 1547d carried by the side plates 506 and 507 of the shiftable accumulator 505. Springs 1569 (FIG. 22) urge the rear end of the bail down and hold tails 1547c in contact with pins 1547d.

When the storage unit 510 is rocked forward by the movement of lever 1481 (FIG. 64) in a DIV. TOTAL operation, bail 1547 moves forward and draws tails 1547c cam-like across pins 1547d for lifting the rear end of the bail. This action raises the cross member 1547b (FIG. 19) to oppose depending shoulders 1556a of the tens-transfer levers 1556 and prevents those levers from being rocked by the cams 1555. Accordingly as the actuator gears 450 drive the drive gears 1480 in the negative direction (counterclockwise in FIG. 19) during the DIV. TOTAL operation, the tens-transfer levers 1556 stop the cams 1555 and gears 1480 in their zero positions. Although the cross member 1547b of bail 1547 will similarly block the tens-transfer levers during the entry of a value into storage unit, as for example, during a multiplier entry (X) operation, and so prevent gears 1480 from turning beyond their "9" positions (positive direction of rotation, clockwise in FIG. 19), the permitted rotation of nine units is sufficient for the single entry.

Each of the counter wheels 1478 of the storage mechanism is provided with a pair of "short cut multiplication" cams 1570 and 1571 (FIG. 19) located respectively at the right and left sides of the corresponding gear 1478 and journaled on the shaft 1475 to turn with the gear. A pair of lever mounting shafts 1572 and 1573 extends transverse the storage mechanism to the rear of the shaft 1475, the shaft 1572 being disposed above the shaft 1475 and the shaft 1573 being disposed below the shaft 1475.

A series of ordinarily arranged, geniculate levers 1574 is rockably mounted intermediate their length on the shaft 1572. Each of these levers has a down turned front end portion 1575 arranged to ride at its terminal edge on the corresponding cam 1570. A second series of ordinarily arranged, geniculate levers 1576 is rockably mounted, intermediate their length, on the shaft 1573. Each of these levers has an upturned front end portion 1577 bearing at its terminal edge on the corresponding cam 1571.

The cams 1570 and 1571 are of partly circular shape and the cam 1570 has an angular extent and is so angularly positioned relative to the counter gear 1478 and the "9½" cam 1555 on the gear 1480, that whenever a value from "1" to "5" is in a counter gear 1478, the corresponding cam 1570 underlies the terminal front edge of the coordinal lever 1574 and holds the front end of this lever in a raised position. The cam 1571 is also of partly circular shape and is of such an angular extent and so positioned relative to the corresponding counter wheel 1478 and the "9½" cam 1555 on the coordinal drive wheel 1480, that whenever a value from "6" to "9," inclusive, is in the counter wheel 1478, the partly circular shaped lobe portion of this cam rides over the terminal edge of the front end of the lever 1576 and rocks the front end of the lever down. The values from "1" to "5" raise the front end of the lever 1574, but do not move the front end of the lever 1576. Values from "6" to "9," inclusive, move the front end of the lever 1576 down, but do not move the lever 1574. A "0" value in the gear 1478 permits both of the coordinal levers 1574 and 1576 to move together at their front ends so that the terminal edges of the front ends of the levers rest on the hub portions of the corresponding cams, as shown in FIG. 19.

The lever 1574 has a tail portion 1578 extending rearward from the shaft 1572 and resting on a shoulder 1579 on an irregularly-shaped lever 1580 rockably mounted on the shaft 1564. There is a series of ordinarily arranged levers 1580, one cooperating with each coordinal lever 1574, and each lever 1580 is resiliently urged to rock in a clockwise direction, as viewed in FIG. 19, by a spring 1581. Each lever 1580 extends down and rearward from the shaft 1564 and has, at its end remote from the shoulder 1579, a rounded abutment formation 1582, the purpose of which will be later described.

Each of the lower levers 1576, as shown in FIG. 19,

has a rearward extending tail portion 1583 bearing at its rear end on a transverse shoulder 1584 of an irregularly-shaped lever 1585 rockably mounted on a shaft 1586 disposed below, and parallel to, the shaft 1564. Each lever 1585 is urged by a spring 1587 to rock in a counter-clockwise direction, as viewed in FIG. 19, and each of these levers is provided at its end, opposite the shoulder 1584, with a rounded abutment formation 1588.

A pair of levers 1590 and 1591 (FIGS. 14 and 19) extend transverse the machine just to the rear of the abutment formations 1582 and 1588. These levers are disposed, one above the other, in horizontal parallel relationship, and both levers are rockably mounted on a common vertical pin 1592 supported at its ends by a bracket 1593 carried by a transverse cross-member 1594 which is supported at one end on the left-hand vertical frame plate 110 and at its right-hand end by the plate 111 carried by the rear frame plate 113. The upper lever 1590 carries a depending roller 1596 carried by a forward extending projection of the lever 1590. The lower lever 1591 carries a similar, but up projecting, roller 1597 carried by a forward extending projection of the lower lever 1591. Both of the levers 1590 and 1591 are urged to rock in a counterclockwise direction, as viewed in FIG. 14, by springs 1599 (only one of which shows) connected between the right-hand ends of these levers and fixed spring anchor pins carried by a bracket 1600 projecting forward from the back plate 113 of the machine. Rollers 1596 and 1597 sense the value in the multiplier unit in connection with the multiplication operation. They sense the digit in one order at a time, and consequently their position defines a readout station. These sensing rollers are aligned with the leftmost position of the rightmost, or lowest, order of the multiplier storage unit. Accordingly, the readout station is the ordinal position of the lowest order of the actuator.

Referring to FIG. 51, the left-hand end portions of the levers 1590 and 1591 are disposed in opposition to a rear vertical edge 1601 of a yoke-shaped sensing slide 1602 slidably mounted for longitudinal movement on a fixed stud 1603 extending from the left-hand frame plate 110 through a longitudinal slot in the yoke-shaped slide. At its upper edge, the slide 1602 has a rearward directed extension 1604 which overlies the upper lever 1590. At its forward end, the slide 1602 carries a pin 1605 extending to the left from the slide and connected to the upper end of a lever 1606 (FIG. 55) which controls the readout operation of the multiplier storage unit in a manner to be later described.

Referring back to FIG. 19, it will be noted that when the upper lever 1574 at the readout station is on the lobe of the coordinate multiply cam 1570, the lever 1574 will be rocked in a clockwise direction and the lever 1580 in a counter-clockwise direction from the position shown in FIG. 19. This rocking of the lever 1580 will force the abutment 1582 against the roller 1596 and move the right-hand end of the lever 1590 rearward (FIG. 14). In the same manner, when the front end of the lower sensing lever 1577 (FIG. 19) at the readout station is on the lobe of the multiply cam 1571, the lever 1576 will be rocked in a counter-clockwise direction and the lever 1585 in a clockwise direction from the position shown in FIG. 19. This will force the abutment 1588 against the roller 1597 and move the right-hand end of the lever 1591 (FIG. 14) rearward. The levers 1574 and 1577 in each order are alternatively rocked by the cams 1570 and 1571 and will not be both rocked at the same time.

A somewhat T-shaped lever 1610 (FIGS. 14, 15 and 49) is disposed in upright position just to the left of the plate 111 and is rockably mounted at the midlength location of its cross portion by a fixed stud 1611. The upper end of the cross-member of the T-shaped lever 1610 is provided with a forward facing abutment edge 1610a opposed to the rearward facing edge of the upper lever 1590. The lower end portion of the cross-member

is provided with a forward facing abutment formation 1610b opposed to the rearward facing edge of the lower lever 1591. With this arrangement, when the right-hand end (FIG. 14) of the upper lever 1590 is moved rearward, the T-shaped lever 1610 will be rocked in a clockwise direction, as viewed in FIGS. 15 and 49, and when the lower lever 1591 is moved rearward, the T-shaped lever 1610 will be rocked in a counter-clockwise direction. The stem portion of the lever 1610 extends rearward from the mounting stud 1611 and is provided with a triangular shaped aperture 1612, having its apex directed rearward.

A readout control cam lever 1613 (FIGS. 14, 15, 70 and 49) is disposed longitudinal of the machine beside the lever 1610 and is rockably mounted, intermediate its length, by a fixed stud 1614 carried by the plate 111. It rocks between fixed studs 1613a and 1613b. At its rear end, the lever 1613 is provided with a longitudinal slot 1615, and a pin 1616, carried at the front end of a link 1617, extends through the slot 1615 and into the aperture 1612. This pin is normally located in the apex of the triangular aperture 1612 and, when so positioned, will be moved up-and-down with the lever 1610 when the lever is rocked, as described above, for rocking the lever 1613. At its rear end, the link 1617 is pivotally connected to the upper part of an up directed arm 1618 at the right-hand end of a bail 1619 rockably mounted on the transverse shaft 1491. At its left-hand end, the bail 1619 carries a second arm 1607 which is effective to rock the bail 1619 in a counter-clockwise direction, as viewed in FIGS. 15 and 49, and move the pin 1616 forward (to the left in FIG. 15) into the wide, forward portion of the aperture 1612 during automatic division, as will be later described. At its forward end, the cam lever 1613 is bent over to provide a return portion 1621 which tapers rearward to a point, providing upper and lower cam edges for a purpose to be presently described.

A slide 1622 (see particularly FIGS. 14 and 19) is mounted on the right side of the bracket 111 for rectilinear movement longitudinal of the machine and this slide is supported by spaced-apart studs 1623 and 1624 (FIG. 19) projecting through corresponding, longitudinal slots in the slide. At its rear end, the slide carries a laterally projecting pin 1625, which pin is received in a terminal notch in the upper end of a lever 1626 fixed to, and extending up from, the rockshaft 1491 (FIGS. 19 and 49).

A feed pawl 1628 is rockably mounted intermediate its length on the slide 1622 by a pivotal mounting 1629. This feed pawl is provided at its front end with a double detent formation 1630 which is engageable with the teeth of the particular gear 1478 that is at the readout station of the shiftable multiplier storage mechanism 510, to turn that gear 1478 one unit space in one direction or the other for each reciprocating movement of the feed pawl. The feed pawl 1628 is resiliently held in a centered position relative to the slide 1622 by centering mechanism, including a pin 1631 (FIG. 19) projecting laterally from the rear end of the feed pawl and disposed between a pair of centering jaws 1632 and 1633 rockably mounted on the slide 1622 at 1634 and 1635, respectively, and urged toward each other by a spring 1636. The pins, by which the spring 1636 is connected to the centering jaws, engage the corresponding edges of the slide 1622 so that neither jaw can move inward past its centering position. This provides a true centering control for the feed pawl. A pin 1637 (FIGS. 14 and 15) projects laterally from the feed pawl 1628 near the front end of the latter and is engageable with the cam edges of the returned tip portion 1621 of the cam lever 1613 (FIG. 15) to control the position of the front end of the feed pawl 1628, whether above, or below, the gear shaft 1475, as the front end of the feed pawl engages the gear 1478 at the readout station.

During those operations of the machine in which a

multiplier is read out of, or a quotient read into, the counter gears of the storage mechanism 510, the slide 1622 (FIG. 19) is reciprocated forward and backward for each operating cycle of the machine. As shown in FIG. 49, an arm 1639 is fixed to a hub 1639a, which in turn is fixed to shaft 1491. An arm 1640, rotatably supported on hub 1639a, is controlled by link 461 (FIG. 51). A spring 1641 (FIG. 51) connected between ears on the arms 1639 and 1640 pulls arm 1639, counter-clockwise in FIGS. 51 and 49, against a stop 1640a on arm 1640 and so provides a yielding connection between those arms.

The link 461 (FIG. 51) is pivotally connected at its rear end to the upper end of the arm 1640 and extends forward of the machine at the right-hand side of the side plate 110. At its forward end, the link 461 is provided with downward opening hook formation 460, previously described (FIG. 17), which is disposed above the laterally projecting pin 459 on the left-hand actuator drive segment 454. The link 461 is resiliently raised by a spring 1642 (FIG. 51) connected between an intermediate portion of the link and a bracket fastened to frame plate 102. The link 461 is moved down to engage the pin 459 in the hook formation 460 by a roller 1445 engaging an upward and rearward inclined cam edge 455 of the link. Movement of the roller 1445 is controlled by the multiplication and division keys in a manner which will be later explained in detail (FIG. 55).

When the hook 460 (FIG. 51) is lowered into engagement with the pin 459, the slide 1622 (FIG. 19) will be reciprocated forward and backward once during each operating cycle of the machine. The feed pawl 1628, moving with the slide 1622, will rotate the storage counter gear 1478 at the readin or readout station one unit space for each reciprocation of the slide 1622. Whether the feed pawl rotates the gear 1478 in a positive or negative direction, depends on the upper or lower location of the pointed tip 1621 (FIGS. 15 and 49) of the cam lever 1613. During readout, that is, during multiplication, the position of the cam portion 1621 at the forward end of the cam lever 1613 depends upon the rocked position of the T-shaped lever 1610. The position of the lever 1610 depends, as has been previously explained, on which of the levers 1574 or 1576 (FIG. 19) is moved at its front end away from the gear shaft 1475 by the corresponding short-cut multiplication cam 1570 or 1571. If, during a multiplication operation, the value in the counter gear 1478 in the readout station is a value between "1" and "5," the lever 1574 will be rocked and this will, in turn, rock the lever 1580 and move the right-hand end of the upper lever 1590 (FIG. 14) rearward. This will rock the T-shaped lever 1610 to raise the front end of the cam lever 1613 (FIG. 15). Under these conditions, when the slide 1622 (FIG. 19) and feed pawl 1628 are moved forward, the pin 1637, carried by the feed pawl, will move under the return cam formation 1621 of the cam lever 1613 and engage the teeth of the gear 1478 (FIG. 19) at the readout station below the shaft 1475 and rotate this gear in a negative direction to sequentially subtract the digit value from this gear as the multiplicand is successively added into the primary accumulator 505. If, on the other hand, the value in the gear 1478 at the readout station is a value included in the digits "6" to "9," inclusive, the lever 1576 will be rocked, rocking the lever 1585 and moving the right-hand end of the lower lever 1591 (FIGS. 14 and 49) rearward and thereby rocking the T-shaped lever 1610 to lower the front end of the cam lever 1613 (FIG. 15). Under these conditions, when the slide 1622 (FIG. 19) and feed pawl 1628 are reciprocated, the pin 1637 will pass over the upper cam edge of the returned cam portion 1621 of the cam lever and the front end of the feed pawl will engage the teeth of the gear 1478 above the gear shaft 1475 and turn the gear 1478 in a positive direction. The reciprocating movements of the slide 1622 will then read

out the tens-complement of the value in the counter gear, rather than the value actually in the counter gear. The mechanism is so arranged that, under these conditions, the multiplicand will be successively subtracted from the value in the primary accumulator. However, as the tens-complement is read out to "0" in this direction, the tens-transfer lug 1555 on the coordinal drive gear 1480 will trip the tens-transfer mechanism and a value of "1" will be transferred into the next highest order of the storage unit gear mechanism. This accomplishes the purpose in short cut multiplication of multiplying the value in the accumulator by "10" and subtracting from this value the tens-complement of the value of the multiplier of the storage mechanism. During division, that is, when a quotient is being counted into the storage mechanism, the operation is the same as that described above, except that the T-shaped lever 1610 is disabled by moving the pin 1616 forward. The division operation and the control of cam lever 1613 during that operation will be described later.

An upper bail 1645 (FIG. 19) extends over the intermediate portions of the upper sensing levers 1574, these levers having abutment formations disposed immediately below the bail, and is pivotally mounted by its terminal legs on the end portions of the shaft 1572. A lower bail 1646 extends across the intermediate portions of the lower levers 1576, which levers are provided with down projecting abutment formations immediately above the bail. This bail is rockably mounted by its terminal legs on the end portions of the shaft 1573 and the two bails are connected together for simultaneous and coextensive movement by pin-and-slot connections 1647 (FIG. 22) between inward directed tail portions of the bail legs. With this arrangement, when all of the levers 1574 and 1576 are retracted inward at their front ends, the bails 1645 and 1646 may be moved inward toward each other. However, when any one of the levers 1574 or 1576 is on the lobe of a corresponding cam 1570 or 1571, the bails 1645 and 1646 are moved outward away from each other.

As shown in FIG. 55, a bail 1648, rockably mounted on the transverse shaft 1286, has an arm 1650 extending rearward from the shaft 1286. By means of the mechanism shown in FIGS. 39 and 40, still to be described, arm 1650 is controlled by a roller 1902 that overlies the upper bail 1645 (FIGS. 19 and 22). With this arrangement, when the bails 1645 and 1646 are moved away from each other, the rear end of the arm 1650 is raised and the bail 1648 is rocked in a clockwise direction, as viewed in FIG. 55. The bail 1648 has a forward extending arm 1651 connected by a pin-and-slot connection 1652 with the rear end of a link 1653, the forward end of which is pivotally connected to a latch pawl 1654 for the multiplication (=) key 307. At its rear end, the link 1653 has a depending tail portion terminating in a laterally projecting abutment formation 1655. When the bail 1648 is rocked in a clockwise direction, as seen in FIG. 55, the rear end of the link 1653 is lowered and the abutment formation 1655 is moved to a position in which it is engaged by the pin 459 on the actuator operator bail sector 454. With this arrangement, after all of the multiplier digits have been read out of the storage mechanism during a multiplication operation, the rear end of the link 1653 is lowered to place the abutment formation 1655 in position to be engaged by the pin 459, and at the end of a cycle, the pin 459 engages the abutment formation and moves the link 1653 rearward to release the multiplication key 307, as will later be described in greater detail.

70 21. DECIMAL ORDER LOCATING AND DECIMAL PLACE DISCARDING MECHANISM

The decimal-point selection, control and printing mechanism and the decimal place discarding mechanism provide for the correct placement of the decimal point in

printed products and quotients and for the discarding of excessive decimal places from products, both for printing and for transfer to the grand total accumulator. They are more fully described in the parent application, Serial No. 123,085, previously referred to.

The decimal stop carriage 1667 (FIGS. 61 and 63) has a downward directed projection 1669 positioned at its rear end which extends down behind the shield 1627. When the print wheel carriers 1085 are released to print, the projection 1669 will limit the decimal wheel 1670 in its rotation in an order that the carriage 1667 is positioned by the engagement of the upstanding spoke 1679 with the abutment 1669. This will position the decimal point embossed spoke 1673 to be in position to be printed on the tape in a known manner. As may be seen in FIGS. 7, 61 and 63, four slotted slides are guided and held in position by fixed studs 1683 and 1684 in a fixed cross-member 1702 which extends transverse the machine immediately to the rear of the keyboard. Reading from the bottom up (FIG. 63) these four slides are 1739, 1703, 1677 and 1678. They are shown individually in FIGS. 50, 52, 53 and 53a. The three top slides are shown in different operated positions in FIGS. 7 and 61.

Slide 1703 has the flat extension 1681 guided on the forward part of the rack structure 1649 for longitudinal movement transverse the front portion of the printing mechanism. A lever 1680 is rockably mounted on the extension 1681 intermediate the length of the lever by a pivotal mounting 1644. Near its right-hand end this lever carries a hand knob 1680a for setting the mechanism to the selected decimal order. Also, at its right-hand end, the lever 1680 has a depending ear formation 1700 which engages between the teeth of the rack 1649. When the hand knob 1680a is moved rearward, this ear formation 1700 is moved rearward of the teeth and the lever 1680 and the slide 1703 can then be moved transverse the machine.

Slide 1703 includes a lower extension 1703a connected to upper extension 1681 by a strut portion 1704 (FIG. 52). At its left-hand end, the slide portion 1703a extends beyond the left-hand end of the cross-member 1702 (FIG. 61) and is provided with a rearward facing abutment formation 1682, which functions in the ENTER DIVD. operation.

The first movement transmitting slide 1677 is disposed immediately above the slide portion 1703a and is supported on the studs 1683 and 1684 for longitudinal movements, transverse the machine. The second movement transmitting slide 1678 is mounted above the slide 1677 and similarly supported for longitudinal movements, transverse the machine. The first movement transmitting slide 1677 is provided, along the left-hand portion of its front edge, with a series of rack teeth 1686 (FIG. 53A), and the second movement transmitting slide 1678 is provided, along the left-hand portion of its rear edge, with a series of rack teeth 1687 (FIG. 53) in substantial horizontal alignment with the rack teeth 1686. A reversing gear 1685 (FIG. 61) meshes with the rack teeth 1686 and 1687 and is mounted on a fixed stud 1685a projecting up from the fixed cross-member 1702 so that it accurately reverses longitudinal movements between the two slides 1677 and 1678. An ear 1705 projects up from the slide portion 1703a (FIG. 52) and abuts the right-hand end of the rack teeth 1687 on the slide 1678 (FIG. 61) so that this slide will be moved to the left coextensively with the left-hand movement of the slide 1703.

A hook 1706 is mounted at its right-hand end on the strut 1704 by a pivotal mounting 1707 and is engageable at its left-hand end to the left of a pin 1688 projecting up from the left-hand end of the slide 1678. The intermediate portion of the hook 1706 is connected to the left-hand end of the lever 1680 by a link 1708. A spring 1709 is connected between the intermediate portion of the hook 1706 and an ear at the rear, left-hand corner of the slide extension 1681 resiliently urges the hook member 1706

to rock in a clockwise direction, as viewed in FIG. 61, and thus to hold the hook member 1706 out of engagement with the pin 1688.

With this arrangement, when the hand knob 1680a of lever 1680 is moved rearward to rock and move the ear formation 1700 on the right-hand end of this lever out of engagement with the teeth of the rack 1649, the hook 1706 is rocked in a counter-clockwise direction, as viewed in FIG. 61, to engage the pin 1688. If the slide 1703 is now moved to the left, the ear 1705 will move the slide 1678 to the left and the reversing gear 1685 will move the slide 1677 to the right. If the slide 1703 is moved to the right, the hook 1706 will move the slide 1678 to the right and the reversing gear 1685 will move the slide 1677 to the left.

A marker tongue 1725 (FIGS. 7 and 61) extends rearward from the right-hand portion of the slide 1739 and overlies the dial portions 332 (see also FIG. 8) of the selection sectors to clearly indicate to the operator of the machine the ordinal location of the decimal point.

An index bail 1727 (FIGS. 61 and 63) is slidably mounted on legs 1728 and 1729 on the shaft 1286 which extends transverse the machine immediately above the machine actuating sectors 450. This bail has a cross-member provided in its forward edge with a series of spaced, substantially rectangular teeth 1730 and in its rear edge with a series of triangular teeth 1731, the purpose of which will be later described in detail. A lever 1732 extends forward and rearward of the machine between the left-hand end of the slide 1678 and the bail 1727 and this lever is rockably mounted intermediate its length on a substantially vertical, fixed stud 1733 and is sprung urged in a counter-clockwise direction by a spring 1757. The forward end of the lever 1732 is provided with a notch receiving the pin 1688 on the slide 1678 and the rear end of the lever carries an up projecting pin 1734 which is engaged in a guide formation extending forward from the left-hand bail leg 1728 of the bail 1727.

With this arrangement, the lever 1732 transmits the movements of the slide 1678 to the bail 1727 in substantially the same amount of movement, but in the opposite direction.

A series of rack teeth 1735 is provided on the right-hand portion of the forward edge of the slide 1677 (FIG. 53A) and an arm 1736 is rockably mounted at its right-hand end on the slide 1739 by a pivotal mounting (FIGS. 7, 63 and 50). This arm has at its left-hand end a detent formation engageable with the rack teeth 1735. The slide 1703 has its front edge terminating in an inclined cam edge 1737 (FIGS. 7 and 52) spaced from the right-hand end of this slide. The arm 1736 carries at its left-hand end a roller 1738 to prevent the nose of arm 1736 from being engaged with the rack teeth 1735 upon right-hand movement of the arm 1736 relative to the slide 1703 to an extent to bring the roller 1738 to the right of the cam edge 1737. The straight front cam face of the slide 1703, between the cam edge 1737 and the right-hand end of this slide, will maintain the arm 1736 out of engagement with the teeth 1735 as long as the roller 1738 is opposed to this portion of the front edge of the slide 1703.

FIG. 61 shows the lever 1680 and slide 1703 in their extreme right position, that is, with the ear 1700 in the rightmost notch of rack 1649 (FIG. 7). This setting causes the decimal point to be printed to the right of the rightmost (lowest) order of the printed value.

In the operations of addition and subtraction, the position of the decimal point will be set by lever 1680 (FIG. 7). Since this setting controls only the printing of the decimal point, the operator must take care to enter digits for exactly the number of decimal places thus shown in the printed values.

As was explained earlier, lever 1732 (FIG. 61) moves bail 1727 to the right each time that lever 1680 is moved to the left for selecting a decimal point. The position of

bail 1727 controls the position to which the primary, or movable, accumulator 505 is set for printing products.

For example, in multiplication, ear 1700 may be set in its rightmost notch. If then two numbers without "decimal places" are multiplied, the product will be printed without decimal places, as for example, $122 \times 111 = 13542$.

Alternatively ear 1700 may be set in some other position, e.g., the third notch from the right, for selecting two decimal places. With this setting the operator must take care that each of the numbers to be multiplied have two decimal places.

Suppose the two numbers to be multiplied are "1.22" and "1.11," the product of which is "1.3542," the machine will discard two decimal places and print "1.35." If all the orders of the product are desired, one method is to enter the multiplier and multiplicand without a decimal point, or with all significant digits to the left of the decimal point. Thus, multiplier, multiplicand and product might be printed as "122," "111" and "13542," or as "122.00," "111.00" and "13542.00."

An L-shaped bail 1741 is pivoted at 1742 to the left-hand side of the frame 107 (FIG. 51) and is positioned below the index bail 1727. An arm 1743 of the bail 1741 extends up from the pivot 1742 and at its upper portion is provided with a cam nose 1748. A crosspiece of the bail 1741 extends to the left from the arm 1743 and has a rearward directed arm 1744 which has a roller 1745 that lies on a cam plate 1746 secured to the paper feed shaft 284. A spring 1747 is connected to the arm 1744 and urges the roller 1745 to ride on the cam surface of the cam plate 1746.

As the paper shaft 284 is rotated when the shift clutch is engaged, the cam plate 1746 will oscillate the bail 1741 in every cycle of the shaft 284. This will cause the bail 1741 to move its cam nose 1748 into and out of engagement with the notches 1730 on the forward edge of the index bail 1727. If the index bail 1727 is out of ordinal alignment, the cam nose 1748 of the bail 1741 will align the index bail in proper alignment. Cam plate 1746 permits cam nose 1748 to disengage the notches 1730 of bail 1727 only when the shift clutch and the cam 1746 are in their home positions. Bail 1727 is actuated by the movable accumulator 505 during certain shift operations, and bail 1741 prevents bail 1727 from being moved right or left at those times.

A two-arm index detent lever 2278 (FIG. 61) is pivoted at 2279 on a bracket 2280 which is fastened to the inner side of the left-hand frame plate 102. The arm 2281 extends to the right, parallel to the index bail 1727. This arm is provided at its distal end with the roller 2282 engageable between the teeth 1731 of the index bail 1727. A rearward directed arm 2283 of the detent lever 2278 has an upturned ear 2284 on its left-hand edge and an ear 2285 at its distal end.

Positioned below lever 2278 and also pivoted at 2279 is a lever 2286 which extends rearward from the pivot 2279 and has at its rear end an abutment 2287 that lies adjacent a collar 2288 fixed to a transverse rod 2289. This rod is guided for transverse movement in the frames 102 and 110.

The lever 2286 has adjacent the pivot 2279 an upturned ear 2290 abutting the rear of the arm 2281 of the detent lever 2278. A spring 2291 attached to the lever 2286 urges the abutment 2287 of this lever against the collar 2288. With this arrangement, when rod 2289 and collar 2288 are moved to the left, the lever 2286 will be rocked in a counter-clockwise direction, as viewed in FIG. 61.

A latch arm 2292 is pivoted on the lever 2286 at 2293. This latch arm has an abutment 2294 at its left end engageable with the upstanding ear 2284 of the detent lever 2278. To the right of the pivot 2293, latch arm 2292 has an extension 2295 that is provided at its end with a spring 2296 fastened between this arm and the upturned ear 2290 on the front of lever 2286. This spring urges the latch arm 2292 in a clockwise direction to hold the latch 2292

in engagement with the ear 2284. With this arrangement, the levers 2278 and 2286 will move as a unit under certain conditions.

A lever 3005 is pivoted midway its length on a stud 3006 to the frame 102 (FIG. 38). The lower end of this lever is positioned to the rear of a pin 1892, which is an extension of the pivot for an arm 1889 (FIG. 55) which is pivoted on the upper part of a lever 1885. The upper extension of lever 3005 lies behind the latch abutment 2294 of the latch 2292 (FIG. 61). Lever 1885 is rocked, clockwise in FIG. 55, by cam 217 shortly before the end of each cycle of main shaft 135, and returned rearward shortly after the beginning of the next cycle. Thus, during most of each cycle of main shaft 135, lever 3005 is held in its clockwise position (FIG. 38) for holding latch 2292 forward, and lever 2286 disengaged from lever 2281. When main shaft 135 is home, latch 2292 is free to operatively connect those levers.

The left-hand counter register frame 1472 (FIG. 20) 20 has attached to its upper end, a formed arm 3007 mounted on the frame 1472 by screws on a cam detent bracket 1975. This arm 3007 lies in alignment with the right-hand end of the rod 2289, to move the rod 2289 and its collar 2288 to the left, as viewed in FIG. 61, when the primary accumulator 505 and counter register 510 as a unit travels to its limiting left-hand position.

The movement of the rod 2289, as described above, will remove the detent roller 2282 from between the teeth 1731 of the index bail 1727 so that spring 1757 can return bail 1727 to its extreme left-hand position. It is to be noted that although lever 3005 (FIG. 38) lets latch 2294 (FIG. 61) move rearward against ear 2284 whenever main shaft 135 is in home position, the shoulder of lever 2294 will be far enough to the right to latch ear 2284 only if the traveling registers 505, 510 are out of their leftmost position. Consequently, as the registers 505, 510 are shifted into their leftmost position (shaft 135 being home during shift operations), latch 2294 will be in latching engagement with ear 2284 so that the final shift of the registers into their leftmost position will move rod 2289 to the left for lifting roller 2282 away from bail teeth 1731 to let spring 1757 return bail 1727 to its leftmost position. While the registers remain in their leftmost position (during addition and subtraction, and during the entry of a multiplier) arm 2286 will be held leftward, but the first cycle of main shaft 135 will cause arm 3005 to push latch 2294 forward for releasing lever 2278, and then spring 2291 will hold roller 2282 in engagement with teeth 1731 for detenting bail 1727 even though abutment 2290 is held away from arm 2281. When the registers 505, 510 are shifted to the right during multiplication, spring 2291 pulls arm 2286 to the right so that abutment 2290 engages arm 2281 to add the force of spring 2291 to the detenting action of roller 2282. Then as the registers are again shifted to their leftmost position (for example, as will be described under "Total After Multiplication"), roller 2282 is again lifted off teeth 1731 to let bail 1727 return to its leftmost position.

22. ENTRY OF MULTIPLIER

In order to establish automatic multiplication, the multiplier is first set up in the selection mechanism by sequentially depressing the keys of the ten-key keyboard 65 in the well-known manner. At this time, a decimal point may be inserted into the multiplier in the manner described above. The multiplier entry (X) key 306 (FIG. 55) is then depressed to enter the multiplier into the multiplier storage mechanism, generally indicated at 510 (FIG. 19).

As previously explained, multiplier entry (X) key 306 has a flat stem 1528 (FIG. 55), carrying at its lower end the roller 1529 bearing on the upper edge of the lever 75 1525 rockably mounted intermediate its length on the

pivot stud 1526. The lever 1525 is rocked in a counter-clockwise direction, as viewed in FIG. 55, when the multiplier entry key is depressed, to raise the pin 1524 projecting to the right from the front end of this lever. The pin 1524 extends through an aperture 1527 in the left-hand frame plate 105 of the machine and engages a rearward projecting arm 1545 of the bail 1416 (FIGS. 4 and 66) to rock this bail in a clockwise direction, as viewed in FIG. 55. At its right-hand end, the bail 1416 is connected to the link 1417 (FIGS. 29 and 66) to operate the symbol printing mechanism of the machine, which mechanism is more fully shown and described in Patent No. 3,181,786, previously mentioned.

As shown in FIG. 66, the pin 1524 also engages the cam edge 1523 at the bottom end of the lever 1522, and rocks this lever in a counter-clockwise direction. The lever 1522 is one arm of the bail 1517, a second arm 1516 of which is connected by the linkage 1515, 1510 and 1513, to the hook 1509 to engage this hook with the pin 1505 on the cam-operated lever 1504 to set the servo mechanism, which, when the add-subtract cam 227 turns, acts through the lever 1501, link 1498, bail 1495, link 1493 and the arms 1492 and 1489 to rock the levers 1481 and 1482 to shift the storage mechanism 510 forward and engage the drive gears 1480 thereof with the actuator sectors 450. From the position of the cam following roller 1506 on the add-subtract cam 227, as shown in FIG. 66, it will be apparent that the storage mechanism is rocked to engage the actuator sectors at the end of the first half of the operating cycle and just before the actuator bail 453 begins its upstroke to return the actuator sectors to their full-cycle, or "0," position.

As has been previously explained in connection with FIG. 4, the stem 1528 of key 306 also carries a pin, or roller, 173 which engages the cam edge 171 of the motor and clutch control slide 163 to move this slide forward, thereby closing the motor control switch.

As there is no provision for lowering the forward end of the link 748 (FIG. 29) to disengage shoulder 754 from tongue 482 for preventing the operation of the add pendent gear unit 475 (FIG. 32), the add-subtract cam 227 will move this unit to engage the selection sectors 338 at the beginning of a cycle to read the value out of the selection mechanism and into the actuator sectors 450 during the first half of the cycle.

The pin 1353 (FIG. 55) projects to the left from the intermediate portion of the multiplier entry key stem 1528 and this pin engages the top edge of the front end 1362 of the double lever 1363 (FIG. 48) previously described in connection with the keyboard clearing operation. Depression of the multiplier entry key thus rocks the lever 1363 and sets the hook 1370 (FIG. 48) in position to engage the left-hand end portion of the gear shaft 480 (FIG. 21) of the add pendent gear 475 to cautiously block this add pendent gear mechanism from moving into engagement with the grand total register to make a false entry in this register during the second half of the operating cycle. As neither the addition hook 738 (FIG. 25) nor the subtraction hook 779 (FIG. 26) is raised by the depression of the multiplier entry key, neither of the add pendent gear trains 512 or 526 will be moved into mesh with the drive gears of the primary accumulator, and the multiplier will not be entered into the primary accumulator at the same time that it is entered into the storage mechanism 510.

Near the end of the cycle, the cam following roller 1506 (FIG. 66) rides off of the high portion of the cam 227, and the spring 1507 rocks the lever 1504 in a counter-clockwise direction, as viewed in FIG. 66. This frees the hook 1509 to drop away from the pin 1505, and the link 1498 to return to its forward limiting position at which the lower end of the lever 1501 rests against the stop 1503. A spring 1499 then pulls the link 1493 down and the spring 1488 rocks the levers 1481 and 1482 in a direction to move the counter storage mechanism 510

rearward and out of mesh with the actuator sectors 450. The multiplier is now stored in the multiplier storage, or quotient register, unit 510. Since the multiplier entry procedure is a single cycle operation of the machine, involving no repeat action, the selection mechanism will be cleared of the multiplier value during the first half of the cycle when the input value is read out of the selection mechanism into the actuator sectors. During the latter portion of this same cycle, the shiftable unit of the selection mechanism is restored to its right-hand, home, position. This puts the selection mechanism in condition to receive the multiplicand. The multiplicand is entered in the usual manner by successive depression of the digit keys and automatic multiplication may then be initiated by depression of the multiplication or (=) key 307.

23. AUTOMATIC MULTIPLICATION

The flat stem 1415 of the multiplication (=) key 307 (FIG. 55) is guided for vertical movement on the vertically spaced studs 1750 and 1751 extending through corresponding, longitudinal slots in the key stem. The key is resiliently urged to its raised position by a suitable tension spring, not illustrated. The latch lever 1654 depends from a fixed stud 1753 and is formed near its lower end with a down facing shoulder 1754. When the key 307 is depressed, a pin 1755, carried by the key stem, engages under the shoulder 1754 so that the key is held depressed until it is automatically released at the end of the multiplication operation.

At the end of the multiplication operation, the link 1653 is pulled rearward by engagement of the pin 459 with the tongue 1655 on the rear end of link 1653 in the manner previously described. A blocking lever 1756 is also mounted on the stud 1753, and has a shoulder engageable under the pin 1755 to preclude depression of the key 307 if the latch lever 1654 is moved to its key-releasing position before the key 307 is depressed. The multiplication key 307 thus cannot be depressed unless the latch lever 1654 is free to latch it in depressed position. The key stem 1415 carries the pin 172 which is engageable with a cam edge 170 of the motor switch and clutch control slide 163 (FIG. 4) to establish cyclic operation of the machine when the multiplication key is depressed.

Referring to FIG. 48, the bail lever 1762 rocks on the shaft 164 and has the rear arm 1343, a down extending arm 1783 and a pair of similar substantially parallel, forward extending arms, of which the left arm 1761 is shown in FIG. 48. The right forward arm 1761a (FIG. 54 of this bail 1762 underlies the latch pin 1755 (FIG. 55) on stem 1415 of the multiplication (=) key 307. Pin 1755 is aligned with a pin 2034 (FIG. 65) on stem 2030 of division (--) key 310. The intermediate portion of this same right arm 1761a overlies a pin 1763 (FIGS. 12 and 54) which is carried by the upright strut 430 (FIG. 12) of the repeat control mechanism. When this forward arm of bail 1762 is forced down by the pin 1755, upon depression of the multiplication key, the strut 430 is also forced down. At its lower end, the strut is connected to the rear end of the arm 431 of the bail 1764, rockably mounted on the shaft 432. The second arm 1765 of this bail carries the pin 433 which engages the lower end of the zero latch lever disabling member 434 and moves this member to its zero latch disabling position upon a downward movement of the strut 430. At its upper end, the strut 430 is pivotally connected at 1766 (FIG. 13) to the right-hand end of an arm 1767 of the lever 420 to rock this lever in a clockwise direction, as viewed in FIGS. 13 and 54, and move the hook formation 407 (FIG. 12) of the selection carriage restore link 405 out of the path of the stud 408 on the cam 217 to thereby disable the carriage restore mechanism. With the zero latch mechanism and the carriage restore mecha-

nism both disabled, the multiplicand will remain in the selection mechanism of the machine during the successive machine operating cycles from the beginning to the end of the multiplication operation.

An interponent lever 1768 (FIG. 48) is rockably mounted, intermediate its length, on the pin 1368 at the upper end of the third, or intermediate, arm 1369 of the print blocking lever 1338. This lever is resiliently urged to rock in a clockwise direction, as viewed in FIG. 48, by a spring 1769, connected between one end of the interponent lever 1768 and the arm 1345 of the print blocking lever 1338. The rearward projecting arm 1343 of the bail 1762 carries, at its rear end, a roller stud 1770 bearing on an up facing cam edge of the interponent lever 1768 disposed rearward of the pin 1368. The spring 1342 normally urges the bail 1762 to rock in a counter-clockwise direction, as viewed in FIG. 48, and this maintains the interponent lever 1768 rocked in a counter-clockwise direction against the force of spring 1769, the spring 1342 being stronger than the spring 1769. When the multiplication key 307 is depressed and the bail 1762 is rocked in a clockwise direction, as viewed in FIG. 48, the spring 1769 rocks the interponent lever 1768 in the clockwise direction and positions the rear end of this interponent lever in the path of a stud 1771 carried by the print cam 220.

Near the end of the first operating cycle after the multiplication key has been depressed, the stud 1771 engages the rear end of the interponent lever 1768 and rocks the print blocking lever 1338 to its print blocking position. A latch hook 1772 is rockably mounted at its lower end on a pivot stud 1773 carried by a frame bracket 1744 at the front end of the machine, and has at its upper end a hook formation engageable with a stud 1775 carried by a rearward extension of the arm 1340 of the print suppressing lever 1338. The latch hook is urged to stud-latching position by a tension spring 1776 and is normally held in inoperative position by a bail 1777 rockably mounted on a pin 1760 carried by the bracket 1774. The bail 1777 has a forward projecting arm 1778 which carries a stud 1779 overlying a forward projecting toe formation 1780 of the latch lever 1772. When the bail 1777 is held in its normal position, that is, rocked in a clockwise direction, as viewed in FIG. 48, the stud 1779 bears on the upper edge of the toe formation 1780 and holds the latch hook 1772 out of position to engage the stud 1775. The bail 1777 has an arm 1781 projecting up from the bail pivot 1760 and connected at its upper end by a link 1782 with the lower end of the depending arm 1783 of the bail 1762. With this arrangement, as long as the bail 1762 is maintained rocked in its normal counter-clockwise direction by the spring 1342, the latch hook 1772 is maintained in inoperative position. However, when the bail 1762 is rocked in the clockwise direction by depression of the multiply key 307, the bail 1777 is rocked in the counter-clockwise direction, as viewed in FIG. 48, and the hook 1772 is released for movement by its spring 1776 to engage the stud 1775 and latch the print blocking lever 1338 in its print blocking position when the lever is moved to this position by the action of the stud 1771 on the interponent lever 1768, as described above. The printing operation of the machine will thus be blocked after the first machine cycle of the multiplication operation, and will be restored when the multiplication key 307 is released at the end of the multiplication operation, as will be later described.

An angularly shaped lever 1785 (FIG. 55) is mounted, adjacent its midlength location, on a shaft 831, which extends transverse the lower portion of the machine adjacent the midlength location of the base 100, and is firmly supported by the upright plates of the machine frame. This lever has an arm 1787 projecting forward from the shaft 831, and a second arm 1788 projecting up and rearward from the supporting shaft. An arm 1789 is fixed to, and extends rearward from, the shaft 1408 and

this arm has at its rear end, a pin-and-slot connection 1790 with the forward end of the lever arm 1787 so that the lever 1785 is rocked in a clockwise direction, as viewed in FIG. 55, when the multiplication key 307 is depressed to rock the lever arm 1412. Near its free end, the lever arm 1788 is provided with a forward facing abutment formation 1791 which engages a pin 1792 and moves this pin forward when the lever 1785 is rocked. The free end of this lever arm 1788 is bail-shaped and includes a cross portion 1793 (FIGS. 18 and 55) which extends to the right from the end of the lever arm 1788 and terminates in a depending abutment formation 1794. The abutment formation 1794 is disposed rearward of a pin 1795 and is effective to move this pin forward when the lever 1785 is rocked by depression of the multiply key 307.

The pin 1795 projects laterally from the lower end of a lever 1784 (shown also in FIG. 6) so that this lever is rocked in a counter-clockwise direction, as viewed in FIG. 55, when the multiply key 307 is depressed and the pin and roller 1445, carried at the upper end of this lever 1784, moves rearward and depresses the cam edge 455 (FIG. 51) of the link 461 and lowers the hook formation 460, at the forward end of this link, into engagement with the pin 459 on the actuator member 449. This connection will cause the link 461 to reciprocate forward and rearward during each subsequent operating cycle of the machine until the end of the multiplication operation, and this action will rock the arm 1640 and the shaft 1491 (FIGS. 51 and 49). As was explained in connection with FIGS. 14 and 19, rocking of the shaft 1491 acts, through the lever arm 1626, to move the slide 1622 backward and forward and the slide 1622 drives the feed pawl 1628 for reading the value of the multiplier out of the storage mechanism.

The pin 1792 (FIGS. 18, 55 and 5) projects laterally from the front end of a slide 1796 extending longitudinal of the left-hand side of the rear portion of the machine. This slide is supported at its rear end by a stud 1797 projecting from the depending arm 1798 (FIG. 55) of a three-armed lever 1799 rockably mounted intermediate its length on a fixed pivotal mounting 1800. The slide, or link, 1796 is connected by a pivot pin 1801 to the lever 1461 rockably mounted at its upper end on the shaft 265. At its lower end the lever 1461 carries the pin 1460 (FIG. 58), which projects to the right from the lever 1461, and is engaged in the groove 1459 of the right shift sleeve 1448. When the lower end of lever 1461 is thus moved forward, pawl 1464 (FIGS. 59 and 60) is set for right shifting of the primary accumulator and the multiplier storage mechanism throughout the multiplication operation.

When the multiplication (=) key 307 is depressed, the machine is conditioned for an automatically selected addition or subtraction operation. As shown in FIGS. 23 to 26, a pair of substantially vertical levers 1805 and 1806 is rockably mounted, intermediate their length, on the shaft 851 disposed forward of, and somewhat above, the main drive shaft 135. The lever 1805 (FIG. 25) extends up from the shaft 851 past the lever 730 which controls the add pendent gear mechanism of the machine, and at its upper end, this lever carries a laterally disposed roller 1807 which overlies the upper edge of the add control lever 730. With this arrangement, when the lever 1805 is rocked in a counter-clockwise direction, as viewed in FIG. 25, the hook 738 of the add control link 736 is raised to engage the laterally projecting tongue 523 on the bail of the add pendent gear 512 of the rear, primary, or shiftable accumulator 505, and move this add pendent gear to operative position to thereby accomplish an addition cycle of the machine.

Referring to FIG. 26, subtract lever 1806 has a portion extending up from the shaft 851 past the subtraction control lever 772. This lever carries, at its upper end, a laterally disposed stud, or roller, 1808 overlying the upper

edge of the lever 772. With this arrangement, when the lever 1806 is rocked in a counter-clockwise direction, as viewed in FIG. 26, the lever 772 is rocked to raise the hook 779 on the subtraction control link 776 to engage the tongue 535 on the bail 534 of the subtract pendent gear 526 of the shiftable accumulator 505 to rock this pendent gear to operative position and thus establish a subtraction operation of the machine.

The lever 1805 is resiliently rocked in the counter-clockwise direction, as viewed in FIG. 25, by a tension spring 1809, and the lever 1806 is resiliently rocked in the same direction by a corresponding tension spring 1810.

Lever 1805 is normally held against rocking movement by the spring 1809 by one arm 1811 of a three-armed lever 1812 rockably mounted on the shaft 741 (see also FIG. 23). At its forward end, the arm 1811 has a transverse shoulder which engages a stud 1813 projecting laterally from the lower end of the lever 1805. When the lever 1812 is rocked in a clockwise direction, as viewed in FIG. 25, the forward end of the arm 1811 is raised to release the stud 1813 from the shoulder at the forward end of the arm 1811 and thus free the lever 1805 for rocking movement. The lever 1805 has a rearward directed extension intermediate its length, carrying, at its rear end, a laterally projecting stud, or roller, 1814. The restore cam 229 (FIG. 1) on the main cam shaft 135 engages the stud 1814 near the end of an operating cycle of the machine and, if the lever 1805 has been released during this cycle, rocks the lever back to an extent at which the stud 1813 is in position to be engaged by the shoulder at the forward end of the arm 1811 to again latch the lever 1805 in inoperative position.

The three-armed lever 1812 (FIG. 23) has an up directed arm 1816, the purpose of which will be described in connection with the division operation of the machine, and has a down and rearward directed arm 1817 carrying at its lower end a laterally projecting stud 1818. This three-armed lever 1812 is resiliently rocked in a counter-clockwise direction, as viewed in FIGS. 25 and 23, by a spring 1819 connected between the tail portion 1817 of the lever and a fixed spring support 1820.

A three-armed bail lever 1821 (FIG. 23) is rockably mounted on the shaft 741 and has an up extending arm 1825 to the right of lever 1812 (left and forward as seen in FIG. 23). This lever 1821 has a cross bail 1804 extending to the left (right and rearward in FIG. 23) and has a forwardly projecting arm 1822 provided at its front end with a shoulder, or abutment formation, 1823 which is normally engageable with a stud 1824 projecting laterally from the lower end of the lever 1806 to normally hold this lever against being rocked by the spring 1810 (see also FIG. 26). The three-armed lever 1821 has a rearward and downward extending tail portion 1826 carrying a laterally projecting stud 1827 at its rear end. The lever 1821 is resiliently rocked in a counter-clockwise direction, as viewed in FIGS. 26 and 23, by a spring 1828 connected between the tail portion 1826 and the fixed spring anchor 1820.

When the three-armed lever 1821 is rocked against the force of the spring 1828 to raise the forward end of the lever arm 1822, this releases the lever 1806 to be rocked by the force of spring 1810 to place the machine in subtractive operation. Near the end of each operating cycle, the lever 1806 is restored to a position at which the abutment formation 1823 can re-engage the stud 1824 by the cam 228 on the main cam shaft 135, engaging a cam following roller 1830 carried by the lever 1806.

As is particularly shown in FIGS. 23 and 24, a link 1835 extends rearward from the stud 1818 on the tail portion of the lever 1812. A similar link 1836 extends rearward from the stud 1827, carried by the tail portion 1826 of the bail 1821. If these links are in longitudinal alignment with the corresponding studs, a forward movement of the link 1835 will rock the lever 1812 to release the addition control lever 1805 and a forward movement of

the link 1836 will rock the three-armed bail 1821 to release the subtraction control lever 1806. Normally, however, the front ends of the links 1835 and 1836 are positioned out of alignment, above the corresponding studs, as shown in FIG. 24, so that forward movement of the links will not rock the bail or the three-armed lever.

As has been previously explained in connection with FIG. 55, depression of the multiplication key 307 rocks the shaft 1408 by rocking the arm 1412. As seen in FIG. 25, rocking of the shaft 1408 rocks the lever 1407 and moves the link 1411 forward. The link 1411 is pivotally connected at its rear end to the lower end of a depending arm 1837 of a bail 1838, rockably mounted on the shaft 831 at the lower right-hand side of the machine. The bail 1838 has an up and rearward projecting arm 1840, which carries at its rear end a laterally projecting pin 1841 which extends through longitudinal slots 1842 and 1843 provided at the forward ends of the links 1835 and 1836, respectively (FIGS. 25 and 26).

With this arrangement, when the multiplication key 307 is depressed and the link 1411 moved forward, the bail 1838 is rocked in a clockwise direction, as viewed in FIG. 25, and the forward ends of the links 1835 and 1836 are lowered into alignment with the studs 1818 and 1827 to engage those studs if these links are moved forward.

At its rear end, the link 1835 is pivoted to the lower end of a depending arm 1845 (FIG. 25) of a bail 1846 rockably mounted on the shaft 1496 disposed at the lower rear portion of the machine. A rearward projecting arm 1848 of the bail 1846 is pivotally connected to the lower end of a substantially vertical link 1849. The upper end of this link is pivotally connected to the rear end of a rearward extending arm 1850 of a geniculate sensing lever 1851. The lever 1851 is rockably mounted at its forward end on transverse stub shaft 1852 fixed to frame member 111 (see also FIG. 14). Lever 1851 has an up projecting arm 1853, the upper end of which is disposed to be engaged by an upper sensing slide 1854. The forward end of slide 1854 (FIG. 14) is articulately joined to the upper sensing lever 1590 of the multiplier storage unit, by a pin 1863 near the right end of that lever. Slide 1854 has an offset abutment 1864 at its rear end which is held in alignment with the upper arm 1853 of lever 1851 by a pin 1865 and angle bracket 1866 fixed to bracket 1600. When the slide 1854 is moved rearward by lever 1590 (FIG. 14), the lever 1851 is rocked in a clockwise direction, as viewed in FIG. 25, rocking the bail 1846 to move the link 1835 forward and thereby raise the arm 1811 of bail 1821 and free the add control lever 1805 for operation.

The link 1836 similarly is pivotally connected at its rear end to a depending arm 1855 (FIG. 26) of a bail 1856, also rockably mounted on the shaft 1496. The bail 1856 has a rearward projecting arm 1857, and a substantially vertical link 1858 is pivotally connected at its lower end to the rear end of the arm 1857. At its upper end, the link 1858 is pivotally connected to the rear end of a rearward projecting arm 1859 of a second sensing lever 1860 rockably mounted at its forward end on the shaft 1852. Bail 1856 (FIG. 26) lies inside of bail 1846 (FIG. 25). Consequently, although link 1835 lies to the left of link 1836 (right as seen in FIG. 23), link 1858 and lever 1860 (FIG. 26) lie to the right of link 1849 and lever 1851, as shown in FIG. 14. The lever 1860 has an up extending arm 1861, the upper end of which is opposed to the rear end of a second sensing slide 1862 disposed below the slide 1854. Slide 1862 is articulately joined to the lower sensing lever 1591 near the right end thereof, and guided by pin 1865. It is thus apparent that when the multiplication key has been depressed, the addition and subtraction operation of the machine is given over to automatic selection by the sensing slides 1854 and 1862.

The addition and subtraction control of the machine during multiplication is automatically selected by the

short cut multiplication mechanism in the storage register 510, as has been previously explained in connection with FIG. 19. If the multiplier value, which has been entered into the order of the storage mechanism at the readout station, is from "1" to "5," inclusive, the corresponding positive cam 1570 will rock the coordinate lever 1574 and the corresponding irregular lever 1580, moving the right-hand portion of the upper, or positive, lever 1590 (FIG. 14) rearward. This is occasioned by the pressure of the abutment formation 1582 on the irregular lever 1580 against the roller 1596 carried by the transverse lever 1590 near the right-hand end of this transverse lever. This rearward movement of the right-hand end of the transverse lever 1590 (FIGS. 14 and 15) moves the slide 1854 rearward and rocks the geniculate lever 1851, forcing the link 1849 down (FIG. 25). This forces the link 1835 (FIG. 25) forward and rocks the three-armed lever 1812 to condition the machine for additive operation.

If the value of the multiplier digit in the order of the storage mechanism at the readout station is a value from "6" to "9," inclusive, the cam 1571 (FIG. 19) will rock the subtract control lever 1576 and the lower irregular lever 1585 so that the abutment 1588 on the lever 1585 will exert pressure on the roller 1597 and force the right-hand end of the lower transverse lever 1591 rearward (FIGS. 14 and 15). This will move the slide 1862 rearward and rock the sensing lever 1860 to force the link 1858 down (FIG. 26). This will force the link 1836 forward and forward movement of this link will rock the three-armed bail lever 1821 to release the subtract lever 1806 and place the machine in condition for a subtractive operation.

The readout position of the rollers 1596 and 1597, that is, the readout station, is in alignment with the lowest order (rightmost order) of the counter register 510 when the accumulator 505 is in its extreme left-hand position. With the accumulator and the storage mechanism in left-hand position at the entry of the multiplier into the storage mechanism, all of the multiplier digits except the lowest order digit will be to the left of the readout station. As the accumulator 505 and multiplier storage unit 510 shift to bring levers 1580 and 1585 of successive orders into alignment with rollers 1596 and 1597 of the readout levers 1590 and 1591, levers 1580 and 1585, when held rearward, will engage those rollers and cam them rearward. When the multiplier is being entered from the actuator, levers 1590 and 1591 will be free and will offer no resistance to deflection by levers 1580 and 1585.

Since, as explained above, the hook formation 460 (FIG. 51), at the forward end of the link 461, is lowered into engagement with the pin 459 on the actuator 449 of the actuator operating bail mechanism when the multiplication key is depressed, and since the multiplication key initiates an operating cycle of the machine, the slide 1622 (FIG. 19) will be reciprocated forward and backward. If the multiplier value at the readout station is "5" or less than "5," the multiplicand in the keyboard will simply be added into the primary register a number of times corresponding to the value standing in the storage gear at the readout station. As has been previously explained, the correct number of additions is counted by the readout feed pawl 1628 engaging the readout abutment 1630 at its forward end with the teeth of the gear 1478 below the gear axle 1475 and turning the gear back toward "0" one unit for each operating cycle of the machine. The proper engagement of the feed pawl with the gear is controlled by the levers 1574, 1580, 1590 and 1610 (FIGS. 14, 15 and 19), rocking the forward end of the guide cam 1613 up so that the guide pin 1637 on the feed pawl passes below the oppositely tapered, returned end portion 1621 of the guide cam, as has been previously explained.

If the value in the storage gear 1478 at the readout station is a number from "6" to "9," the levers 1577, 1585, 1591 and 1610 will be rocked to lower the front end of the guide cam 1613 and the front end of the

feed pawl 1628 will then be raised by engagement of the guide pin 1637 with the upper edge of the returned end portion 1621 of the guide cam, so that the abutment 1630 at the front end of the feed pawl will engage the teeth of the gear 1478 above the gear axle 1475. This will feed the gear 1478 forward to "0" so that the multiplicand value standing in the keyboard will be subtracted from the primary accumulator a number of times equal to the tens-complement of the value standing in the storage gear 1478 at the readout station. As the gear 1478 turns from "9" to "0," a tens-transfer will be made to the storage gear of the next higher order, as has been previously described.

When a multiplier storage gear has been returned to its "0" position at the readout station, this frees the associated lever 1574 or 1577 (FIG. 19) to rock to its normal position, at which the front end of the lever is located adjacent the gear shaft 1475. This, acting through the link and lever train, moves the link 1835 (FIG. 25) or the link 1836 (FIG. 26) rearward, thereby freeing the lever 1812 or 1821. Then, as soon as the cam 229 or the cam 228 returns the released lever 1805 or 1806 to its latching position, the lever is latched by the bail arm 1811 or 1822, and the addition or subtraction operation of the machine is disabled. It then becomes necessary to shift the primary accumulator and the storage mechanism one order to the right to bring the gear 1478 carrying the next order of the multiplier to the readout station.

During multiplication, the lever 1180 (FIG. 51) will be latched, as described in application Serial No. 123,085, previously referred to, for taking the load of the spring 1199 off of the pin 1200 and frees the shaft 265 (FIG. 51). Freeing of the shaft 265 from the action of the spring 1199 leaves the arm 264 (FIGS. 55 and 6) free for operation by the readout sensing element of the multiplication mechanism, as will now be described.

When the storage gear 1476 at the readout station has been returned to its "0" position, and the pressure of the abutment formation 1582 (FIG. 19) has been relieved from the roller 1596, or the pressure of the abutment 1588 has been relieved from the roller 1597, as the case may be, whichever of the levers 1590 or 1591 was held in rocked position, with its left-hand end displaced forward, is released to return to a position parallel to the alternative lever (FIG. 14). This frees the sensing yoke 1602 (FIG. 51) to move rearward.

Referring to FIGS. 55 and 6, the lever 1606 is rockably mounted intermediate its length on the shaft 265 and is pivotally connected at its upper end to the forward end of a tail 1871 (FIG. 51) of the yoke 1602 by the connecting pin 1605 extending through an opening in the rear left-hand frame plate of the machine. The lever 1606 is resiliently urged to rock in a counter-clockwise direction, as viewed in FIG. 55, by a tension spring 1873 and is normally latched against such rocking movement by a hook 1874, which is mounted on a pin 1875 and engages a pin 1876 projecting from the lever 1606. The hook 1874 has a depending dog formation 1877 which bears against the forward edge of the cross portion 1793 at the rear of the lever arm 1788 (FIG. 18) so that, when the lever 1785 is rocked in a clockwise direction, as viewed in FIG. 55, by the depression of the multiplication (=) key 307 and as explained above, the hook 1874 is moved counter-clockwise to release the lever 1606. The spring 1873 then rocks the lever 1606 until the rear end of the yoke 1602 (FIG. 51) is brought to bear against the forward edge of the lever 1590 or 1591, which has its left-hand end displaced forward, and to move rearward to engage the forward edges of the left-hand portions of both of these levers when the levers are brought to parallel position by reading out to "0" the value in the storage gear at the readout station. This rearward movement of the yoke 1602, when a value in the storage gear at the readout station has been read out to "0," will free the spring 1873 to rock the lever 1606 in a counter-

clockwise direction, as viewed in FIGS. 55 and 6. The lever arm 264 is fixed to one end of the shaft 265 and a three-armed lever 1878, particularly shown in FIGS. 44 and 45, is fixed to this shaft to the right of the arm 264. The lever 1878 has an upward extending arm 1880 carrying at its upper end a pin 1879 which extends to the right, past the rear edge of the upper portion of the lever 1606 (FIGS. 56 and 6), so that, when the lever 1606 is rocked in a counter-clockwise direction, as explained in connection with FIG. 6, lever 1606 will abut pin 1879 to also rock the shaft 265 and the arm 264 in a counter-clockwise direction, although the lever 1606 is itself freely rockable on the shaft 265. The lever 1878 has a downward and rearward projecting arm 1881, carrying at its lower end a laterally projecting pin 1882, and a downward and slightly forward extending arm 1883, carrying at its lower end a laterally projecting pin 1884. The purpose of the pins 1882 and 1884 will be described later in connection with total-taking after multiplication, and with division aligning.

Rocking movement of the lever 1606 is coordinated with the cyclic operation of the machine by the cam 217 mounted on the main drive shaft 135. As shown in FIG. 55, the cam lever 1885 is mounted at its lower end on the shaft 831 which supports the lever 1785. This lever extends up to the rear side of the cam 217 and carries a cam following roller 1886 substantially at the level of the main drive shaft 135. A spring 1887, connected to the upper portion of the lever 1885 and extending forward from this lever to a fixed connection, maintains the roller 1886 in firm engagement with the peripheral edge of the cam. The cam 217, shown in home position in FIG. 55, is substantially circular in shape but has a single low portion 1888 into which the cam following roller 1886 rides just before the end of each cycle of the machine and which continues into the beginning of the next cycle. The lever 1885 will thus be rocked to a limited extent in a clockwise direction, as viewed in FIG. 55, immediately prior to the end of each operating cycle of the machine. The link 1889 is pivotally connected at its forward end to the upper end of the lever 1885 by the pivot pin 1892, and is connected at its rear end to the lower end of the lever 1606 by a pin-and-slot connection 1890. The spring 1873 (FIGS. 55 and 6), located on the lever 1606, resiliently urges the pin to the forward end of the pin-receiving slot in the link. This will cause the lever 1606 to be rocked when lever 1885 is rocked, but will also permit rocking of the lever 1885 without rocking of the lever 1606 when this lever 1606 is immobilized by the hook 1874.

As shown in FIG. 3, when the strut 263, connected at its upper end to the outer, or distal, end of the lever arm 264 (FIG. 6) is forced down when the spring 1873 rocks the lever 1606 forward, the lower end of this strut urges the pin 268 down to engage the shift clutch (FIG. 3). However, this action of lever 1606, controlled by cam 217 (FIG. 55), occurs just before the end of a machine cycle, and therefore occurs while the main clutch 136, 135 (FIG. 3) is still engaged. The interlock which includes shaft 275 prevents the two clutches from being engaged at the same time. Therefore, when lever 1606 swings arm 264 (FIG. 6) down, pin 268 cannot move, so link 263 is simply compressed. Immediately thereafter, at the end of the machine cycle, the main clutch disengages and permits the shift clutch to engage under the urging of the resilience of link 263, roller 1886 being still in the low of cam 217. It will be recalled that the main clutch has two control arms 150 and 271a, each independently capable of disengaging the clutch by intercepting abutment 143 on pawl 139. During multiplication, arm 150 is held free of pawl 139 by pin 173 (FIG. 4) on key 307 and linkage 175, 155 and 151, which also keep motor switch 123 (FIG. 2) closed. Normally, control arm 271a is held free of abutment 143 so that arm 150 exercises control, but the interlock compels arm

271a to move into pawl-intercepting position whenever arm 261 of the shift clutch frees the pawl 253 for engaging that clutch. Because arm 271a carries a roller similar to roller 149 on arm 150, and because that roller rides 5 a clutch disk 138, similar to disk 137, with a single low at home position, arm 271a can move into intercepting position only at the very end of the machine cycle. Thus, after the reading out of the storage gear 1478 (FIG. 19) at the readout station to "0" has been sensed by the yoke 1602, the shift clutch is engaged and the main clutch is disengaged at the end of the last readout cycle. During the next cycle, the primary accumulator 505 and the storage mechanism 510 will be shifted one step to the right, the conditioning of the machine for right shift of 10 the primary accumulator, upon depression of the multiplication key, having been previously described. As soon as the single step to the right has been accomplished, the value in the next order of the multiplier storage gears will move one of the levers 1590 or 1591 to shift 15 the yoke 1602 forward and disable the shift mechanism until the value has been read out of this storage gear. If the next storage gear in order should happen to contain a "0" value, a second shift cycle will be accomplished immediately to bring the third order of the storage gears 20 to the readout station. As many successive right shifts will be accomplished as there happen to be successive zeros in the multiplier.

The reading out and right shifting operations will continue until the highest value of the multiplier has been 25 read out of the storage mechanism and all of the multiplier storage gears are at their "0" position. When this occurs, the two bails 1645 and 1646, shown in FIG. 19, will move together so that the upper bail 1645 is free to move down.

30 35 A cross, or bridge, member 1895 (FIGS. 39, 40 and 55), extends transversely across the upper portion of the machine above, and somewhat forward of, the cross portion of the bail 1645. A lever 1896 (FIG. 40) is disposed at the rear side of the cross-member 1895 and pivotally mounted at its right-hand end to the cross-member near the right-hand end of the latter by a pivotal mounting 1897. At its left-hand end, the lever 1896 is connected to the right-hand end of a lever 1898 by a pin-and-slot connection 1899. Intermediate its length, 40 the lever 1896 carries a rearward extending arm 1900 (FIG. 39) terminating in a downward extending bracket 1901 carrying at its lower end the roller 1902. The roller is disposed rearward of, and somewhat below, the cross-member 1895 and rides on the upper surface of 45 the cross-member of the bail 1645 (FIG. 19). The axis of this roller extends transverse the machine so that the cross-member of the bail 1645 can pass under the roller as the storage mechanism 510 is moved forward and rearward, into and away from the position in which it engages the actuator sectors of the machine. When the 50 storage mechanism is in its normal or rear position, disengaged from the actuator sectors, the cross-member of the bail 1645 is directly under the roller 1902, and when there is a multiplier stored in the storage mechanism, the bail is raised and raises the roller 1902 and the left-hand end of the lever 1896. The lever 1896 (FIG. 40) is rockably mounted, near its right-hand end, on the cross-member 1895 by a pivotal mounting 1903. Raising of the left-hand end of the lever 1896 raises the 55 right-hand end and lowers the left-hand end of the lever 1898. Near its left-hand end, the lever 1898 has a depending extension, from the lower end of which projects a forward extending arm 1904 (FIG. 39) having a notch in its forward end. A pin 1905, projecting laterally from the rear end of the bail arm 1650, is received in the notch in the forward end of the arm 1904.

60 65 With this arrangement, as long as the arm 1904 is held in its lower position by the presence of a value in the storage register, the bail 1648 is held rocked in a counter-

70 75

clockwise direction, as viewed in FIG. 55, and the tongue 1655 on the rear end of the link 1653 is held above, and out of engagement with, the pin 459 on the operator bail plate 454. As soon as the last digit of the value stored in the multiplier storage mechanism has been read out and the bail 1645 descends, the bail 1648 is rocked in the clockwise direction, as viewed in FIG. 55, and this moves the tongue 1655 down behind the pin 459. This action takes place in the first half of the machine cycle when pin 459 is moving forward. It will be recalled that it is the forward motion of pin 459, acting through link 461, arms 1640 and 1639 (FIG. 49), shaft 1491, arm 1626 (FIG. 19), slide 1622 and feed pawl 1628, that drives the counter gears 1478 during this operation. During the second half of this same machine cycle, pin 459 moves rearward against ear 1655 (FIG. 55) and moves link 1653 and latch 1654 rearward to release the multiplication key 307.

24. CLEARING KEYBOARD AFTER MULTIPLICATION

The release of the multiplication key 307 does not immediately stop the machine since it is necessary for the machine to complete one additional cycle to clear the multiplicand out of the selection mechanism. As shown in FIG. 38, a lever 1910 is rockably mounted at its upper end on a fixed pivot 1911 carried by the left-hand frame plate of the machine and carries near its lower end, on a rearward projecting extension, a cam following roller 1912 which bears against the forward side of the peripheral edge of the cam 215. An up curved link 1913 is pivotally connected at its rear end to the lower end of the lever 1910 and extends forward from the lower end of the lever. The forward end of the link 1913 is supported by a fixed pin 1914 projecting through a longitudinal slot in the front portion of the link. A spring 1915, connected between the link 1913 and a fixed spring pin carried by the left-hand frame member of the machine, resiliently urges the link rearward to maintain the roller 1912 in engagement with the edge of the cam 215 so that the lever 1910 will rock during each cyclic operation of the machine and the link will be reciprocated backward and forward.

A bail 1916 (FIGS 38 and 42) extends transverse the front portion of the keyboard of the machine and is rockably supported on a transverse bail shaft 1917. At its right-hand end, this bail has a forward projecting arm 1918 that rests on a pin 1919 projecting to the left from the stem 1335 of the CLEAR KEYBOARD key 308, see FIGS. 48 and 65. When the bail 1916 is rocked in a counter-clockwise direction, as viewed in FIG. 38, the forward end of the arm 1918 will be forced down against the pin 1919 and will depress the CLEAR KEYBOARD key 308 to establish a clearing operating cycle of the machine.

At its left-hand end, the bail 1916 has a depending arm 1920, upon the lower end of which is pivotally mounted an interponent 1921 of geniculate shape (FIG. 38). This interponent has a rearward projecting arm 1922 terminating in an abutment formation 1923, which, when brought into opposition to the forward end of the link 1913, rocks the bail 1916 to depress the CLEAR KEYBOARD key 308, as described above. The interponent 1921 has a downward extending arm 1924. A spring 1925, connected between the lower end of the arm 1924 and the pin 1914, normally keeps the interponent rocked to a position at which the abutment formation 1923 is above the forward end of the link 1913, so that the link passes under the abutment formation and the bail 1916 is not rocked.

A second bail 1926 extends transverse the upper intermediate portion of the keyboard and is rockably mounted on a bail shaft, or pin, 1927 extending through the side

members of the keyboard frame. This bail has, at its left-hand end, a forward projecting arm 1928, the forward end of which is connected by an upright link 1929 with the forward end portion of the interponent arm 1922. With this arrangement, when the bail 1926 is rocked in a clockwise direction, as viewed in FIG. 38, the rear end of the interponent arm 1922 is lowered to a position in which it is engaged by the forward end of the link 1913 as this link is returned forward after having been moved rearward by the spring 1915 when the cam roller 1912 rides into the low portion of the cam 215. The bail 1926 has forward projecting arms 1930 and 1931, disposed one near each opposite end of the bail, and a third bail 1932 (FIG. 42) and a supporting pin therefor, extend between the rear ends of the bail arms 1930 and 1931. At its left end, bail 1932 includes the depending arm 1943 (FIG. 38). A spring 1937 biases the bail 1932 counter-clockwise, as seen in FIG. 38, and an ear on arm 1943 abuts arm 1930 for limiting that counter-clockwise rotation. Similar latch bails 1933 and 1933a, rotatably mounted on the same pin as bail 1932, lie below bail 1932. Light torsion springs, not shown, bias these bails 1933 and 1933a counter-clockwise, as seen in FIGS. 38 and 41, and upstanding ears 1934 and 1935 at their front edges abut bail 1932 to limit that counter-clockwise rotation.

The stem 1415 of the multiplication key 307 has, near the upper end of its forward edge, a forward projecting tooth 1936 (FIG. 41). This tooth has a transverse top surface which is positioned to engage under the front edge of the cross-member of the bail 1933 and to lift this bail when the multiplication key rises after a multiplication operation has been completed. The lower portion of the tooth 1936 is inclined up and forward so that this tooth can pass the rear edge of the bail 1933 when the multiplication key is depressed, and the bail will rock to bring its rear edge over the upper surface of the tooth when the key has been fully depressed. When the cross-member of the bail 1933 is engaged over the tooth 1936 on the stem 1415 of the multiplication key and this key is raised at the end of the multiplication operation, the bail 1933 is raised and raises the rear ends of the arms 1930 and 1931, thus rocking the bail 1926 in the clockwise direction, as viewed in FIG. 38. This clockwise rocking of the bail 1926 lowers the abutment 1923 on the interponent 1921 into the path of the front end of the link 1913 so that the CLEAR KEYBOARD key will be depressed by the servo operation of the cam arm 1910 at the end of the cycle in which the multiplication operation was completed.

An interponent 1938 is rockably mounted, intermediate its length, on a fixed pin 1939 and has a portion depending from the pin 1939 and disposed forward of a pin 1940 on the link 1913. This interponent is urged by a spring 1941 in a clockwise direction, as viewed in FIG. 38, and is rocked in the counter-clockwise direction by the pin 1940 when the link is moved forward. The interponent 1938 extends up from the pin 1939 and is provided at its upper end with a rearward directed extension carrying an abutment pin 1942. When the interponent is rocked clockwise, this abutment pin is moved forward of a forward facing abutment formation at the lower end of arm 1943, which extends down from the left-hand end of the bail 1932. During the early part of the last cycle of the multiplication operation, the link 1913 will move rearward and arm 1938 will move clockwise to a position clockwise of that shown in FIG. 38. At this time the bail 1926 will be in a counter-clockwise position and the lower end of arm 1943 will lie below the path of pin 1942. Near the end of the machine cycle, key 307 will be released by link 1653 (FIG. 55) and will rise until stopped by bail 1933 (FIG. 41). Bail 1933 will be lifted and bail 1926 rotated clockwise to lower interponent 1923. Thereafter, just as the machine cycle comes to its end, link 1913 is pushed forward by cam 215. Interponent 1938 is driven

counter-clockwise by pin 1940, and because bails 1932 and 1933 have been raised, pin 1942 strikes the abutment at the bottom of arm 1943 and swings bail 1932 clockwise. Bail 1932 abuts ear 1934 on latch bail 1933 (FIG. 41), swings bail 1933 clockwise and disengages tooth 1936 to release the multiplication (=) key 307. This release of key 307 by bail 1933 occurs at the same time as roller 149 (FIG. 3) of the main clutch control arm 150 begins to drop into the low of the clutch disk 137 to let bar 175 (FIG. 4) also release key 307. As the machine continues, partly on momentum, link 1913 (FIG. 38) completes its forward movement, depresses "CLEAR KEYBOARD" key 308 and thereby initiates another cycle of machine operation. Spring 1937 will restore bail 1926 to its normal counter-clockwise position, and if spring 1925 doesn't lift interponent 1923 immediately, it will do so when link 1913 moves rearward during the "CLEAR KEYBOARD" cycle. Only one cycle is required for the keyboard clearing operation, so that the machine is left with the product in the primary register and the selection mechanism of the machine in the cleared condition. It should perhaps be mentioned that the raising of the multiplication key to engage the cross-member of bail 1933 disables the repeat mechanism so that the selection mechanism can be cleared in the manner previously described.

25. TOTAL AFTER MULTIPLICATION

After the multiplication operation has been completed, the product may be printed by depressing the total key of the machine. Since, at the end of the multiplication operation, the primary accumulator was left in the right-hand position to which it had been stepped during the multiplication operation, in order to have the product printed in the proper ordinal position on the printing tape, it is necessary to return the primary accumulator to the left to align the numerical orders with the position selected for the printed decimal point. Accordingly, when the TOTAL key 318 is depressed, the machine first shifts the accumulator 505 to the left to the correct position for printing the total. In general, one or more orders at the right of the accumulator will be discarded, as was previously described, simply because they will not be aligned with any sectors of the actuator. In order to clear these orders, the printing of the total is followed automatically by a shift of the accumulator to its extreme left position and another total operation with printing suppressed. When the SUB TOTAL key 315 is depressed, the machine similarly shifts to correct alignment for printing, prints a subtotal, shifts to the extreme left and goes through another subtotal operation without printing.

Whenever the TOTAL key 318 or the SUB TOTAL key 315 is depressed, this establishes an operating cycle of the machine, as described above in connection with FIGS. 29 and 31, and, as has been described, depression of either of these keys rocks the bail 827 in a counter-clockwise direction, as viewed in FIGS. 4, 29 and 31, or in a clockwise direction as viewed in FIG. 43, about the bail supporting shaft 155.

When either the TOTAL or SUB TOTAL key 318 and 315, respectively, is depressed, it is latched down in depressed condition by a keeper 1015, engaging a forward projecting tongue 1019 on the total key stem 915, or a forward projecting tongue 1018 on the subtotal key stem 815. The left-hand end of the bail 827 has a rearward extending arm 1945 (FIG. 43), provided at its rear end with a terminal notch receiving a pin 1946 projecting laterally from the rear end of a bail arm 1947. The arm 1947 is one arm of a bail 1948 rockably mounted on the shaft 1408 and having a second arm 1949 extending rearward from the shaft 1408. Depending from bail 1948 is an ear 1948a to the rear of an ear 1944 depending from bail 1777. As was described in connection with the initiation of the operation of automatic multiplication, bail 1777

(FIG. 48) is connected by link 1782 to bail 1762. With this arrangement, when the TOTAL or SUB TOTAL key is depressed (FIG. 43) bail 1948 is rocked counter-clockwise, and ear 1948a pushes against ear 1944 to swing bail 1777 counter-clockwise and bail 1762 (FIG. 48) clockwise. This action lifts roller 1770 to set interponent lever 1768 so that, as in multiplication, printing will be suppressed after the first machine cycle.

Referring again to FIG. 43, the rear end of the bail arm 1949 has a pin-and-slot connection with the forward end of an arm 1950 of a two-armed angular lever 1951 rockably mounted at the juncture of its two arms on the shaft 831 (see also FIG. 18). With this arrangement and as viewed in FIG. 43, when the TOTAL or SUB TOTAL key is depressed, the bail 827 is rocked in the clockwise direction (FIG. 43), the bail 1948 is rocked in the counter-clockwise direction and the lever 1951 is rocked in a clockwise direction.

The lever 1951 has a second arm 1952 upward and rearward inclined from the shaft 831 and is provided at its upper end with a U-shaped formation 1961 providing a downward opening hook 1953 below and somewhat to the rear of the upper end of the lever arm 1952. The bail 266 is rockably mounted on the bail shaft 265 and has an arm 1954 extending forward from the shaft 265 and then down (see also FIG. 68). This arm carries, at its lower end, a laterally projecting pin 1955 which is engaged by the hook 1953 to rock the bail 266 in the counter-clockwise direction, as viewed in FIG. 43, when the lever 1951 is rocked in the clockwise direction, as described above.

The bail 266 has a second arm 1956 extending rearward from the shaft 265 and having, at its rear end, a pin and-slot connection 1957 with a forward projecting arm 1958 of the three-armed lever 1799 (see also FIG. 55).

35 The lever 1799 has an arm 1959 extending up from the shaft 1800, on which the lever is rockably mounted and engageable with a fixed stop pin 1960 to limit rocking movements of this three-armed lever in the counter-clockwise direction, as viewed in FIGS. 43, 55 and 68. The arm 1798 of the three-armed lever 1799 extends down from the shaft 1800 and carries, at its lower end, the pin 1454 which shifts the left shift clutch 1447 (FIGS. 58 and 60). Thus, when the lever 1951 (FIG. 43) is rocked by depression of the TOTAL key or the SUB TOTAL key, the shift mechanism for the primary carriage is 40 placed in left shift condition. The right shift condition established with the depression of the multiplication key will have been discontinued at the beginning of the clear cycle previously described. However, the link 1796 (FIGS. 55 and 5) is connected to the arm 1798 of the lever 1799. When the lever 1799 is rocked (clockwise in FIGS. 43 and 55) to engage the left shift mechanism, the link 1796 is pulled rearward to pull arm 1461 and pin 1460 rearward to disengage the right shift mechanism (FIG. 58) and hold the right shift mechanism disengaged 45 as long as the machine is conditioned for a left shift operation. A link 1989 (FIGS. 43 and 18) is disposed beside the lever arm 1952 and is rockably mounted, at its lower end, on a pin 1982. This pin is carried at the forward end of a forward projecting arm 1983 of 50 a bail 1884 (FIG. 43) rockably mounted on the shaft 275, and having a second arm 1985 extending down from shaft 275 for a purpose to be later described. The link 1989 is provided near its upper end with a longitudinal slot receiving a pin 1990 projecting laterally from the upper end portion of the lever arm 1952. The link 1989 is normally held in a raised position, as shown in FIG. 43. When lever arm 1952 is swung clockwise in response to depression of the TOTAL or SUB TOTAL key, an abutment 1995 at the upper end of link 1989 55 engages a pin 1962 and pushes it forward. Pin 1962 is carried at the lower end of an arm 1963 (FIGS. 44 and 6) which swings on pin 1875. Pin 1962 carries an arm 1964 (FIG. 44) having at its rear end a hook 1966 60 engaging the pin 1884 on the lever 1878, which, through shaft 265 and arm 264, controls the shift clutch (FIGS.

55 and 3). When pin 1962 (FIG. 43) is pushed forward by abutment 1995, it acts through arm 1964 (FIG. 44) to rock lever 1878 (counter-clockwise in that figure) to engage the shift clutch. This action, through the interlock 275, 281, etc. (FIG. 3), prevents the main clutch from engaging. Consequently the initial response to the depression of the TOTAL or SUB TOTAL key is the left shift of the primary accumulator 505.

A bail 1967 (FIG. 44) is rockably mounted on the pin 1875 and positioned above this pin. This bail has a forward projecting arm 1968, carrying at its forward end a laterally projecting pin 1969 which rides on the upper edge of a forward extending tail portion 1970 of the link 1964. When the bail 1967 is rocked in a clockwise direction, as viewed in FIG. 44, the link 1964 is rocked clockwise to disengage the hook 1966 from the pin 1884, thus freeing the left shift mechanism. The bail 1727, previously described in connection with the decimal point mechanism of FIGS. 61 and 63, and rockably mounted on the shaft 1286 has, at its left-hand end, the downward extending leg 1728 carrying at its lower end a downward projecting pin 1972 disposed adjacent the rear edge of the cross-member of the bail 1967. At its right-hand end, the bail 1727 has the downward extending leg 1729 (also FIG. 61) carrying, at its lower end, a rearward projecting pin 1974. The cam detent bracket 1975 is mounted on the upper forward corner of the left-hand end plate 1472 of the multiplier storage unit 510 (FIG. 20). This bracket 1975 carries a double detent including two elements 1976 and 1977 (FIGS. 46 and 61) disposed in side-by-side relationship and provided with downward projecting pointed ends. The element 1976 is fixed, but the element 1977 is rockably mounted and resiliently held in operative position by a compression spring 1978.

The arrangement is such that the element 1977 will slip over the pin 1974 without depressing it when the primary accumulator carriage is moving from right to left (FIG. 46), but will operatively engage this pin when the carriage is moving from left to right. The fixed element 1976 will operatively engage the pin 1974 in either direction of movement of the carriage. The purpose of the two detents is to stop the carriage at the proper ordinal position regardless of the direction of movement of the carriage.

When the primary accumulator 505 has been shifted to the left to the position in which the detent 1976 (FIG. 46) is brought against the pin 1974 (FIGS. 61 and 44), the bail 1727 is rocked in the counter-clockwise direction, as viewed in FIG. 44. As was previously described in connection with the decimal point mechanism of FIGS. 57 and 61, the position of bail 1727 at the end of a multiplication operation depends on the setting of lever 1680 and the operation of lever 1736 in response to the entry of digits after the decimal point. As soon as the pin 1974 is moved under the detent 1976 and the bail 1727 is rocked, the pin 1972 (FIG. 44) is moved forward, rocking the bail 1967 in the clockwise direction, as viewed in FIG. 44, and moving the lever 1964 to release the pin 1884 and discontinue the left shift operation of the machine by disengaging the shift clutch (FIG. 45). When the shift clutch is disengaged, the main clutch will be engaged and the machine will now print a total or subtotal, the product of the multiplication which has been entered into the primary accumulator. The function of hook 3001 is to engage pin 1884, swing lever 1878 (counter-clockwise in FIGS. 43 and 44) for compressing shift-clutch link 263, disengage pin 1884, and let hook 1966 re-engage pin 1884. When the main shaft 135 and cam 217 are in the full-cycle position, hook 3002 is farther forward than the most forward position of the hook portion of lever 1966.

When lever 1951 is being rocked (clockwise in FIG. 43) by the depression of the TOTAL or SUBTOTAL key, pin 1990 permits hook 3001 to rise, but because cam 217 is in full-cycle position, the hook merely abuts the

lower side of pin 1884, which is being drawn forward by hook 1966 for rotating lever 1878 (counter-clockwise in FIGS. 43 and 44). This action, incidentally, also lowers pin 1882 against abutment face 3008 to limit the rise of hook 3001. Later, during the shift operation, hook 1966 is rocked by the motion of bail 1727 (FIG. 44) for releasing pin 1884 and thereby terminating the shift operation. Then the main clutch engages for performing the total or subtotal-taking cycle. Early in the cycle, cam 217 moves hook 3001 rearward, and hook portion 3002 rises behind pin 1884. Just before the end of the cycle, arm 1885 swings forward so that hook 3001 moves forward and rocks lever 1878 counter-clockwise for again compressing shift-clutch link 263. As hook 3001 completes this forward motion, pin 1882 moves down against an abutment face 3008 to push hook 3001 down for disengaging pin 1884, and hook 1966 drops behind that pin 1884.

During the latter part of this total (or subtotal cycle) stud 1771 (FIG. 48) has engaged interponent lever 1768 for rocking the print blocking lever 1338 clockwise, where it is held in print-blocking position by latch 1772.

At the end of the total (or subtotal) cycle, the resilience of strut 263 (FIGS. 45 and 3) engages the shift clutch for resuming the shift of the accumulator 505 to the left under control of hook 1966. During the first shift cycle of this resumed shift operation, the resiliently supported element 1977 (FIG. 46) will slip over pin 1974 without rocking bail 1727.

As the accumulator 505 is shifted into its leftmost position, a bracket 3007 (FIG. 61) abuts pin 2289 and moves it toward the left. Collar 2288 rocks lever 2286, and since latch 2294 is engaged, also rocks lever 2281. This action lifts pin 2282 from teeth 1731 and permits spring 1757 to return bail 1727 to its leftmost, or home, position.

A ramp 1020 on the lower front portion of the accumulator carriage 505 (FIGS. 22 and 65) engages a pin 2257 upstanding from the upper end of a lever 2255, and rocks this lever in a clockwise direction, as viewed in FIG. 65, as the shiftable accumulator reaches its extreme left position. Lever 2255 is rockably mounted intermediate its length on transverse shaft 2256 and has an arm 2254 extending down from shaft 2256, and connected at its lower end by means of a link 2253 with the lower end of the depending arm 1986 of the bail 1984. This rocks the bail 1984 in the clockwise direction, as viewed in FIG. 43. Downward movement of arm 1983 lowers link 1988 and pulls abutment 1995 below pin 1962, thereby releasing hook arm 1964 to move rearward to let lever 1878 (FIG. 44) rotate clockwise for disengaging the shift clutch. Thereupon, the main clutch re-engages and the machine goes through another TOTAL or SUBTOTAL cycle. Lowering of link 1989 lowers a pin 1991 against hook lever 3001 to prevent lever 3001 from again engaging pin 1884 so that the shift operation will not be resumed again.

Since print blocking lever 1338 (FIG. 48) is held in print-blocking position by latch 1772, this second total or subtotal is not printed. If it was the TOTAL key that was depressed, this non-printing total operation serves to clear from the accumulator, the values in those rightmost orders that were discarded from the printed total. If it was the SUBTOTAL key that was depressed, this last, non-printing subtotal operation accomplishes nothing.

A trigger member 1981 (FIG. 43) is slidably mounted for vertical movement on the bar, or lever 1986, pivotally mounted at its upper end on lever 1885 which is cam-actuated to rock forward just before the end of each cycle of the main shaft 135. The forward edge of lever 1986 engages a fixed fulcrum pin 1988. The lower end of bar 1986 and the trigger member 1981 are moved rearward as lever 1986 rocks against pin 1988, each time the lever 1885 rocks forward.

Trigger member 1981 is mounted at its upper end on pin 1982 carried at the forward end of bail arm 1983 and is moved down when bail 1984 is rocked clockwise with lever 2255 (FIG. 65) when ramp 1020 engages pin 2257 as the shiftable accumulator reaches its terminal left-hand position. This engages the trigger member 1981 in front of a hook formation 1980 (FIG. 47) on the rear end of a link 1026. When the trigger member 1981 is moved rearward by levers 1885 and 1986, this will move link 1026 rearward. Link 1026 extends longitudinal of the machine immediately below the base plate 100 and is supported near its rear end by a pin 2252 for movement forward and rearward of the machine. At its front end, link 1026 is connected by a secondary link 1025 to the lower end of an arm 1024 depending from shaft 1017 (FIG. 29). Rearward movement of link 1026 thus rocks shaft 1017 in a counter-clockwise direction, as viewed in FIG. 29 (clockwise in FIG. 43), and rocks the keeper 1015 to release the latched-down TOTAL or SUB TOTAL key.

Accordingly, near the end of the last cycle of the main shaft, that is, during the non-printing, TOTAL or SUB TOTAL cycle, trigger 1981 (FIG. 43) moves rearward to release keeper 1015, and at the end of that cycle the TOTAL (or SUB TOTAL) key is released. The release of the key releases bail 1948, which releases both lever 1951 (FIG. 43) and bail 1777 (FIG. 48). The release of bail 1777 disengages hook 1772 and lets the print-blocking lever 1338 return to normal. The release of lever 1951 (FIG. 43) lets lever 1799 return to normal so that the left shift pawl 1451 is returned to its neutral position (FIGS. 58 and 60). The operation ends with the accumulator 505 in its leftmost position. If the operation was a TOTAL, the accumulator will be clear. If the operation was a SUB TOTAL, the accumulator will contain the complete value including the orders that were "discarded" from the printed value, so that another key depression of either the TOTAL, or SUB TOTAL, key will cause the complete product to be printed. Alternatively, a depression of the BACK TRANSFER key 317 with the TOTAL or SUB TOTAL key will enter the whole product into the multiplier register 510 for use as the multiplier in another operation. But since this procedure can enter a multiplier with excess decimal places, without operating the decimal point mechanism of FIG. 61, the next product may have its decimal point printed in the wrong place.

When the TOTAL or SUB TOTAL key is depressed with the accumulator already in its leftmost position, as after addition or subtraction, abutment 1995 or link 1989 (FIG. 43) is held below pin 1962 because ramp 1020 (FIG. 65) holds lever 2255 in its clockwise position in that view. Consequently, the shift clutch is not put into operation and the machine goes immediately into the total or subtotal cycle and goes through it only once.

When taking a total, but not a subtotal after multiplication, the value may also be entered in the fixed, or grand total, accumulator 489 (FIG. 16). As previously described, key 305 (FIGS. 2 and 7) is set for either a positive or negative entry before the TOTAL key 318 is depressed. Then during the first cycle of shaft 135, when the total is taken and printed, the total will also be entered in the grand-total accumulator in alignment with the printed decimal point. Near the end of that cycle, pin 1009 on cam 233 (FIG. 2) will rotate bell-crank 1005 (clockwise in FIG. 2) for restoring key 305 to its central, neutral position, so that, when the non-printing total operation later clears the "discarded" orders of the primary accumulator 505, the values from those orders will not be entered in the grand-total accumulator. From the grand-total accumulator, the product (without the discarded orders) can be transferred to the multiplier register for use in another multiplication operation, with the decimal point printed in the correct position.

26. DIVISION

A number in the primary accumulator may be divided by a divisor in the selector by repeated subtraction and shifting. The net subtractions are counted, order by order, into the storage unit 510. The resulting quotient may then be read out and printed by a DIVISION TOTAL operation initiated by key 314 (FIG. 7), as previously described.

The operations of entering the dividend, aligning the divisor with the dividend, and performing the division are described in detail in the parent application, Serial No. 123,085 previously referred to.

I claim:

1. In a calculating machine, an input value selection mechanism, carriage means movable transversely of the machine, power-operated means effective to impart transverse movements in both directions to said carriage means, a primary accumulator constituting a combined product and dividend register mounted on said carriage means, a combined multiplier-storage and quotient-receiving mechanism mounted on said carriage means in ordinal alignment with said primary accumulator, means for controlling said machine for performing multiplication and division, a printing mechanism fixed in position transversely of the machine, a grand total accumulator fixed in position transversely of the machine, and power-operated transmission mechanism effective under selective manual control to transmit an input value from said selection mechanism either additively or subtractively into said primary accumulator or additively into said multiplier storage mechanism, to transmit a total value or a product from said primary accumulator to said printing mechanism and selectively to said grand total accumulator at the same time, to transmit a grand total value from said grand total accumulator to said printing mechanism, and to transmit a quotient from said quotient receiving mechanism to said printing mechanism and selectively to said grand total accumulator at the same time.
2. In a calculating machine, a printing mechanism fixed in position relative to the machine, a ten-key input value selection mechanism having a selection unit movable transordinally of said printing mechanism, an accumulator mounted for movement transordinally of said printing mechanism, power-operated means effective to move said accumulator one order per machine operating cycle in either transordinal direction, manually actuated total-taking conditioning means effective to condition said power-operated means to move said accumulator to the left, and power actuated means effective to read out and print the total value in said primary accumulator when said primary accumulator has been moved to its terminal left-hand position.
3. In a calculating machine, an input selection mechanism, printing mechanism fixed in position transversely of the machine, actuating mechanism coordinal with said printing mechanism and fixed in position transversely of the machine, an accumulator mounted for movement transordinally of said actuating and printing mechanisms, power-operated shifting means effective to move said accumulator in both directions, storage mechanism mounted on said accumulator for transverse movement therewith and movable on said accumulator into and out of engagement with said actuating mechanism, total control means for causing said actuating mechanism to extract a value from said accumulator and enter it into said printing mechanism, power-operated servo mechanism effective to move said storage mechanism into engagement with said actuating mechanism for entering a value from said actuating mechanism into said storage mechanism, and manually actuated control means effective to first enable said power-operated shifting means to return said accumulator and storage mechanism to their terminal left-hand position if displaced therefrom and to then

enable said total control means and said servo mechanism.

4. In a calculating machine having

- (1) a number selector including a selector carriage that moves from a home position order-by-order during the entry of a number therein,
  - (2) selector-homing means for returning said selector to its home position during an operating cycle of said machine,
  - (3) a normally operable selector-clearing key for initiating an operating cycle of said machine for returning said selector to its home position,
  - (4) digitation means for entering the number in said selector into a calculation,
  - (5) control means for causing said machine to perform a plural-cycle calculation and to repeatedly activate said digitation means therefor,
  - (6) main operating mechanism including a cyclically operable cam for driving said selector-homing means and said digitation means, and
  - (7) a manually operable calculation key for actuating said control means for causing the machine to perform said calculation,
- said control means including means
- (a) for disabling said selector-homing means during said calculation,
  - (b) for holding said calculation key in its operated position during the calculation, and

- (c) for returning said key to its unoperated position at the end of the calculation,
- the improvement comprising a power-setting linkage driven by said main operating mechanism for moving said selector clearing key to its operated position, said linkage including an interponent normally in an inactive position for interrupting said linkage and movable to an active position by said calculation key as said key returns to its unoperated position.
